UNITED STATES PATENT OFFICE

2,200,351

BUSINESS DICTATING SYSTEM

Cecil L. Whitehead, Pasadena, Ray M. Chenoweth, West Los Angeles, Emmett M. Irwin, Richard H. Duval, Walter P. Huntley, and Bruce H. Rule, Pasadena, and George E. Lewis, Alhambra, Calif., assignors to C-W-B Development Co., Los Angeles, Calif., a corporation of California

Application November 23, 1938, Serial No. 241,988

29 Claims. (CL. 179—6)

Our invention relates to business dictation systems and has particular reference to a system which embodies a plurality of recording and reproducing machines, any or all of which are 5 available for the common use of any number of dictators and any number of transcribers.

In present day dictation machine systems the most commonly known include a recording machine, usually disposed adjacent to the dictator 10 upon which he records his dictation, while the transcription of the dictated material is accomplished upon a different and separate machine located adjacent to the transcriber, and requires the transfer of the dictated records and the transcribed or reconditioned records back and forth 15 between the locations of the various machines. These systems require individual machines for each user which are completely idle when not being used by the individuals to whom they have 20 been assigned. Such dictating machines have the further disadvantage that as soon as one of the records has been filled with dictation it is necessary for the dictator to remove said record from the machine and substitute a clean record 25 in order to continue the dictation.

Considerable care and effort is involved in the changing of the records as well as in maintaining notes, reference slips, tags, cards or other record identifying devices in order to co-relate a 30 predetermined sequence of records which constitutes one complete series of parts of the dictated material, in order to permit the transcriber to pick such records in the same sequence in which material was dictated upon them.

A system has been proposed whereby the dictation recording and transcribing machine itself 35 may be located at a point remote from the dictator and from the transcriber and arranged to be commonly used by both of them. For example, a system of this character has been illustrated 40 and described in the co-pending application Serial No. 53,396, filed December 7, 1935, of Ray M. Chenoweth, Emmett Irwin and Walter P. Huntley. Such a system, however, allows a single 45 machine to be available only to one dictator and one transcriber so that in order to carry the load of any office which includes any considerable 50 number of dictators and any considerable number of transcribers it is necessary to provide a single recording and reproducing machine unit for 55 each dictator who expects to use the machine.

In order to provide sufficient machine capacity or sufficient record capacity for a busy office it is necessary not only to provide individual machines or machine units for each of the dictators but to

arrange for the removal, changing of, or replenishing of the record supply, so that when one of the records has been filled another record is available for dictation of the dictator. Again, however, it is essential that some manner of determining the sequential order of the records be provided in order that the transcriber may follow the same sequence of records in transcribing the dictated material. 5

It will be readily appreciated that the enormous 10 machine capacity which must be provided when individual machines are assigned to individual dictators constitutes a great waste, particularly in view of the fact that during the ordinary business day a dictator will only use his machine for 15 a relatively small portion of the day and that during all other portions of the day this machine will lie idle since it is unavailable to any other person who would like to dictate material 20 thereto.

Another disadvantage readily apparent in the present dictating machines and dictating machine systems is that the user of the machines must invest considerable amounts of money in equipment as well as in labor in order to handle 25 a relatively small amount of actual dictation and transcribed material.

A typical example is that of a small business office which must employ a stenographer, or at 30 least a typist, and then invest in the necessary dictation and transcription machinery in order to handle what ordinarily constitutes an extremely small amount of business dictation. Likewise, in a relatively large office the investment in the necessary machines required for a 35 large number of dictators and a large number of transcribers mounts proportionately with the number of dictators employing the machines and further requires costly space within the offices for the housing of the machines and equipment. 40 Any attempt to employ present day dictating machines by more than one dictator necessitates the transporting of the machine from dictator to dictator with the attendant risk of damage to the machine and the loss of time and labor in so 45 doing.

It is, therefore, an object of our invention to provide a dictating system wherein a relatively small number of recording and reproducing machine units may be located at any centralized 50 point with connections therefrom to a relatively large number of dictators and transcribers, either located within the same office, or in independent offices, or in independent buildings, and in which any dictator may at any time dictate material to 55

the group of machine units, and in which any one of the units which is not being used or occupied at that time will be readily available to such dictator.

5 Another object of our invention is to provide a dictation system, as set forth in the preceding paragraph, wherein the transcription of the material dictated by any dictator may be privately transcribed by the transcriber in his own office 10 or in a stenographic or transcription pool particularly designated by the dictator to transcribe his material.

Another object of our invention is to provide a system of business dictation as set forth in the 15 preceding paragraph wherein the individual capacity of the recording medium on one machine unit does not in any way limit the length or amount of the dictation which may be continuously made by a dictator but in which, as soon as 20 the recording medium on one unit has been filled with dictation, the system will automatically select some other unit in the group and transfer the controls from the dictator to the new unit and permit him to continue the dictation on the 25 new unit without interruption and without necessarily allowing knowledge of such transfer to be transmitted back to the dictator.

Another object of our invention is to provide a dictation system as set forth in the preceding 30 paragraph wherein the transcriber when starting to transcribe a dictator's work will be automatically connected to that machine unit of the group which contains the start of his dictated material, and wherein the transcriber will automatically 35 be transferred from unit to unit in exactly the same sequence which was previously followed by the dictator in placing the material on the record.

Another object of our invention is to provide a business dictation system of the character set 40 forth wherein any individual dictator may dictate material which will include the recording media on a sequence of a plurality of machine units, and wherein said dictator may dictate additional material on a new and different sequence 45 of machine units, the dictator thus setting up a series of sequences.

Another object of our invention is to provide a system of the character set forth in the preceding paragraph in which the transcriber may select 50 which of the sequences she will transcribe first, and in which the transcription apparatus will automatically follow the sequence of machine units and recording media set up for that particular sequence of dictation.

55 Another object of our invention is to provide a system of the character set forth in the preceding two paragraphs wherein while transcribing one sequence the transcriber may interrupt the transcription, select any other sequence, and 60 then return to the point in the first sequence at which she stopped, without altering or otherwise disturbing the first sequence or losing control for the transcribing of the recorded material thereon.

65 Another object of our invention is to provide a dictation system as set forth hereinbefore wherein during the dictation of any material a dictator desiring to immediately get out some "rush" work may select one of a special group of 70 machine units reserved for "rush" or emergency work, dictate thereon such emergency communication, and have the same immediately transcribed and without interrupting the sequence of machine units comprising the interrupted dictation.

Another object of our invention is to provide a dictation system as set forth in the preceding paragraphs wherein during the dictation of any material which may extend through a sequence of machine units, the dictator may at any time 5 play back to himself any portion of the dictated material in that sequence whether upon the record on which he is then recording or upon another record in the same sequence and in which the play-back of material will follow the same sequence of records as that followed in the original 10 dictation of the material.

Another object of our invention is to provide a dictation system as set forth wherein the dictator may play back any of the previously dictated material on any of the preceding records of the sequence, and may immediately resume dictation at the point where he left off without 15 delay.

Another object of our invention is to provide 20 a dictation system as set forth wherein the actual resumption of dictation by the operator automatically places the machine in condition to resume recording at the point at which it was interrupted.

Another object of our invention is to provide a system of the character set forth, wherein the transcriber at any point during the reproduction of the material for transcription may return to earlier dictated material or proceed to later dictated material and automatically return to the point at which the transcription of the material was interrupted.

Another object of our invention is to provide a dictation system of the character described in 35 the preceding paragraphs wherein all of the voice transmission functions and all of the necessary control functions and all of the functions permitted by the machine unit structures may be performed over a pair of conductors extending 40 between the transcriber or dictator and the centralized location of the machines.

Another object of our invention is to provide a dictation system as set forth, in which at any time the total number of machine units then in use by dictators, by transcribers, or awaiting transcription and reconditioning may be indicated at one or more locations to determine at any time the load on the installation.

Other objects and advantages of our invention 50 will be apparent from a study of the following specification read in connection with the accompanying drawings, wherein

Fig. 1 is a simplified diagrammatic illustration of one embodiment of our invention as applied to 55 two offices, one having a plurality of dictators and a plurality of transcribers and a second office having a single dictator and no transcriber and a third office which may be designated as a transcription pool.

Fig. 2 is a perspective view illustrating, somewhat diagrammatically, one form of recording and reproducing machine which may be employed in the practice of our invention.

Fig. 3 is a diagrammatic view of the driving 65 mechanism which may be employed to drive the recording medium shown in Fig. 2; to drive the recording and reproducing head and the instruction head of the machine shown in Fig. 2; and to operate a measuring device which measures the 70 displacement of the head from the point of last recording or last transcription upon the recording medium.

Figs. 4A, 4B, 4C, 4D, to 4J, together constitute a diagrammatic view of one form of control 75

system which may be employed in the practice of our invention and illustrating the system as adapted for the number and location of dictators, transcribers, and machines shown in Fig. 1.

5 Figs. 4K, 4L, 4M, 4N, 4P, 4R, 4S, and 4T illustrate specific electrical symbols employed in the diagrammatic view referred to in the preceding paragraph.

10 Fig. 5 is a diagrammatic view of one form of selector switch peculiarly adapted to the practice of our invention as illustrated in Fig. 1 and Figs. 4A, etc.

15 Fig. 6 is a diagrammatic view of a foot operated selector control switch which may be employed at the transcriber's station for performing certain of the control functions necessary in the system shown in Figs. 1 and 4A through 4J.

20 Referring to the drawings, we have illustrated in Fig. 1 the adaptation of our dictating and 25 transcribing system to a plurality of offices including an office designated as I in which is presumed to be two dictators A and B and in which is presumed to be two transcribers C and D. Office I may, of course, include any number of 30 dictators each of whom may be located in his own private office in the suite of offices embraced within office I. Also, any number of transcribers may be considered as embraced within office I, each of whom may be located in individual offices 35 in the suite or may be located in a common stenographic or transcription room within that suite of offices. Also, it will be understood that office I may be located in one building and other offices connected to our system, as hereinafter described and illustrated, may be located in other buildings or in another part of the same office building.

40 We have also illustrated in Fig. 1 another office designated as II in which is located a dictator X, who for purposes of illustration is presumed to be a small professional or business man whose ordinary load of dictation does not require the full time services of a stenographer, transcriber, or office girl, and who may therefore depend upon having his dictation transcribed by a public or a private transcription pool maintained at any suitable location either in the same building with office II or in some other building. We have illustrated such transcription pool or public transcription service as being located in a separate office designated as III in which is located a transcriber designated as Y. As will be understood by those skilled in the art, for simplicity of description herein and the more ready understanding of our invention without complication, we have selected for office I only two transcribers and only two dictators and have selected for office II only a single dictator and for office III a single transcriber.

45 In order to assist in the understanding of our system as illustrated in Fig. 1 we have boxed office I in dashed lines and office II in another box of dashed lines, while office III is similarly indicated within a box of dashed lines to emphasize the segregation of and separation of the offices, one from the other.

50 While a complete illustration of the apparatus required, and the manner of operating our complete system will be more fully described herein-after, in Fig. 1 we have schematically illustrated the equipment necessary for the recording and 55 reproducing of the dictated material and for the selection, segregation and control of the recording and reproducing machines located in a centralized location or station designated as IV and

illustrated in Fig. 1 as enclosed within a box of dashed lines. The actual recording and reproducing machines may be, and are illustrated herein as, located in the central office.

60 For simplicity of illustration herein and also for illustrating the manner in which ordinary telephone transmitters, receivers, and selecting equipment may be utilized in the practice of our invention, we have throughout the following disclosure so arranged the various circuits and control equipment as to utilize as far as possible well known telephone apparatus. Thus, in Fig. 1 we have illustrated diagrammatically at each of the dictators' stations the necessary dictators' equipment as including a rectangular box bearing the 65 legend or reference character identifying the particular dictator who uses the equipment. Thus, in office I we have illustrated dictator A's position by means of a rectangle marked A upon which is illustrated a telephone dial and associated with which is represented an ordinary "French" style hand telephone set.

70 As a matter of fact, as will appear more fully hereinafter, the telephone hand set and dial equipment employed may be the usual hand 75 telephone set and dial equipment which the dictator will use in making ordinary telephone calls. Such "French" hand telephone set is in common use and the mechanism thereof will be readily understood by those skilled in this art.

75 Also each of the transcribers is provided with suitable listening equipment and control equipment whereby she may listen to previously dictated material while transcribing same and also control the various operations of our system and 80 machine. For simplicity of illustration we have again selected as the mechanical equipment associated with each of the transcribers an ordinary hand telephone set including the dial thereof. Associated with this hand telephone set 85 is a receiver head set of common construction which will permit her to listen to the material and yet have both hands free for manipulating the typewriter and other devices.

90 We have also shown in addition to the telephone equipment and head set associated with each of the transcribing stations C, D, or Y respectively, a foot control switch by which the operator during transcription of the material may control all of the necessary start-stop operations 95 of the machine, the forward and rearward movement of the carriage of the machine whenever it is desired to play back or play over some of the material previously listened to and transcribed or to listen to material further along on 100 a part of the record to which she has not arrived in the normal transcription thereof.

105 Within the confines of the central station or centralized location we have illustrated for purposes of this description a series of dictation and transcription machine units sufficient to carry the assumed load of dictation of all of the dictators and the transcribing load of all of the transcribers, there being illustrated ten of such recording and reproducing machine units numbered respectively 1, 2, 3, 4, 5, 6, 7, 8, 9, and 10. 110 Each of these machine units may be constructed as illustrated in Figs. 2 and 3 or may be machines of the character set forth in the co-pending application of Ray M. Chenoweth et al. hereinbefore referred to.

115 It will be understood by those skilled in the art that the particular construction of the recording and reproducing machine units is not material to the operation of our system as disclosed 120

herein, other equivalents of such units being readily substituted for the particular machine units described herein, provided that such units are adapted to include a recording medium upon which dictation may be recorded and from which dictation may be reproduced. Such machines much include a recording device which may receive sound undulations from a dictator and record them upon the record while the same or other devices may be employed for reproducing the undulations previously recorded upon the record and transmitting them to either the dictator's playback system or the transcriber's reproducing system, and means for reconditioning the recording medium for further dictation.

It will be further understood that the particular character of recording medium employed in our system is not material, since it will be readily understood that the present well known wax recording medium may be employed or a magnetic recording medium may be employed, both of which forms are illustrated in the said co-pending application, Serial No. 55,396 hereinbefore referred to, and in the co-pending application of Walter P. Huntley et al., Serial No. 213,638, filed June 14, 1938.

At this point it might be well to note that it is desirable that each of the machine units should be provided with suitable mechanism upon which errors or end of letters or end of other elements of dictation may be suitably registered in order to assist and guide the transcriber with suitable instruction in the transcription of the recorded material. Such a system of recording, reproducing and transcribing such instructions is fully illustrated in the co-pending application of Ray M. Chenoweth et al., Serial No. 53,396. Or, as will be hereinafter more fully described, the instruction material may be suitably recorded in superimposed relation upon the same recording medium which receives the dictated material. Each of the machines or machine units must also include suitable means for starting and stopping the actual application of the dictated material to the recording medium or the actual reproduction of the material from the recording medium under the control of the dictator or transcriber and may be accomplished in a manner to be more fully described herein-after.

Machines illustrated in Fig. 1 as machines 1, 2, 3, 4, 5, 6, 7, 8, 9 and 10 may be considered as the "load carrying" machine units allocated to accommodate the ordinary dictation material associated with any of the subscribers to the system, such as all of the dictators in office I, all of the transcribers in office I, the dictator in office II and all of the transcribers in office III and in any other offices connected into the system.

It will also be noted from an inspection of Fig. 1 that we have illustrated two additional machine units EAB and EX which may be considered as "emergency" units allocated to receive emergency or "rush" messages, telegrams, or other material for transcription which by reason of the urgency of these communications require immediate transcription.

Note, however, that all of the machine units 1-10 inclusive which are available to all of the dictators A, B, and X and to all transcribers C, D, and Y, as well as the emergency machine EAB allocated particularly to office I for the use of the dictators A and B and transcribers C and D in that office, and the emergency ma-

chine EX allocated to and available for use particularly by dictator X in office II and transcriber Y are located at the central station or centralized location and may be selected, controlled, and operated over a system of wires interconnecting the various offices with the centralized location or central office in much the same manner as various telephone subscribers are now interconnected with the central office or the central location in which the selecting and controlling mechanisms may be located.

Again, as will hereinafter more fully appear, the particular equipment required to be located at each of the subscriber's offices I, II, and III, may be so arranged that only a single pair of wires need extend between each of these subscriber's offices and the central station equipment, and, it will appear from the inspection of the complete wiring diagram shown in Figs. 4A through 4J that the same pair of telephone wires required to connect the several subscribers' offices to the regular telephone exchange may be employed as the necessary interconnection and control of the wires for controlling all of the functions of our dictation system. Utilizing this feature of our invention permits all of the control equipment, the selector switches and other relay equipment to be located in the central office. However, as will be understood, where it is not desired to locate all of the control equipment in the central office, certain portions thereof may be located in the various offices, I, II, and III, in which event it will be necessary to provide a greater number of interconnecting wires between the location of the actual recording and reproducing machines and the particular subscriber's offices, I, II and III.

In order to obtain a more ready understanding of our invention and to more readily understand the detailed description of the various control and operating devices in the performance of the functions included in our system, we have illustrated in Fig. 1, briefly and diagrammatically, sufficient portions of the complete system to permit of a discussion of certain assumed operations which may be performed and the manner in which this performance is achieved.

In Fig. 1 we have made no attempt to show all of the control apparatus which will be located at the dictator's station by which the several functions of the machine and the system may be controlled by the dictator, but have merely indicated a rectangle bearing the legend A which is assumed to include all of the control apparatus necessary to be located adjacent to or within the confines of the office associated with dictator A. The actual speaking and listening apparatus to be employed by dictator A is illustrated diagrammatically as a "French" hand phone set such as is commonly employed in telephone installations and which allows the dictator to speak and have his dictation transmitted for recording to the several machines while, through the receiver portion of the instrument, he may listen to play-back of any of the material which he desires to have repeated to him.

In like manner, a similar rectangle and "French" hand set is designated by the reference character B as constituting the equipment necessary for dictator B. Associated with the transcribers C and D we have also illustrated a rectangular box which will be assumed for the purposes of the following brief description to include all of the control apparatus which may be necessary for each of the transcribers C and D

respectively, the listening apparatus associated with each of these transcribers being indicated as a receiver head set such as is commonly employed by telephone switchboard operators. Also 5 dictator X has associated with him a rectangular box indicating the various control apparatus associated with his station and a "French" hand set representative of the transmitting and receiving equipment by which he may dictate or 10 listen to the play-back of material.

Transcriber Y is likewise indicated as having located at office III the necessary control and listening equipment by which she may listen to the material to be transcribed.

15 Assuming that at the start of the operation dictator A desires to dictate material for record and assuming at this time that none of the several machines 1-10 inclusive is occupied, dictator A may pick up the transmitter-receiver apparatus whereupon an automatic selector somewhat similar to the selector employed in telephone systems will immediately start into action to connect dictator A with any one of the unoccupied machines 1-10. The initial selector for accomplishing this selection is designated as selector AS, the movable arm of which will pass over several contacts until it arrives at a contact connected to and corresponding to one of the machines which is not occupied. We have assumed 20 that machine 1 will not be occupied and the selector AS will therefore stop with its movable contact member on the first point or contact of this selector. This will connect the dictator A directly with machine 1 through the interconnecting wires extending from the control box for dictator A comprising a pair of conductors illustrated by lines 106-107. Lines 106-107 associated with dictator A extend to the selector AS through normally closed contacts AEL on a relay 25 which will determine whether or not the dictator will be connected to any one of the regular dictating machines 1-10 inclusive, or to the emergency machine EAB.

In our assumed operation the dictation by dictator A is regular dictation and not an emergency communication so that the contacts AEL will be assumed to be closed.

The connection of the dictating machine 1 will be continued through the selector AS and 30 through a conductor associated with the first contact on this selector which interconnects with a machine-multiple group of conductors or cables indicated at M. It will be understood from an inspection of Fig. 1 that the 35 multiple group of conductors or cables M will have a connection as indicated at N with the first point on a machine selector 1S associated with dictating machine 1. The connection, however, with machine 1 is made independently 40 of the movable arm of this selector so that the dictator will now be directly and immediately connected to the machine 1. This not only connects the transmitter and receiver for dictator A with machine 1 to permit him to record his 45 dictation thereon but also interconnects dictator A's machine control apparatus with the apparatus of machine 1 by which its several functions are to be controlled, and thus he may proceed with his dictation of the desired material, starting and stopping the machine as he desires for recording material upon the machine in much 50 the same manner as he now starts and stops the ordinary dictating machine.

He also may control the necessary play-back 55 devices by which he may play back to himself

any of the previously dictated material, the detailed description of the construction and operation of which will be set forth hereinafter.

Assuming now that the particular piece of material which the dictator is attempting to record upon the dictation system of our invention exceeds the normal length or capacity of one of the machine units or recording media associated with machine 1, it is entirely unnecessary for dictator A to know or realize that the material he has dictated exceeds or has reached the end of the record on machine 1. As will be more fully described hereinafter the approach of the recording device or recording head of machine 1 to the end limits of this machine will 15 automatically set into operation suitable control apparatus, more fully described hereinafter, which will cause the connections from the dictator's station A to be transferred to a new and unoccupied one of the machines 1-10 inclusive. 20 Assuming for the example herein that for some reason machine 2 is occupied or is unavailable at the time the dictator reaches the end of the record on machine 1 but that machine 3 is vacant and ready to take dictation, the close approach of the recording head on machine 1 to the end limit of its operation will actuate the selector 1S to cause this selector to seek an unoccupied machine.

The movable arm of the selector 1S will proceed from one end of its travel toward the opposite end; crossing the several contacts which, as hereinbefore described, are connected with the several machines in the group 1-10; until it arrives upon a contact associated with an unoccupied machine. The selector will then stop on such contact, thus completing direct connection of the dictator A with the new machine. Assuming that machine 3 is the newly selected machine for continuation of the dictation, the connection 40 to machine 3 now will be made through the same group of conductors or cables M and N, through jumpers P on machine selector 1S, and thence through the movable contact of this selector to one of the group of conductors or cables N' back 45 to the machine-multiple group of conductors M. Since machine 3 is connected to this same machine-multiple group of conductors the connection of machine 3 will now extend downwardly through a conductor or group of conductors indicated at Q. All of this selection of machine 50 3 will occur in a sufficiently short time so that there is no need whatever for the dictator A to interrupt the continuous flow of his dictation. As will be understood by those skilled in this art, 55 and in the art of telephony, selector equipment is now available which selects at the rate of approximately seventy per second so that no unnecessary time is lost and no interruption of the dictation is required. The dictator A, now being 60 connected with machine 3, continues with his dictation.

Assuming now that the material which the dictator is engaged in dictating exceeds the capacity of machine 3, transfer of connections from 65 the dictator's station A will be made to a still further machine in the group 1-10 in the same manner as was described for the transfer from machine 1 to machine 3. Assuming for the sake of this example that the next available machine 70 in the group to which the dictator was connected is machine 5, the connections to this machine will be made through the machine-multiple group of conductors M and through selector 1S for machine 1, thence through selector 3S for 75

machine 3 and back through the machine-multiple group M to the selector 5S for machine 5 so that the dictation may be continued as hereinbefore described.

- 5 At this point it should be noted that from the time the dictator A lifts his telephone set from its hook until he has reached the end of this particular piece of dictation, the dictator has been permitted to dictate uninterruptedly, and
 10 to play back at any time any of the previously dictated material. The amount of dictation of any one piece of dictated material may be substantially unlimited, the dictator neither having knowledge of, nor any responsibility for the total
 15 number of records or machines upon which he has dictated nor the order in which these several machines have been selected to receive the dictation.

As will be more fully pointed out hereinafter
 20 in the detailed description of the wiring diagram, the interconnection of machines 1, 3 and 5 for this piece of dictated material is made not only through the machine selector group 1S, 3S and 5S but also by employing additional levels
 25 on the selectors 1S, 3S and 5S. The particular equipment which is actuated by the approach of the recording head on each of the several machines to either of its limits, "start" or "end", is so interconnected that should the dictator A
 30 desire to play back any portion of the previously dictated material he may do so merely by operating suitable play-back control devices, and the listening equipment at his station will be connected to the proper machine and at the proper
 35 place which he has selected for initiating the play-back, and the machine reproducing devices will be suitably controlled to play back the material to him. When, however, he has completed such play-back as he desires he again conditions
 40 his control apparatus for resumption of dictation so that he may immediately resume dictation upon the last machine in the sequence of machines to which he has been connected, and he therefore continues his dictation from that point
 45 in the same manner as though he had not interrupted the same for play-back purposes.

When the dictator arrives at the end of any particular piece of dictated material he may immediately start a new piece of dictation material or, in order to permit the transcribers to immediately have access to the material just completed, he may release all of the machines employed for the dictation of this first piece of material by merely restoring the hand phone set to its support. He may then immediately start a new piece of dictation material and in starting the same the lifting of the hand telephone set from its support will cause the selector AS to immediately seek a new machine which is not at that moment occupied by some other dictator subscribing to the system or which machine is not then awaiting transcription of material previously recorded thereon. The selection of the first machine in the new group or sequence of machines upon which he will record the second piece of dictated material will occur as described for the selection of the first sequence of machines 1, 3 and 5. The dictator may therefore proceed with the
 60 65 70 dictation of the new piece of material without interference with and without delaying the transcription of some previously dictated material.

In the following description we refer to this first piece of dictated material recorded by dictator A as the first "sequence" associated with

dictator A and by which we mean the first sequence of a single machine or a number of machines upon which the first piece of dictated material has been recorded.

Thus the first sequence associated with dictator A includes machines 1, 3 and 5, in that order, and it is necessary upon the transcription of this material that the transcriber shall be connected to the same sequence of machines and in the same order with which the dictator A was connected thereto. For this purpose we have included in our system a sequence remembering device or system which, as illustrated in Fig. 1, is a sequence remembering selector RSA'. Suitable control apparatus included within a rectangle designated by the reference character A' will permit the transcriber who desires to transcribe dictator A's first sequence of the dictated material to control the machines included in this first sequence, independently of the selection and control of a subsequent sequence, which has been dictated by the dictator A, or the selection and control of a subsequently dictated sequence by any other dictator or a transcriber associated with office I. In order to permit a transcriber at any time to select one of the sequences which has been dictated by the dictator A we provide a sequence selector CS actuated by the control apparatus located within the rectangle C. Manipulation of the sequence selector CS will connect the transcriber C with any one of a plurality of sequences previously recorded by either dictator A or dictator B so that any one of the transcribers C or D in office I may at any time start the transcription of any of the sequences which has been dictated by dictators A or B.

In our assumed operation dictator A has completed one sequence, which we will refer to as his sequence A' and transcriber C we will assume is 40 to transcribe the material in this first sequence. Transcriber C will operate her control apparatus or sequence selector CS in such manner as to connect her with a sequence-multiple group of cables or conductors R, the first point on selector CS 45 being connected to the control apparatus A' and through the sequence remembering selector RSA' to the machine-multiple group of conductors M, the particular one of such cables or conductors to which the equipment A' will be connected will have been selected by the sequence 50 remembering selector RSA' and will therefore place the transcriber C directly into communication with the first machine of this particular sequence, namely, machine 1. Since the sequence of machines 1, 3 and 5 is maintained by the machine selectors, 1S, 3S and 5S, the transcriber C may listen to and transcribe all of the material recorded upon machine 1, be automatically transferred to machine 3, transcribe 55 all of this material, be transferred to machine 5, and then transcribe all of the material which has been recorded on that machine. In the event the transcriber C desires to repeatedly listen to any of the material which has previously been placed upon any of the machines 1, 3 and 5, she may operate the foot-switch 212 to cause the reproducing head on the machines 1, 3 and 5 to move back toward the beginning of the record associated with these machines and 60 then may re-listen to any of this material.

As will be more fully described hereinafter each of the machines is so constructed and arranged that the transcriber may not only move the heads backward to any previously listened-to 65 70 75

material, but also may move the heads forwardly of any particular position at which she may then be transcribing to listen to other material which has been recorded or to listen to inserts or corrections or instructions. Again as will be more fully described hereinafter, whenever the transcriber desires to move forwardly or rearwardly from the point of last transcription, suitable apparatus is provided for "remembering" where she left off transcribing and to automatically insure the return of the reproducing head to this point of last transcription whenever she desires to resume transcription.

In the system thus far described it will be apparent that the dictator A may dictate one piece of material upon any sequence of machines 1-10, which particular machines and the order in which he dictates material to them will be automatically selected. It will also be apparent that having finished one piece of material which may include one or more of the machines 1-10 he may again start a new piece of dictation and a new sequence of machines will be allocated to him depending upon which of the machines is free and available at the time he starts his dictation and at the time he, in the course of the dictation, completes the capacity of one full record on the machine so selected.

For purposes of illustration herein we have shown our system as including a sufficient capacity of control equipment to permit the dictator A to dictate three distinct pieces of dictation material and have shown sufficient control equipment to include a first sequence A', a second sequence A'', and a third sequence A'''.

It should also be noted at this point that as soon as dictator A has completed one piece of dictated material that sequence of machines which contains that material is now free to be transcribed by either of the transcribers C or D located in office I. At the same time, dictator A upon the completion of a new sequence of material, say sequence A'', releases all of the machines in this new sequence so that either transcriber C or transcriber D may immediately start the transcription of the material in this new sequence and neither transcriber C nor transcriber D will interfere with each other in the transcription of any sequence previously dictated by dictator A. It will also be noted that dictator B's connection to the several machines 1-10 is made in the same manner as previously described for dictator A, the selection of the particular machine to which dictator B will be initially connected will be made through his selector BS.

Assuming for purposes of illustration that dictator A has already dictated upon machines 1, 3 and 5, and that the material on these machines has not yet been transcribed, these machines are "busy" and must remain so until one of the transcribers has transcribed all of the material in this first sequence and has reconditioned the recording media on all of these machines ready for the reception of new dictation. Since all of the machines 1-10 are interconnected to the machine-multiple group of cables or conductors M it follows that as soon as one of these machines has been selected by any of the dictators' selectors AS or BS it immediately becomes "busy" so that upon a subsequent movement of any of the selectors AS or BS into connection with the wires or cables connected with this machine, a suitable "busy" condition will be immediately set up on selectors AS and BS and, as will be apparent to

those familiar with the telephone selector art, the selector AS or BS will continue movement across its various contacts until it arrives in connection with one of the wires or cables leading to a machine which is not "busy." At this time, by employing suitable apparatus which is familiar in the telephone art a "tone" may be produced in the receiver of the dictator to indicate that his equipment has selected a "non-busy" machine, and he is ready then to start his dictation.

It will be noted, however, from the foregoing description that the particular sequence in which the dictator A or dictator B will be connected to the machines 1-10 is not material, all that is necessary being that upon the initiation of dictation by dictator A some one of the ten machines is then "non-busy" and thus available to him for the start of his dictation. By arranging a suitable number of machines 1-10, selected by any previous survey of the expected quantity of material which will be dictated by all of the subscribers to the system, it will be apparent that a sufficient number of such machines may be supplied to exceed the maximum "demand" upon the complete system. Thus there will be a free or "non-busy" machine available at all times to any dictator who wishes to dictate material.

As hereinbefore described, three possible sequences of pieces of dictated material may be arranged and allocated to dictator A. A similar series of three possible sequences of pieces of dictated material may be allocated to dictator B, these being indicated diagrammatically as including the control equipment B' to be associated with the first sequence to be dictated by dictator B, control equipment B'' for the second sequence and B''' for the third sequence.

Again it will be understood that while we have illustrated only three possible sequences allocated to each of the dictators A and B, any other desired number of sequences may be rendered available by merely adding additional control equipment and the additional number of machines necessary to take care of an increased demand upon our system. It will also be noted that since transcribers C and D are both available to transcribe any of the material dictated by either dictator A or dictator B, the total load of transcription from any given office may be readily handled by a minimum number of transcribers, one of such transcribers, having completed the transcription of any given sequence, may immediately start upon another sequence which is not at that time being transcribed by another of the transcribers in her office.

As will hereinafter be more fully pointed out, when each of the transcribers has completed the transcription of a certain sequence of material, she may recondition the machines containing that material whereupon each of these machines is restored upon the line in "non-busy" condition and are thus available for use by any of the other subscribers to the system.

At this point it might be well to note that if during the dictation of any one piece of material by dictator A or dictator B, either of these dictators desire to do some "rush" work such as getting out a telegram or a particular letter which must be immediately transcribed, he may do so without interfering with or losing control of the sequence of machines upon which he has up to this time been dictating. We have provided an emergency machine EAB allocated to office I to take emergency dictation from any of the dictators associated with this office. Again,

- while we have only illustrated a single emergency machine available to all of the dictators in office I, it will be apparent that by merely duplicating this machine with other machines a sufficient 5 number of emergency machines may be supplied to insure satisfaction of the "demand" for emergency messages from that office. The selection of the emergency machine EAB may be controlled by suitable apparatus under the control 10 of dictators A and B which through operation of the emergency relay AEL and BEL, will transfer the control apparatus of dictator A or dictator B over to the line or cable U leading to the emergency machine EAB.
- 15 As will be more fully pointed out hereinafter, the transfer of the control devices for any one of the dictators to the emergency machine will not release the previous sequence on which he was then dictating so that upon the completion 20 of the dictation of the emergency message the dictator A or the dictator B may immediately resume dictation upon the interrupted material and continue this dictation to its end. The complete piece of dictated material, though interrupted, 25 will remain upon a complete "sequence" of machines ready to be followed in the same order of selection of machines by the transcriber as these machines were automatically selected for the dictator during the recording of the 30 piece of material thereon. Upon the completion of an emergency message the dictator, having dictated such message, may by any suitable intercommunication system employed in his office notify the transcription room or the particular 35 secretary or transcriber allocated to him that there is an emergency message which must be immediately transcribed, and the transcriber may interrupt such material as she is then transcribing and through her control equipment select the emergency machine and transcribe this 40 emergency message immediately. Then by reason of the fact that the equipment is provided for holding the sequence she was then transcribing for reconnection, she may immediately 45 resume the transcription of the interrupted dictation sequence.
- A portion of this control equipment is illustrated in Fig. 1, including not only the transcribers' selectors CS or DS, but also the auxiliary transcribers' selectors CSX and DSX. The 50 transcriber may initially be connected to the first sequence she desires through the selector CS and by interrupting this sequence of transcription to immediately transcribe either an 55 emergency message or to give precedence to some later but more important sequence, the selector CS will hold the first sequence in abeyance for her while the selector CSX will select the new sequence or the emergency machine for her.
- 60 Then upon the completion of this second piece of material which she starts, control will be transferred back to selector CS or DS and permit resumption of the interrupted transcription.
- It will therefore be noted that even though 65 all of the machines 1-10 and EAB are located at some point remote from the locations of dictators A and B and remote from the locations of transcribers C and D, each of the dictators may at any time dictate a piece of material of 70 any desired length, release such dictated material for transcription and start a new piece of dictation material. It will also be noted that provision is made for the recording and immediate transcription of emergency messages.
- 75 Each of the transcribers C and D may also

at any time reach any of the previously dictated material for transcription thereof and may either transcribe all of the material in one piece of dictation as a continuous operation or interrupt the same for the transcription of emergency messages or to switch to a different sequence. At the same time all of the machines 1-10 are available at all times to the dictators and transcribers except for such of the machines as are then being dictated upon, or which bear untranscribed material. Thus, at least a portion of the machines 1-10 will at all times be available to the dictators, and any of the previously dictated material will be instantly available to any of the transcribers immediately upon the completion of one piece of dictation. Again it will be noted that, regardless of the sequence in which any one piece of dictated material is applied to the machines 1-10, the sequence which has been automatically selected will be maintained in such fashion that the transcriber cannot miss receiving the dictated material in the same order in which it was dictated by the dictator.

In the foregoing description we have applied our system particularly to the office I, including a plurality of dictators and a plurality of transcribers especially employed to transcribe all material which has emanated from this office I.

In this manner it will be apparent that even though the machines 1-10 may be located in a central location such as a telephone office or other centralized dictation service, none of the material which has been dictated by any person in office I is available to reproduction for or transcription by any other person except those in office I or allocated to office I by reason of the fact that the conductors R extend into connection with only the transcribers of office I. Thus, absolute privacy with regard to the dictation of material emanating from any one office is maintained.

In Fig. 1 we have also illustrated the dictator X presumably with only sufficient dictation to intermittently employ the system and thus not requiring the full time services of a transcriber. The dictator X is interconnected into the machine-multiple group of cables or conductors M through his selector XS in the same manner as dictators A and B were connected through their selectors AS and BS. Thus dictator X may upon the initiation of any piece of dictation find a machine which is not "busy," automatically selected for him and he may dictate such piece of material even though it may exceed the capacity of one of the machines.

It is assumed for purposes of illustration herein that the dictator X has made arrangements with some other office (here shown as office III) to transcribe this dictated material for him. For example, the office III may represent a transcription pool in which a large number of transcribers are available to dictators located in the several offices subscribing to a transcription service offered by office III. Thus, transcriber Y located in office III is representative of one of a group of transcribers located at this office. Transcriber Y through her control equipment, YS AND YSX, may select any one piece of material which has been dictated by dictator X, through the sequence selecting equipment X', X'' and X''' and through the remembering selectors RSX', RSX'' and RSX''' in the same manner as was described for the selection of the several sequences allocated to dictators A and B.

Again it will be noted that the transcribers allocated to office III are connected to a sequence-multiple group of conductors or cables V distinct and separate from group R, and which are in turn associated with the selectors for the several sequences emanating from the dictator X at office II. Hence, transcribers in office III cannot select any of the sequences allocated to dictators A and B or other dictators not subscribing to the office III transcription service.

By thus separating the transcriber's sequence-multiple cables for each of the subscribers to our system from the groups allocated to other subscribers, any material dictated by dictator X is available only to transcriber Y and cannot be picked up or received by the transcribers C and D. Thus, it will be noted that absolute privacy as regards the dictation emanating from office I and that emanating from office II is maintained.

It will be apparent from the foregoing description that our dictation system provides a service available to an office of any size from the most modest requirements, namely, of only intermittent use such as that represented by office II, or offices in which there is a great load of dictation and transcription, such as that represented at office I. Again it will be noted that the transcription service maintained at office III may include a plurality of subscribers to such transcription service so that a large number of dictators located in separate offices may have their dictation transcribed by a single or common transcription pool, or they may have available to them a service corresponding to that shown for office I wherein a single dictator in any one office may have a single transcriber located in his own office or in some other office but privately connected to receive only dictation emanating from his office.

Again it will be noted that should the dictator X or any of the subscribers to the transcription service emanating from office III desire to dictate emergency messages one or more emergency machines may be allocated thereto, indicated in Fig. 1 as emergency machine EX, and arranged as will be more fully described hereinafter to be selected for emergency messages in the same manner as was described with reference to the emergency machines EAB allocated to office I.

RECORDING AND REPRODUCING MACHINE UNIT

Before entering into a more detailed description of the precise control apparatus and the complete wiring system required for the operation of our dictation system, it may be well to describe one form of machine unit which may be successfully employed in the practice of our invention. Such machine unit is illustrated in Figs. 2 and 3 as including a suitable frame or base 11 by which the units may be supported in any suitable manner at the central office location, the frame including a bearing post and gear box 12 upon which is mounted rotatably a suitable turn table spindle or other record medium carrier 13. Mounted upon or formed with the medium carrier 13 is a suitable recording medium 14 illustrated in Figs. 2 and 3 as comprising a cylindrical shaped recording medium of the magnetic type such as is illustrated in the co-pending application of Huntley et al., Serial No. 213,638, referred to hereinbefore.

The recording medium 14 is adapted to be rotated by a suitable record rotating motor RM which may be either directly connected to the record supporting device 13 or may be coupled

thereto through suitable bearings housed within the bearing supporting portions 12 and 12a of the frame 11. Forming a part or attached to the frame 11 is a translation head supporting bar or guide 15 upon which is slidably mounted a carrier 16 having mounted thereon a dictation recording and reproducing device 17 which again may be constructed as illustrated and described in the co-pending application of Huntley et al. or may take the form of a recording and reproducing mechanism as illustrated in the co-pending application of Ray M. Chenoweth et al. hereinbefore referred to.

The recording device 17 is moved along the recording medium 14 by a suitable feed screw 18 adapted to be operated by the record motor RM through suitable gearing (in the gear box 12) of the general character now employed to rotate the screw of ordinary present day dictation machines. The feed screw 18 imparts a motion to 20 the carriage 16 through a suitable nut 19, adapted to engage the feed screw 18, and adapted to be disengaged therefrom as follows: the nut 19 may be formed upon or attached to a slide 20 mounted upon the carriage 16 in such manner as 25 to be moved toward and away from the feed screw 18, the nut 19 being normally urged into an engagement with the feed screw 18 by a spring 21 engaging a lever 22 pivoted as at 23 upon the carriage 16, the outer end 24 of the lever 22 being 30 pivotally secured to the slide 20 in such manner that the normal resilience of the spring 21 will cause the engagement of the nut 19 with the feed screw 18.

It will thus be noted that the recording device 17 may be started at one end (the left hand end of the recording medium 14 as viewed in Fig. 2), and rotation of the recording medium 14 together with the longitudinal travel of the recording device 17 will cause the stylus 17a thereof to describe a helical path about the recording medium along which dictated material may be recorded. During the recording of the material there may be pauses or short interruptions in the continuity of the dictation by the dictator which may be effected by stopping and restarting of the rotation of the recording medium 14 as by providing suitable start-stop controls for the record motor RM in the same manner as the recording media of the present well known machines are started and stopped. For simplicity of illustration herein and to illustrate the manner in which the electrical control devices hereinafter described may control the start-stop of the recording medium, we have shown record motor RM as having its circuit completed to start the record 14 and interrupted to stop the record 14.

A brake RB is employed on the motor RM, adapted to be engaged with the shaft of motor RM or to the recording medium support 13, immediately upon the interruption of the motor circuit and to be released whenever the motor circuit is energized. Thus, the actual recorded material will be continuous upon the medium 14 irrespective of short pauses or interruptions in the continuity of the dictation.

Again, as was illustrated and described in the co-pending application of Ray M. Chenoweth et al. Serial 53,396, whenever it is desired to play back any portion of the previously recorded material by the dictator, it is desirable that the carriage and the recording-reproducing mechanism 17 be transported as rapidly as possible to that part of record containing the material which is to be played back and to rapidly transport 75

the carriage and the recording device 17 back to the point of last recording when the dictation is to be resumed. We provide a means for moving the carriage 16 at a relatively high speed longitudinally of the medium 14 in the form of a high speed feed screw 26 which may be suitably rotated by motor HSM.

Motor HSM will, as is hereinafter more fully described, be energized to rotate the high-speed feed-screw 26 only when it is desired to rapidly return the recording device 17 toward the forward portion of the record or back to the point of last recording, during dictation of material upon any record. In order that little or no over-travel of the carriage 16 may occur when the high-speed motor HSM is in operation or is stopped, we prefer to provide a suitable brake device HSB on the motor HSM to be released when the motor is energized and to apply the brake when the motor is de-energized to cause immediate stopping of the feed screw 26.

In order to permit the high-speed feed-screw 26 to move the carriage 16 either forwardly or rearwardly along the record 14 we provide upon the opposite end of the slide 20 a second feed nut 28 adapted to move into engagement with the high-speed screw 26 whenever a suitable feed-shift solenoid or magnet SS is energized, and which is so disposed relative to the lever 22 as to cause this lever to be swung in such direction as to move the slide 20 to engage feed nut 28 and high-speed feed-screw 26. As will be more fully described hereinafter, the recording device 17 may be employed both for recording the dictated material upon the record 14 and for the reproduction of the recorded material during playback by the dictator. Also the same device may be employed to reproduce the previously recorded material for the benefit of the transcriber when she is transcribing the dictated material.

As will be understood by those skilled in this art, the recordation of "errors," "ends of letters," and other instructions may be made directly upon the same magnetic recording medium 14 upon which the dictated material has been recorded by employing an audible or inaudible frequency supplied to the recording device 17 by appropriate control mechanism as is illustrated and described in the Ray M. Chenoweth et al. application, Serial 53,396, hereinbefore referred to, or in the Huntley et al. application, Serial 213,638, hereinbefore referred to. Such instructional material as will be more fully described hereinafter may be taken off of the recording medium 14 through suitable filters and other devices as to segregate it from the reproduced material on the record 14.

However, in order that such instructions as "errors," "end of letters," etc., may be transmitted to the transcriber in advance of the actual reproduction of the recorded material to which such instructions relate, we prefer to provide an additional device 29 which may comprise a magnetic reproduction device corresponding in all respects to the device 17. However, due to the fact that the reproducing device 29 is spaced along the carriage 16 by a distance indicated at 30, the instructional material will be transmitted to the transcriber at some time, prior to the actual reproduction of the recorded material to which such instruction relates.

It will be apparent that she will have ample time to note that a correction is to be made and may stop the actual typing of the dictated material for a sufficiently long time to listen to the recorded material, and to note what portion

thereof is to be corrected, and where such corrected material is to be found. In this manner the operator will be pre-warmed as to "errors," "end of letters" or other instructions prior to her actual transcription of the material to which the instruction relates.

It is apparent, therefore, that when a machine is initially conditioned to receive the dictation from a dictator the stylus 17a of the dictator's recording and reproducing device 17 should be located at approximately the left-hand or starting end of the recording medium 14, while as the carriage 16 progresses along the length of the recording medium 14 toward the right-hand end or finish thereof, the stylus 29a of device 29 will arrive at the right-hand end or finish of the record considerably in advance of the stylus 17a. We utilize this advance displacement of the information stylus 29a from the recording stylus 17a as a means for assisting in the automatic selection of the next recording medium to be used in the sequence.

As will be readily understood from the herein-after recited detailed description of the operation of our control system, whenever the dictator has dictated a sufficient amount of material to completely fill one of the record cylinders or other recording media 14, the system will automatically select some other one of the machine units 1-10 to permit him to continue his dictation, should such dictation exceed the capacity of the medium 14 on one of such machine units. We therefore utilize the displacement of the stylus 17a and the stylus 29a as a means for automatically achieving selection of the next available machine unit in the system for the continuation of the dictation and achieving this selection at a sufficient interval of time prior to the actual completion of the filling of the record 14 as to set up the necessary selection devices and transfer the control devices at the dictator's station over to the new or next machine unit in the sequence in ample time that no actual interruption of the dictation need be made. In order also to achieve the necessary transfer of the circuits from one machine to the next as the dictator dictates material upon a plurality of recording machine units in sequence we provide at the finish end of each of the machines suitable limit switches RE and EE. The limit switch EE is adapted to be engaged by a cam 31 upon the forward end of the carriage 16 when the instruction reproducing stylus 29a arrives at the finish end of the recording medium 14.

It will be noted that the second limit switch RE is adapted to be operated by the cam 31 when the recording stylus 17a arrives at the finish end of the record 14.

For purposes of illustration herein, we have shown the limit switches RE and EE as simple leaf spring switches wherein for switch EE the spring member 32 has its end 33 adapted to be engaged by the cam 31 and lifted thereby to bring the contact piece 34 thereon into contacting relation with a contact piece 35 upon a stationary contact bar or spring 36. Similarly, the switch RE is provided with one leaf spring member 37 adapted to be engaged by the cam 31 to bring its contact member 38 into engagement with a stationary contact member 39 on a stationary leaf spring 40. As will be understood by those skilled in this art, suitable insulation will be interposed between the frame 12a mounting the limit switches EE and RE and the several spring members 32, 36, 37 and 40 of these switches.

It will also be noted from an inspection of Fig. 2 that the "starting end" of each of the machine units is provided with a similar pair of limit switches designated as RS and ES.

- 5 The limit switch RS is adapted to be engaged by a cam 41 whenever the recording-reproducing stylus 17a is located at the beginning of the recording medium or record cylinder 14, and is adapted to be released by this cam to permit the 10 contacts of the switch RS to open as soon as the stylus 17a has moved away from its starting position, either during the recording of the first part of the material to be recorded upon record 14 or when the stylus 17a has been moved away 15 from the starting position for any other reason, as will be more fully hereinafter described.
- Likewise the switch ES is adapted to be engaged by the cam 41 and to be moved thereby into circuit-closing position whenever the carriage 16 has been so retracted toward the starting end of the machine to position the information-recorder stylus 29a at the start of the record 14. The switch ES will have its contacts opened whenever the stylus 29a has been moved 20 along the record 14 away from this starting position. As will more fully hereinafter be described the operation of the limit switches RS and ES is employed to automatically control the transfer of our control system to the next preceding machine in the sequence, for example, when it is desired to play back previous dictation on a preceding record.

Whenever the head or carriage 16 on one of the machines is moved back to and arrives at 35 the starting end of one record the switches RS and ES will cause the control transfer. Switches RS and ES will similarly function when the transcriber wishes to re-listen to material on a record preceding the one she is then transcribing. Likewise the switches RE and EE will be employed to transfer the controls to the next succeeding machine in the sequence during a return of the recording and reproducing apparatus 17, toward the point at which the dictator left off 40 dictation or the transcriber left off transcribing. These limit switches also constitute actual "limit 45 switches" in the sense that they automatically stop operations of the machine whenever the recording-reproducing apparatus 17 and information recording and reproducing apparatus 29 arrive at either end of the record and thus prevent overtravel at either end of the machine.

HOLDING "POINT OF LAST RECORDING OR TRANSCRIPTION"

As was stated hereinbefore in the brief description of our system as illustrated in Fig. 1, another of the desirable features of our system is that, at any time during the dictation of any piece 60 of material the dictator may interrupt the continued dictation for the purpose of playing back or listening to any of the previously dictated material or for the purpose of making inserts or inserting instruction material relating to some 65 previously dictated material.

However, whenever the dictator has moved back from the point at which he interrupted his dictation, it is desirable that some means be employed to mark the point along that record on 70 that particular machine at which he interrupted his dictation, so that, when he desires to resume dictation he will automatically resume dictation at the point on that record at which he last recorded material. Again as was hereinbefore 75 described with reference to Fig. 1, whenever the

transcriber is transcribing any portion of the dictated material and desires to re-listen to some of the earlier transcribed material she may move the carriage of the machine unit to which she is then listening rearwardly or toward the start of that particular record and in so doing some means should mark the place at which she left off transcribing the material so that upon her resumption of transcription she will automatically resume transcription at the point at which she interrupted the same. The purpose of this will be apparent in that it is desirable that the operator be prevented from missing any of the recorded material.

Likewise as was hereinbefore described with 15 reference to Fig. 1, should the transcriber in transcribing some of the material find that instructions refer her to some other portion of the dictation which lies beyond the point to which she has then arrived, she should be able to move 20 the carriage 16 forwardly along the record 14 to rapidly reach and listen to inserts or other material necessary for aiding her accurate and speedy transcription of the dictation.

In such event some means should mark the 25 point at which she interrupted the transcription of the material for the purpose of listening to this additional or auxiliary material and to permit her to readily find the point at which she left off transcription when she desires to resume 30 the same.

We therefore provide upon each machine a device which, as soon as either the dictator or the transcriber leaves the point of last dictation or last transcription respectively, will mark such 35 point in such manner that upon the re-arrival of the recording or reproducing devices 17 at this point, the machine will be conditioned automatically for dictation or transcription. This device which may be termed "a point-defining 40 means" is illustrated particularly in Fig. 3, in diagrammatic form wherein each of the machine units is illustrated as being equipped with a commutator switch device PDM which may be housed in gear box 12.

While this device may take any one of a number of forms we have illustrated the same as including an arcuate contact segment 44 over which a movable contact 43 may wipe whenever the "point defining means" acts to locate a point 50 rearwardly (that is, toward the "start" of the record) of the then position of the recording head.

A second contact segment 42 extends in the opposite direction and is arranged to be traversed 55 by the movable contact 43 whenever the recording head 17 is moved in a direction ahead (that is, toward the "finish" of the record) of the point of last dictation or the point of last transcription. The two arcuate segments 42 and 44 are 60 separated from each other and are suitably insulated from each other, an insulation segment 45 being interposed between the two segments 42 and 44 to be engaged by the movable contact arm 43 whenever the position of the recording head on 65 the machine is co-incident with the point of last recording or the point of last transcription. The movable contact 43 remains upon the insulating segment 45 during the normal motion of the recording head 17 in its usual or normal travel 70 along the length of the record 14 during normal recording or normal transcription.

For this reason during the normal recording or transcription movements of the carriage 16 the movable contact 43 should remain stationary with 75

respect to the segments 42 and 44. The segments 42 and 44 and the insulating segment 45 may be therefore stationarily mounted upon some stationary portion of the frame of the machine while 5 the movable contact 43 may be secured upon a suitable shaft 46 adapted to be rotated whenever a clutch PDC is actuated.

For purposes of illustration herein and particularly with reference to the more detailed description 10 of our system to follow, the clutch PDC is illustrated as being magnetically operated, a coil or magnet 47 thereof being arranged to be normally energized during the normal operations of the carriage 16 relative to the record 14. The 15 clutch PDC is also illustrated as having one of its clutch plates 47a as being normally urged toward a clutch plate 47b (mounted upon the shaft 46) by means of a spring 47c so that upon the de-energization of the coil or magnet 47 the clutch plates 47a and 47b will be engaged.

As will be understood by those skilled in this art, whenever the recording device 17 is moved toward the "start" of the record as for a play-back of previously dictated material, the extent 25 of this movement should be indicated, recorded, or "stored up" by the point-defining-means PDM. Thus the motion of the recording device 17 toward the "start" of the record is, as hereinbefore described, accomplished by means of the high-speed feed screw 26 at a time when the normal rotation of the recording medium 14 and the operation of the low-speed feed screw 18 is idle or stationary. Again having arrived at the point 30 at which it is desired to begin the play-back, the recording medium 14 is started into rotation and the recording device 17 re-starts and travels at the low-speed toward the "finish" end of the record at the usual slow reproducing speed under the influence of the slow-speed feed screw 18.

40 In other words, whenever dictation is stopped for the purpose of returning to some previously dictated portion of the material, the point defining means should "count back" from the "point of last recording" a distance corresponding to the 45 distance from the point of last recording at which the dictator desires to start the play-back. Now, as the dictator listens to the played-back material the recording device 17 reapproaches the "point of last recording" and the amount of such 50 approach should be "counted up" by means of the point-defining-means. Thus at any time the dictator desires to resume dictation he may then cause the recording device 17 to move rapidly or at high speed forwardly (that is, toward the 55 "finish" end of the record) through such distance as may remain to bring the recording device 17 back to the point of last recording and then immediately be reconditioned for resumption of dictation. This is illustrated in Fig. 3, in a dia- 60 grammatic form as including a suitable combination of gears and shafts which interconnect the slow-speed feed screw 18 (used to drive the recording-reproducing device 17 during either recording or reproducing operations from the start 65 of the record toward the finish of the record) and also to interconnect the point-defining-means with the high-speed feed screw 26 (which it will be remembered will always be operated whenever recording device 17 is either moved forwardly or rearwardly upon the record 14 whenever the 70 recording device is desired to be rapidly shifted from or to "the point of last recording").

This gearing (which may be housed in gear box 12) is illustrated as including a differential gear assembly 48 which includes a ring gear 48a

carrying a plurality of idler gears 48b and 48c permanently engaged with a driving gear 48d and a driven gear 48e. The gear 48c is permanently fixed upon a shaft 48, which is permanently and rigidly coupled to the magnetic clutch PDC. The 5 ring gear 48a is arranged to be driven by the high-speed feed screw 26 as by a pinion 50 fixed on the high-speed feed screw 26. Also the driving gear 48d is arranged to be driven by the low-speed feed screw 18 as by securing gear 48d upon 10 an extension 51 of screw 18. The feed screw 18 is driven by means of suitable reduction gearing indicated diagrammatically at 52 interconnecting the record motor RM and the feed screw 18.

From a review of Fig. 3 it will be apparent, 15 therefore, that whenever the recording device 17 is recording material upon recording medium 14 and is being driven forwardly (that is, toward the "finish" of the record) at low-speed along this recording medium, the driving gear 48d of the 20 differential 48 will be continuously rotated. Rotation of the gear 48d will, by reason of its continuous meshing with the idler gears 48b and 48c, drive the driven gear 48e to continuously rotate the magnet 47 of the point-defining clutch 25 PDC in a direction which would tend to move the movable contact 43 forwardly or in a clockwise direction relative to the segments 42 and 44.

However, for purposes of illustration herein and as is more fully described with reference to the 30 detailed description and wiring diagram, during the normal forward travel of the recording device 17, that is, during normal recording of dictation (and also during normal reproduction of material during transcription) the clutch magnet 47 will 35 be energized so as to maintain the clutch plates 47a and 47b out of engagement with each other and there will be no relative motion between the movable contact 43 and the segments 42, 44 and 45.

Assuming, however, that having arrived for example at approximately the mid-point of the record 14, the dictator desires to listen to some of the previously recorded material on the forepart (that is, toward the "start") of the record 14, 45 he operates his control devices (hereinafter more fully described) in such manner as to cause the recording device 17 to move rapidly toward the "start" end of the record 14. At this time the control devices will de-energize the clutch magnet 47 and permit engagement of the clutch plates 47a and 47b.

The rapid retraction of the recording head 17 toward the forepart or "start" of the record is caused by operation of the high-speed motor HSM 55 to rotate the high-speed feed screw 26. By referring to Fig. 3, it will be noted that at this time the record-revolving motor RM will be stationary as will be the slow-speed feed screw 18.

Thus while the pinion 50 will be driving the 60 ring gear 48a, the driving gear 48d will be held stationary. Thus the rotation of the ring gear 48a will move the idler gears 48b and 48c about the now stationary driving gear 48d as a center. Now, by reason of the engagement of the idler 65 gears 48b and 48c with gear 48d these idler gears will be rotated and will impart a rotary movement to the driven gear 48e tending to rotate the clutch shaft 49. Rotation of the clutch shaft 49 and the clutch PDC will cause motion of the movable contact 43 of the point-defining-means PDM in a 70 counterclockwise direction, that is, in a direction to cause the movable contact 43 to leave the insulating segment 45 and to pass back along the segment 44, the extent of such movement from 75

the normal "central" or "off" position (that is, on insulating segment 45) being measured by the amount of rotation required of the high-speed feed screw 26 to retract the recording device 17 to the desired point for playback. For example, assuming that the part of the material which the dictator desired to "play-back" was located at approximately the "start" end of the record 14, sufficient rotation will be required of the high-speed feed-screw 26 to move the recording device half the length of the record.

The movable contact 43 will be moved away from segment 45 and along segment 44 by such distance as corresponds to half the length of the record.

Furthermore, in view of the fact that the point at which the dictator may desire to leave off dictating and to start play-back may occur at the "finish" end of the record and that the point at which he desires to start the reproduction or playback of the material may lie at the "start" end of the record, the total amount of travel which may be required of the movable contact 43 along the segment 44 may be such as to correspond to the full length of the record 14. For this reason we have illustrated and described herein the point-defining-mechanism and its segments and the gearing necessary to operate the movable contact 43 as capable of permitting motion of the movable contact 43 along the segment 44 throughout a total distance equal to or proportional to the full distance of travel of the recording device 17 from the "finish" end of the record completely to the "start" end of the record.

In the assumed operation of the retraction of the recording device 17 it was understood that the dictator had in his normal dictation arrived at the mid-point of the record 14 and desired to play-back certain of the previously recorded material, for example, at the start of record 14.

The movable contact 43 will then have been retracted through approximately one-half of its total distance of travel along the segment 44. Now, as will appear from the later description, as soon as the recording-reproducing device 17 reaches this new position, the regular record-revolving motor RM will be started and the record 14 will be put into rotation, while at the same time the slow-speed feed screw 18 will be actuated to move the recording device 17 along the record toward the "finish" end at regular slow-speed in the normal manner hereinbefore described for the recording or the reproduction of material upon or from the record.

It should be noted at this time that the clutch PDC will, however, remain de-energized for the reason that the recording device 17 is now away from the "point of last recording." Thus the readvancing movement of the recording device 17 along the record 14 will cause rotation of the movable contact 43 in a clockwise direction tending to bring it back to a position of contact with the insulating segment 45.

Under these conditions the high-speed feed screw 26 will remain stationary and the slow-speed feed screw 18 will be operating, and therefore the rotation of the feed screw 18 will cause rotation of the driving gear 48d of the differential 48.

The ring gear remaining stationary at this time, the driven gear 48e will be rotated in such direction as to move the pointer or movable contact 43 in the clockwise direction, toward the insulating segment 45. Assuming now that the dictator listens to all the previously dictated material re-

corded on the first half of the record 14, until the recording device 17 rearives at the mid-point or point of last recording, the arrival thereat will be accompanied by the arrival of the movable contact 43 again upon the insulating segment 45. As soon as the movable contact 43 rearives upon the insulating segment 45 the circuit to the clutch PDC will be re-established through suitable relays, hereinafter more fully described, and the clutch plates 47a and 47b will be disengaged. At the same time through the operation of the control apparatus, hereinafter more fully described, the machine will be immediately reconditioned for recording, and the dictator may immediately resume dictation, and the further movement of the recording device 17 along the record 14 will be accompanied by no further movement of the movable contact 43. In other words, the movable contact 43, having re-arrived at the position corresponding to the point of last recording, now remains stationary and inactive until it is again called upon to "count back", which occasion will occur upon any subsequent attempt to play back some of the previously recorded material.

Assuming, however, that while the dictator was listening to certain of the play-back material he was satisfied to listen to only a portion of the previously recorded material, for example, during the first one-fourth of the record 14. At this time he desired to immediately resume dictation at the point at which he left off. As will be more fully described hereinafter he will so operate his controls to recondition the machine for resumption of dictation, the operation of such controls immediately putting into action the high-speed feed screw 26 to immediately and at high speed move the recording device 17 along the record 14 back to the point of last recording. This, of course, will be accompanied by a rotation of the pinion 50 at the same time that the record motor RM and the slow-speed feed screw are stationary and the ring gear 48 will, therefore, be driven in the opposite direction to that heretofore described. Since the movable contact 43 has not yet arrived at the insulating segment 45 the clutch PDC will be de-energized, and the forward movement of the recording device 17 will be accompanied by the clockwise movement of the movable contact 43 until it again coincides with the position of the insulating segment 45. Instantly upon the arrival of the movable contact 43 at the insulating segment 45 the clutch PDC will be re-energized and further motion of the movable contact will be prevented.

Again as hereinbefore pointed out, whenever the movable contact 43 arrives at the insulating segment 45 the recording device 17 will be reconditioned for recording, and the dictator may immediately resume his interrupted dictation without loss of time and without loss of space along the record 14.

This same position-defining-mechanism is employed by the transcriber during the normal transcription of material. Again it will be noted that the same recording and reproducing device 17, which recorded or played-back the material for the dictator, is also employed by the transcriber for the reproduction of material for transcription purposes. Hence the travel of the recording-reproducing device (hereinafter for this part of the description being referred to as the reproducer 17) will be normally driven at slow-speed along the length of the record 14 during the rotation of the record 14 and while the trans-

scription occurs. Thus, during this normal listening to or transcription of the material from the record 14 the clutch PDC will be energized and will hold clutch plates 47a and 47b out of engagement with each other and prevent any relative movement between movable contacts 43 and its segments 42, 44, and 45.

Now, assuming that the transcriber desires to relisten to some portion of the previously transcribed material, she may so operate her controls that the reproducing device 17 will be rapidly retracted toward the forepart or "start" of the record 14. The transcriber's controls are, as hereininafter described, so arranged that whenever she attempts to move the reproducing device 17 toward the forepart or "start" of the record 14 the clutch magnet 47 will be de-energized and allow the clutch plates 47a and 47b to be engaged. Thus during such high-speed retractive movement the high-speed feed-screw 26 will be operated while the slow-speed feed-screw 18 will be stationary and the movable contact 43 will be retracted away from the insulating segment 45 and back along the segment 44 as hereinbefore described for the retraction of the recording-reproducing device 17 during the dictator's play-back. Again it will be noted that the extent of the retraction of the reproducing device 17 along the record 14 will be accurately represented by the amount or distance of the retraction of the movable contact 43 along the segment 44.

When the reproducer 17 arrives at the desired portion of the record control devices will so condition the machine as to play-back this material, and the high-speed feed-screw will be stationary and the slow-speed feed-screw 18 will be operating at the time she is re-listening to this material.

The total amount of the slow-speed travel of the reproducing device 17 along the record 14 will thus be "unwound" by the movable contact 43 travelling in a clockwise direction along its segment 44 towards the insulating segment 45. If she listens to all of the previously transcribed material until the reproducing device 17 rear-arrives at the "point of last transcription" the movable contact 43, upon arriving at the insulating segment 45 will re-energize the clutch PDC and disconnect clutch plates 47a and 47b, leaving the movable contact 43 upon the insulating segment 45, and she may therefore resume transcription of the material at the point she left off, without further operation of any controls on her part and without further forward movement of the movable contact 43. Now, assuming that instead of listening to the full amount of the previously transcribed material she only listens to a relatively short part thereof and then desires to resume transcription at the point where she left off. She may operate her controls, as hereinafter described, to cause the reproducing device 17 to be moved back along the record 14 at high speed toward the "point of last transcription" (toward the point which has been defined by the point defining means). This operation will include the stopping of the slow-speed feed-screw 18 and the starting and operation of the high-speed feed-screw 26 and the movable contact 43 on the point-defining-mechanism PDM will be moved rapidly back toward the insulating segment 45 in the same manner as was described for the high-speed or rapid resumption of dictation by the dictator.

However, upon the rearival of the reproducing device, under these conditions, at the point of last transcription, not only will the clutch PDC

be reenergized to prevent further forward movement of the movable contact 43, but the transcriber's control apparatus will be so automatically operated as to place the machine ready for slow-speed forward drive of the reproducing device 17, and she will immediately resume transcription at the point at which she interrupted the same.

It frequently occurs, however, that the transcriber in listening to certain of the recorded material will note from the "error information" transmitted to her that an insert or some correction has been dictated further along on the record 14 and when she arrives at the point at which error or insert should be considered in the transcription of the material, she may be required to hunt along the record 14 to find the insert or to find further instructions with regard to the "error."

Another condition which may be encountered by the transcriber is that she may desire at the starting of a letter or some particular portion of the material she is transcribing to know approximately how long this particular piece of the dictation is, in order that she may suitably arrange the paper in the typewriter or may suitably space and arrange the writing upon the paper as to fit the length of this portion of the dictated material.

For instance, should this portion of the material constitute a letter she should know approximately how long this letter is and whether she should start typing at the top of the page or should so arrange the writing from the top of the page as to present an even appearance. Any of these conditions may require that the transcriber be enabled to at any time interrupt the transcription of the material and move the reproducing device 17 forwardly along the record 14 to listen to either the end of this letter or to inserts or other corrective material. Again, however, it should be noted that having interrupted the normal transcription of the material she should have some means for marking the point at which she interrupted the normal transcription. This is readily accomplished by the use of the same point-defining-mechanism as hereinbefore described.

As will be apparent from the more detailed description of the wiring diagram herein, any time that the transcriber desires to move the reproducing device 17 forwardly along the record 14 she may do so by operating suitable controls which will cause the reproducing device 17 to move at high speed to the desired point. At this time the record revolving motor RM and the slow-speed feed-screw 18 will remain stationary and the high-speed feed-screw 26 will be operated.

The controls actuated by the transcriber under these conditions will also de-energize the clutch magnet PDC to cause engagement of the clutch plates 47a and 47b. Under these conditions it will be apparent that the movable contact 43 will move away from the insulating segment 45, and in a clockwise direction so as to bring the movable contact 43 across the segment 42. As was previously described for the retractive movement of the movable contact 43, the amount of movement of the movable contact 43 along the segment 42 (representing an advancing movement, toward the finish of the record, of the reproducing device 17 along record 14) by a distance exactly corresponding to the distance to which the reproducing device 17 is moved away from

the "point of last transcription". Now, assuming that, having moved the reproducing device 17 at a high-speed to a desired point, the transcriber desires to listen to certain of the material 5 at this point she may so operate her controls as to stop the high-speed feed-screw 26 and to start the record-motor RM and the slow-speed feed-screw 18. This will permit her to listen to the normal reproduction of this portion of the 10 material on record 14.

However, at this time since the movable contact 43 is away from its insulating segment 45 the clutch PDC will remain de-energized and any further advancing movement of the 15 reproducer 17 along the record 14 will be accompanied by a still further forward movement of the movable contact 43 along its segment 42. Thus it will be apparent that at any time the 20 total amount of movement of the movable contact 43 over its segment 42 will represent the total distance the reproducing device 17 has been moved away from the point of last transcription. Now, assuming that the transcriber 25 has listened sufficiently to the advance material and now desires to resume transcription at the point where she left off, she may so operate her controls as to return the reproducing device 17 to the point-of-last-transcription. This will be accomplished at relatively high-speed by the 30 operation of the high-speed feed-screw 26 during the time at which the record motor RM and the slow-speed feed-screw 18 are stationary. This retractive movement, under the influence of the high-speed feed-screw 26, will "unwind" 35 the movable contact 43 back from its forward position along segment 42 toward the insulating segment 45, and instantly upon the arrival of the contact 43 upon the insulating segment 45 the clutch PDC will again be energized, separating 40 clutch plates 47a and 47b and preventing further movement under these conditions in either direction away from the insulating segment 45.

The controls which will be automatically operated at this time will be the same as those which 45 were described for the rearival of the movable contact 43 at the insulating segment 45 when the transcriber was listening to previously transcribed material and hence the controls will 50 be so actuated as to place the machine ready for resumption of normal reproduction of materials to be transcribed at the slow speed.

Another important feature of our invention, however, is that if the operator has been listening 55 to some of this advance material such as insertions, etc., and then desires to go back along the record 14 to some point beyond the "point-of-last-transcription" (that is, further toward the forepart or "start" of the record 14) 60 she may so operate her controls as to cause this retraction of the reproducing device 17, not only back to the "point-of-last-transcription," but beyond the same, and if she so operates her controls, the arrival of the movable contact 43 65 at the insulating segment will not under those conditions cause re-energization of the clutch PDC and the point-defining-means will now pass beyond the insulating segment 45 and "wind up" on the segment 44 the total retractive distance 70 past the point of last transcription.

Now, when she desires to resume transcription she operates her controls in the same manner as hereinbefore described and the reproducing device 17 will be returned at high-speed to the 75 point of "last transcription" and upon arrival

thereat she may resume the transcription at normal speed.

At this point it will be noted that if the transcriber has been re-listening to some previously transcribed material such as to re-listen to certain instructions as to inserts, etc., she may then immediately advance the reproducing device 17 beyond the point of last transcription to some further advanced portion of the record and listen to that portion of the record. In any event, 10 whenever the operator interrupts the normal transcription, the point-defining-means PDM will mark the point of such interruption and though she may operate the reproducing device 17 in either direction away from this point of "last 15 transcription" such point will remain defined until she returns thereto and resumes normal transcription. Thus, the point being defined, she may always or at any time return to the "point of last transcription" with assurance 20 that she will not have missed any of the dictated material.

ERASING EQUIPMENT

As was described in the co-pending application of Ray M. Chenoweth et al., Serial No. 53,396, the reconditioning of the records after they have been transcribed may be accomplished by means of an erasing head adapted to travel along the length of the record. However, for simplicity herein we have illustrated an erasing magnet 53 as being located upon some stationary portion of the machine so as to be disposed along the entire length of the record 14. The erasing magnet 53 may comprise an elongated 30 bar of suitable magnetic material having a V shaped cross section extending toward and substantially into contact with the surface of the record 14. A suitable electrical winding or coil 54 may be wound around the magnet core 53 and energized by operation of the special control 35 on the part of the transcriber whenever she has finished transcribing a complete sequence of records. Thus, energization of the coil 54 will supply erasing magnetism throughout the entire 40 length of the record 14 and recondition this record for the reception of new dictation material.

It will be observed therefore that by employing the elongated erasing magnet structure 53—54, the reconditioning of the records will be accomplished almost instantaneously, it being 50 necessary only to rotate the record 14 through one complete revolution after the coil 54 has been energized.

SELECTOR SWITCHES

Again before considering in detail the wiring diagram by which we accomplished the several results set forth hereinbefore, it may be desirable to note the certain peculiarities of construction which we employ in the various selector switches. 60 For a more ready understanding of the particular selector-switch we employ reference may be had to Fig. 5. In general the several selector-switches employed in our system correspond to the well-known construction of the selector-switches used in telephone equipment for the purpose of selecting lines or for the selection of numbers under the influence of a manually operated dial-telephone. That is, each of these switches (for example selector-switch AS, the 70 first of these switches to be described in the later description of the wiring diagram) may comprise a plurality of contact levels each of which includes a series of contact points adapted to be successively engaged by a wiper or mov- 75

able contact rotated relative to the several contact points of each blank. (Note that hereinafter, reference to the levels and their associated wipers will be indicated as *a* or *b*, etc., for both 5 levels and wipers).

Also, as will be understood by those skilled in the telephone art, the movement of the several wipers across the contact points in their associated banks may be accomplished by a suitable 10 motor-magnet AS—M which when actuated will move a shaft 60 in a step by step motion so that upon each step of movement of the shaft 60 the contact wipers *a*, *b*, *c*, etc., will be moved from contacting relation with one of their contact 15 points and into contacting relation with the next of the contact points on its level. Again it will be noted also that when the selector is at its "home" or "off" position all of the several wipers on that selector will be engaged with a 20 "home" contact point on their respective levels and that whenever the selector has been moved away from its "home" position or its "off" position it will be held in the new position by means of a holding or locking device which can be released only upon the de-energization of a release 25 magnet AS—R.

The particular selector which we employ for purposes of illustration herein and to fit the details of the wiring diagram hereinafter to be 30 described requires certain peculiarities of construction and operation distinct from those of which we have knowledge now employed in the telephone art.

Referring particularly to Fig. 5, it will be observed that we have indicated diagrammatically a plurality of levels, *a*, *b*, and *c*, each of which includes a series of contact points. Associated with the level *a* is a wiper *a* adapted to traverse the several contacts in the bank or level *a*. A 35 similar contact wiper *b* is arranged to traverse the contacts of level *b* and a third wiper *c* is arranged to traverse the contacts of the level *c*. While, for purposes of illustration, we have shown only three levels on the selector switch illustrated in Fig. 5, it will be apparent to those 40 skilled in this art that any number of levels may be employed by merely adding such number of levels of contacts and such number of wipers as may be desired for the complete operation of a particular system. The shaft 60 which will be 45 employed to mount and to rotate the several wipers *a*, *b*, *c*, etc., is arranged to be normally returned to its "off" or "home" position by means of a biasing spring 63 illustrated diagrammatically herein as connecting with an arm 64 50 rigidly secured upon the shaft 60. The force of the spring 63 will be exerted in such direction that, whenever the wipers *a*, *b*, *c*, etc., have been moved away from their "home" position, tension 55 will be exerted by the spring 63 to return the wipers to their "home" position or "home" contacts. A stop 65 may be employed to limit the retractive movement of the wipers to their "home" position.

As a means for moving the wipers across and into contact with the several contacts of their levels *a*, *b*, *c*, etc., we have illustrated a ratchet 66 rigidly secured upon the shaft 60 and arranged to be moved in a counter-clockwise direction by 60 means of a motor pawl 67. The motor pawl 67 is fixed upon the outer end of a lever 68 which is in turn fulcrumed upon some stationary part of the selector-switch as indicated at 69. The pawl 67 is normally urged in a direction to move 65 the ratchet 66 in a counter-clockwise direction 70

by means of a tension spring 70 which has sufficient strength to overcome the tension exerted by the return spring 63. In order to cause the motor pawl 67 to step the shaft 60 one step in a counter-clockwise direction the motor-magnet 5 AS—M may be energized and de-energized. This will be apparent from the detailed description of the wiring diagram hereinafter. The motor-magnet AS—M will be constantly energized until its circuit is interrupted for the purpose of causing a selection of contacts by the selector-switch. Thus, upon the first operation of the motor-magnet AS—M to move the wipers away from their "home" position the motor-magnet AS—M 10 will be de-energized momentarily and again energized. The motor-magnet is so arranged as to oppose the effect of the tension spring 70, and hence immediately upon the de-energization of the motor-magnet AS—M the tension spring 70 15 will shift the ratchet 66 one notch in a counter-clockwise direction. 20

If the motor-magnet is interrupted more than one time, it will cause a ratcheting of the shaft 60 and the various wipers *a*, *b*, *c*, etc., a corresponding number of notches in a counter-clockwise direction and will move these wipers a corresponding number of contact points away from the "home" position, creating or establishing circuit connections to one of the contact points or sets in their respective levels, corresponding to the number of impulses (interruptions) given to the motor-magnet AS—M. Now, whenever the motor-magnet has been energized to move the wipers *a*, *b*, *c*, etc., away from their "home" positions the selector-switch should be 35 held in the new position. This is accomplished by providing a holding ratchet 71 rigidly fixed upon the shaft 60 and adapted to be engaged by a holding pawl 72. The holding pawl 72 is normally urged away from possible engagement with the ratchet 71 by means of a relatively light tension spring 73, but is held into engaging position with the ratchet 71 by the energization of the release magnet AS—R. As will be understood by those skilled in this art, as the ratchet 71 is rotated under the influence of rotation of the shaft 60 by the motor pawl 67, the pawl 72 will ride up on the notches in the ratchet 71, against the force exerted by the release magnet AS—R and as soon as the ratchet 71 has moved 40 one of its notches into alignment with pawl 72, pawl 72 will immediately snap back into notched 45 relation therewith.

Assuming now that the wipers have been moved three positions away from their home position; 55 namely, to a position engaging the fourth contacts in each of the levels, the entire switch may be restored to its off position or "home" position by de-energization of the release magnet AS—R. When the magnet AS—R is de-energized the spring 73 will pull the holding pawl 72 away from the ratchet 71 and by reason of an extension bar 74 secured to the holding pawl 72 and extending in front of the motor pawl 67, the retraction of the release pawl 72 will be accompanied by a movement of the motor pawl 67 60 out of possible engagement with the motor ratchet 66 and spring 63 will immediately snap the shaft 60 and the wipers back to their home position. 65

By employing this arrangement it will be apparent that each of the selector-switches, hereinafter referred to in the detailed description of the wiring diagram, will be advanced in a given direction from its "home" position and pass its 70 75

wipers over the several contacts of the levels associated with this switch. Whenever the selector is to be restored to its "off" position it will move backward to arrive at the home position.

Again it will be noted that certain operations, to be more fully hereinafter described, require that certain contacts or circuits be changed or altered with respect to the selector switches whenever the switches are away from their "home" positions or as hereinafter referred to their "off normal" positions.

In Fig. 5 we have illustrated such "off normal" switch as a leaf-spring switch structure wherein in a spring bar 75 is arranged as one of a pair of normally-closed contact members, the other of which includes a bar 76 toward which the spring 75 may be pressed as hereinafter described. A second pair of contacts forming a normally-open switch may include a spring contact member 78 arranged to be engaged by spring 75 to be urged thereby into contact with a cooperating contact bar 79 whenever the spring 75 is released by movement of the switch AS away from its "home" position. A suitable insulation strip 77 may be interposed between springs 75 and 78 to separate the electric circuits controlled respectively by contacts 75-76 and 78-79.

Whenever the wipers are in their "home" positions the switch contacts 75-76 and 78-79 are held in the positions shown in Fig. 5, but whenever the wipers are away from their "home" positions these contacts reverse their open and closed positions respectively. This operation is illustrated diagrammatically in Fig. 5 as including a cam 80 rigidly secured upon the shaft 60 in such manner and in such relation to the spring 75 that whenever the selector is in its home position the positions of the contacts 75-76 and 78-79 are as illustrated and whenever the selector switch has been moved away from its home position the cam 80 will be moved away from spring 75 allowing the spring 75 to reverse the positions of the switches.

As will appear from a study of the detailed description of the wiring system certain of the selector switches employed in our system are "automatically" operated so as to move the wipers from their "home" positions to their first positions, then to their second positions, then to the third positions, etc., until a vacant or "non-busy" line is found. In such event it may be necessary to provide upon each of those selector switches automatically interrupted contacts in the motor magnet circuit. These contacts are illustrated in Fig. 5 and designated by the reference character AS-I and may be connected in series relation with the coil of the motor magnet AS-M in such manner that whenever the circuit is initially completed to the motor magnet AS-M and is maintained completed the contacts AS-I will be interrupted each time the motor magnet operates to notch the ratchet 66 one notch. In this manner the motor magnet will be repeatedly energized and de-energized until the circuit for the motor magnet AS-M is broken externally of the selector. However, as will be remembered others of the selector switches must be operated only by the repeated closing or opening of an external circuit and in such instances the interruptor contacts AS-I may be either omitted or the circuit to the motor magnet AS-M or these switches may be connected to the motor magnet independently of the interruptor contacts AS-I.

In the detailed description of the wiring diagram hereinafter, the "off normal" switch just described is employed for establishing and maintaining certain circuit connections and the several levels associated with each of the selector switches, corresponding to levels a, b, c, etc., are referred to by specific reference characters designating their association with a complete selector-switch assembly. However, for simplicity in illustrating the wiring diagram each of the selector-switches referred to therein may be considered as being constructed and as operating in the manner just described with reference to Fig. 5.

COMPLETE SYSTEM

15

In order that the manner in which the system of our invention operates under the various operating conditions may be shown, we have illustrated a complete wiring diagram in Figs. 4A through 4J for the equipment illustrated diagrammatically in Fig. 1. To aid in tracing the circuits involved and the manner in which the machine operates, a brief description of the symbols used in these figures will be of assistance. The coils of all relays are shown on the diagram as a circle with appropriate reference characters inscribed within the circle. The reference characters selected have, as far as it is possible so to do, been selected as the initials of the portion of the system with which it operates and the functions it performs in that part of the system.

For example, one of the relay coils illustrated in Fig. 4E bears the legend within the circle AS-H. Translated this legend means "dictator-A's-selector-holding-relay". The contacts which are actuated by any particular relay coil will, in general, bear the same reference characters as the coil, with a suffix comprising a lowercase letter (a, b, c, etc.), identifying the separate contacts of the same relay from each other. For example, as shown in Fig. 4E, one of the contacts of the relay AS-H bears the designation AS-Ha indicating that this is one of the contacts actuated by the holding-relay AS-H.

Inasmuch as the timing of the operation of the certain contacts of the various relays is important in the operation of this embodiment of our invention, we have accordingly adopted a system of symbols for indicating the timing of the operation of the various relay contacts. For example, certain of the contacts are shown as particularly illustrated in Fig. 4K as normally open relay contacts, time-delayed in the opening direction. The "normally open" feature is apparent from the fact that the triangular shaped contact-completing bridge is shown spaced from circles representing the contact points. The direction in which the contact will move during the time-delayed operation is indicated by the direction in which the apex of the triangle is directed. Inasmuch as in Fig. 4K the apex of the triangle is directed away from the contact points, this symbol then indicates that the timed operation is that operation in which the contacting bridge moves away from the contact points or toward circuit-opening position.

In the same manner the symbol shown in Fig. 4L represents a normally-open contact, time-delayed in the closing direction while Fig. 4M represents a normally-closed contact, time-delayed opening, and Fig. 4N represents a normally-closed contact, time-delayed closing.

The symbols for normally-open relay contacts and normally-closed relay contacts of the in-

stantaneously operating variety are illustrated in Figs. 4P and 4R respectively. Mechanically operated contacts, such as those described as operated by cams or shafts of rotating parts of the machines, etc., are shown in Figs. 4S and 4T, respectively designating normally-open and normally-closed contacts, in which figures the contacting bridge is illustrated to indicate that there is no time-delayed operation in either direction. 5
10 The other symbols used in the drawings are either standard symbols or are pictorial in type, the operation of these devices or their functions being obvious from the association of the appearance of the device with the previously described construction and operation of the various parts of the mechanical equipment.

In order to simplify the illustration and the understanding of the system of our invention we have given the various pieces of equipment indicia referring to their operation and their location. For example, the two dictators and the two transcribers assumed to occupy office I have been assigned A, B, C and D respectively while the dictator assumed to be occupying office II 20 has been labeled X and the transcriber associated therewith occupying office III has been given the indicia Y. The equipment associated respectively with the several dictators A, B and X and the several transcribers C, D and Y has been 25 given reference characters in which letters A, B, etc. appear as the first letter of the complete reference character. For example, the selector for dictator A is labeled AS, while the auxiliary sequence selector for transcriber Y is labeled YSX, 30 the letter X in this case indicating auxiliary.

To reduce the complications and number of drawings in this application, we have illustrated the dictation system of our invention in Figs. 4A to 4J and have included in these drawings one complete and detailed showing of the equipment and wiring therefor for one dictator A situated in office I and that portion of the central station equipment which is directly controlled by dictator A.

We have also illustrated the complete and detailed wiring for only one of the twelve machines 45 I-10 and EAB and EX provided and have simplified the drawings by indicating duplicate equipment and wiring for dictators B and X, the central station equipment which they control 50 and all of the machines other than machine I as merely rectangles on the drawings and have designated each of these rectangles with appropriate reference characters. In the same fashion 55 we have illustrated in detail the equipment and wiring which is provided for operation by transcriber C and the central station equipment which is directly controlled by her. In the same manner we have illustrated in detail but one of the 60 nine sequence remembering devices together with its associated equipment, the others of these devices being indicated as rectangles with appropriate indicia.

The equipment which is located at the positions of transcribers D and Y and to be operated 65 and directly controlled by the transcribers D and Y has been indicated on the drawings as rectangles bearing appropriate designations (see Fig. 4C). It is to be remembered that the equipment and wiring which is not fully shown but is understood to be included within one of the 70 rectangles on these drawings is an identical duplicate with the corresponding portion of the equipment and wiring which is illustrated in detail.

For example, the machine unit and wiring of machine 2 is understood to be exactly the same as that of machine 1.

In order to properly and completely describe the construction and operation of the equipment and the cooperation of the various parts of the system with other inter-related parts, we will assume certain operating conditions and describe the manner in which the system operates under these conditions, carrying forward the description of the construction of the individual parts thereof as the description of the operation is continued. Initiating a dictating operation let us assume that the dictator A, occupying office I, desires to dictate material, that all of the machines are idle and that no transcribing operator is then working. Referring to Figs. 4A-4J we have indicated the equipment located in office I for dictator A as including a standard French-type telephone handset (Fig. 4C) which, as will be understood by those familiar with such telephones, comprises a microphone or transmitter 100, a sound reproducing device or receiver 101, with the usual induction coil 102 and capacitor 103 connected in circuit with a hook switch or 25 cradle switch 104 and an impulsing device or dial 105.

This equipment is connected as in the usual telephone practice to a pair of incoming wires 106 and 107, such connection including the attachment of wire 106 to one terminal of the cradle switch 104, the other contact of the cradle switch 104 being connected in a circuit 108a to an impulsing contact 108 of the impulsing device 105, the circuit then extending from the impulsing contact 108 by means of circuit 109 to the microphone or sound responsive device 100 and thence via circuit 110 through the induction coil 102 and out on the line 107.

By supplying direct current to the wires 106 40 and 107 will cause a speech current to flow through the conductors 106 and 107 in a manner readily understood by those skilled in the telephone art. A source of direct current is indicated in Fig. 4I as including a battery (so labeled) 45 which may be connected to a battery charger (so labeled) in turn supplied from a suitable source of power such as power-supply conductors 111 and 112. As in standard telephone practice, we have grounded the positive terminal 50 of the battery and have connected the negative terminal thereof through a disconnecting switch 113 to a conductor bearing the reference character L— (and shown as a heavy line). By tracing the ramifications of wire L— from Fig. 55 4I to Fig. 4C, it will be observed that the wire L— is connected directly to the conductor 106.

Again, as is usual in telephone practice, we provide a circuit 114 extending from the conductor 106 through the capacitor 103 and a secondary 60 winding of the induction coil 102 and by means of a wire 115 to another contact of the cradle switch 104. After passing through the cradle switch 104 the circuit then extends by way of wire 116 through the receiver or sound responsive device 101 and then back to the conductor 107 through conductor 110 and primary of induction coil 102. It will be observed that speech current impressed across conductors 106 and 107 will cause such sounds to be reproduced by the 70 device 101.

Short-circuiting contacts 117 of the impulse device 105 are provided in a circuit which shorts across the sound responsive device 101 so as to prevent clicks or other characteristic sounds re- 75

sulting from the operation of the impulsive contacts 108 from being reproduced in the operator's ear. It should be understood that the pair of wires 106 and 107 originating at the dictator's equipment located at the desk of the dictator A extends from there to the central office equipment, the operation of which will now be described.

It is to be understood that the previously described dictator's control equipment is identical with that employed in many telephone systems today and that the extension of wires 106 and 107 between this equipment and a central office equipment may be such that the wires 106 and 107 may be also connected to a telephone system so that the control equipment previously described may also be used as a standard telephone either for intercommunication purposes or for the placing and receiving of regular telephone calls to any part of the country which is served by such a telephone system.

It is to be further understood that it falls within the scope of our invention to provide switching means either at the location of dictator A or at the central office for transferring the wires 106 and 107 from the dictating system equipment to the telephone system equipment.

In describing the central office equipment we will first show how the necessary connections may be established to permit the dictating operator to record his dictation and then show in what fashion such dictation is recorded.

AUTOMATIC MACHINE SELECTION

In order that the dictator's operation of removing the handset from the cradle may automatically connect the control equipment to an available machine, we have provided a dictator's selector AS which will connect his equipment successively to the several machines 1-10 until a "non-busy" machine is found. The selector AS is connected to the dictator's circuit by a line relay AL (see Fig. 4D), the circuit for which extends between the conductor 107 and ground so that the removal of the handset from the cradle 104 completes the circuit extending from wire 106 through the dictating equipment back via wire 107 through the relay AL and thence to ground and the grounded side of the battery. Energization of the relay AL then closes contacts ALa (see Fig. 4E) extending from the battery negative L- through a wire 118 to a normally closed "off-normal" contact of the dictator's selector AS (see Figs. 4D and 4E), thence through conductor 119 and conductor 120 to previously described interrupter spring AS-I on the selector mechanism. The circuit continues via a conductor 121 through a motor magnet AS-M of the selector AS to ground. It will be readily observed that this allows current to flow from the battery negative L- through the motor magnet AS-M of the selector AS.

As soon as the motor-magnet AS-M is energized it will move its lever 68 (Fig. 5) to open interrupter contacts AS-I, again de-energizing motor-magnet AS-M and causing selector AS to step up one point from its "home" or "off" position.

It will be remembered in connection with the description of the mechanism of the selector relays employed in the dictating system of our invention that it is necessary for a release magnet AS-R of the selector mechanism to be energized at the time the motor magnet AS-M is energized in order that the pawl on the motor magnet

mechanism may be placed in an operative position relative to the ratchet wheel on the selector AS. In order to accomplish this we also extend the wire 118 down to the "off" or "home" terminal of level g of the selector AS contacted by the wiper 5 g when in its home position. We also extend a conductor 123 from the wiper g to the coil of a holding relay AS-H and include therein a normally closed contact AS-Sb of a sequencing relay AS-S. It will be observed that as soon as the contacts ALa of the dictator's line relay AL are closed, current will flow from the battery negative L- through the conductor 118, the wiper g of the selector AS, through conductor 123 and energize the holding relay AS-H.

In order that the energization of the holding relay AS-H may energize the release magnet AS-R we include the release magnet AS-R in a circuit 125 which extends from the battery negative L- and includes normally open contacts AS-Ha of the holding relay AS-H. It will therefore be observed that as soon as the contacts ALa of the dictator's line relay AL are closed the release magnet AS-R will be energized at the same time as motor-magnet AS-M so as to allow 25 the motor pawl of the motor magnet AS-M to be engaged with the ratchet wheel on the shaft of the selector AS. Since this initial movement of the wiper g from its "home" position would interrupt the circuit to holding relay AS-H and 30 cause de-energization of release magnet AS-R, we prevent such false operation by providing a normally-open "off-normal" contact in a circuit which extends from the conductor 118 through the "off-normal" contact and via conductor 124 35 to the holding relay AS-H. It will readily be seen that as soon as the selector AS had advanced to the first point, this "off-normal" contact was closed so as to complete the circuit from the battery L- through conductor 118, the "off-normal" contact, conductor 124, and the holding relay AS-H to ground. Re-energization of the holding relay AS-H then re-establishes the circuit to the release magnet AS-R.

As will be remembered in connection with the description of the mechanism included in the selector switch which we employ in this method of practicing our invention, energization of the release magnet AS-R engages the holding pawl with a ratchet wheel on the wiper shaft so as 45 to hold the wiper in its new position, engaging the first contact.

We have also connected the relay AS-S in a circuit 122 which extends from the conductor 120 through normally open contacts AS-Hb of the 55 relay AS-H, through the coil of the relay AS-S to ground, so that as soon as the relay AS-H is energized, the relay AS-S is also energized. This instantly closes the contact AS-Sa extending the circuit including conductor 119 through 60 to the wiper g of the dictator's selector AS as by means of the conductor 123 so that should the wiper g contact a terminal on its level that is energized from the battery negative, the circuit would be completed through the contacts AS-Sa 65 of the relay AS-S through conductor 120 to the motor magnet AS-M so as to cause the selector to advance another position. It will be remembered, however, that the preliminary assumption was made that none of the other dictators were 70 operating and therefore the first contact upon which the wiper g landed is not energized and consequently the motor magnet AS-M is not re-energized.

It will also be noted that the "off-normal" 75

contacts included in the circuit between conductors 118 and 119 were opened as soon as the selector AS advanced one point and thereby de-energized the sequencing relay AS-S and the motor magnet AS-M. The contacts of the relay AS-S are arranged to be time delay operating upon de-energization of the coil thereof and therefore it is apparent that inasmuch as the relay coil AS-S is not subsequently energized, the normally open contacts AS-Sa extending between conductors 119 and 123 will shortly re-open and thereupon disconnect the motor magnet AS-M from the wiper g, whereby wiper g remains upon its first position contacts, coupling dictator A to machine 1 (the first "non-busy" machine).

Attention is also called to the fact that we have included normally-closed contacts TS-Sb of the relay AS-S in a circuit connecting the conductors 123 and 124. It will be remembered, however, that inasmuch as the contacts AS-Sb of the relay AS-S are instantaneously operating upon energization of the coil for this relay that at the time of the previously described operation of the selector AS there was no interconnection of conductors 123 and 124. Almost immediately, however, after the opening of contacts AS-Sa of the relay AS-S, contacts AS-Sb of said relay connected between the conductors 123 and 124 will reclose.

It will be observed that this completes the circuit from the battery negative L- through conductors 118 and 124 and the aforementioned relay contacts via conductors 123 to the wiper g of the dictator's selector AS rendering the terminal contacted by wiper g "hot" or "busy" against any other dictator or transcriber who might seek connection with machine 1.

Inasmuch as we prefer to arrange the equipment in such manner that the various machines numbered 1 to 10 inclusive are arranged in numerical order on the dictator's selector AS so that machine 1 appears at the first point or point nearest the "home" position and machine 10 appears nearest the limit of travel of the dictator's selector, it will be observed that the movement of the dictator's selector AS to the position herein described now connects that selector in a position to place machine 1 in condition to receive the beginning of dictator A's dictation.

As will be more fully described hereinafter, there are seven control wires which may be required to be selectively energized or de-energized by the dictator in order to effect the necessary and desired control operation of the machine unit. We therefore provide on the dictator's selector AS seven levels, namely, a, b, c, d, e, f, and g, and seven wipers associated therewith, all mounted on the same shaft.

It will be apparent that each of these wipers is now contacting a point on the corresponding level which in turn corresponds to the machine 1, inasmuch as we have shown how removal of the handset from the cradle by the dictator A completes the controlling circuit so as to cause the dictator's selector AS to search for and find machine 1 as the first available idle machine and come to rest thereupon.

DICTATOR DICTATES

We will now illustrate in what manner the dictator A may control the operation of this machine 1. For this purpose let us first consider the circuits involved in the recording of speech upon the recording medium 14 of ma-

chine 1. For this purpose we have connected one terminal of the battery L- to a primary terminal of a dictator's recording transformer ADR (see Fig. 4D) and another terminal of said winding by means of conductor 126 through a pair of resistors R-1 and R-2 in series by means of a conductor 127 to the aforementioned and previously described conductor 107. It will be observed that direct current will flow from the battery terminal L- through wire 106 and the dictator's equipment including the microphone or sound responsive device 100, back through conductor 107 and through the dictator's line relay AL to ground, and that as the dictator speaks into the microphone 100, variations of the resistance of the sound responsive device 100 will cause a fluctuating current to flow through this circuit and consequently a fluctuating potential to appear between conductors 106 and 107.

Inasmuch as conductor 107 is connected through the series of resistors R-1 and R-2 to one side of the dictator's recording transformers ADR by means of conductors 126 and 127 and inasmuch as the other terminal of the primary winding of said transformer is connected by means of the wire L- to the conductor 106, it follows that such fluctuating potentials will appear across the primary of the transformer ADR. In order that this voltage across the primary of the transformer ADR may be amplified and conducted to the recording device of machine 1, we prefer to connect one terminal of the secondary of the transformer ADR to ground by means of conductor 128 (see Fig. 4D) and the other terminal to a recording-amplifier ARA by means of a conductor 129 connected to the other terminal of the secondary winding of the transformer ADR through a normally-open contact AVXa of a relay AVX and to the input terminal of the amplifier ARA by means of a conductor 130.

Assuming for the time being that the contact of the relay AVX is closed it will be seen that inasmuch as the other input terminal of the amplifier ARA is connected to ground by means of conductor 131, that induced voltage appearing between the conductors 128 and 129 of the transformer ADR will also be impressed upon the input of the recording amplifier ARA.

We prefer to connect the output of the amplifier ARA in such manner that one terminal of the output is also connected to ground by means of conductor 131 while the other terminal is connected by a conductor EA through a normally-closed contact of relay AEL to the wiper d of dictator's selector AS.

Power for operating the amplifier ARA may be derived from the battery negative L- through a circuit 131a which extends from the battery negative L- through a normally-open contact ALc of the line relay AL to the power supply connection of the amplifier ARA. The other supply terminal is connected to ground. The contacts ALc are preferably made time-delay operating in the opening direction so that dialing impulses which momentarily de-energize the relay AL will not de-energize the amplifier ARA.

The wiper of level d of the dictator's selector AS resting upon the first contact of this level passes such potential to a wire connected to this point and which we have indicated as E1.

The designation E1 on this wire may be interpreted as follows. The letter E indicates that the function of this wire is to convey speech currents, as does the wire EA previously described. The secondary designation 1 following 70

indicates that this wire is associated only with machine 1. By tracing this wire through the machine-multiple group (through Figs. 4D, 4E, 4J, 4I and 4H to Fig. 4G) to machine 1 it will be observed that wire E1 extends unbroken into the mechanism of machine 1 wherein is connected to a normally closed contact 1PDBa (now closed) of a point defining relay 1PDB and thence by means of a conductor 132 to the recording and reproducing device 17 on machine 1. Interposed in conductor 132 are a pair of normally closed contacts 1DSXy and 1RSy connected in parallel and at least one (1DSXy) of which will be closed at this time as will more clearly appear hereinafter. The recording and reproducing device 17 has its other terminal connected to ground so that the aforementioned amplified speech voltage is caused to appear across the recording and reproducing device 17.

If we assume the contacts 1PDBa to be closed (it will be shown hereinafter how during the recording operation these contacts are maintained in a closed position) it will be seen that alternating voltages generated by the dictator's microphone 100 are impressed across the primary of the transformer ADR and transformed thereby and in turn impressed across the input of the amplifier ARA. The amplifier ARA is then operated to amplify these voltages to a magnitude sufficient to insure good and clear recording. These voltages are then transmitted over the circuit previously described through the dictator's line selector AS to the recording and reproducing device 17 contained in machine 1, so that such sound as the dictator may emit into the microphone 100 may be recorded in the recording medium of machine 1.

In the description of the foregoing circuit and its operation it was assumed that the relay AVX was energized and that its contacts AVXa which are connected between conductors 129 and 130 were closed during the recording operation. The energization of relay AVX is controlled by voice-responsive relay AV (see Fig. 4D) which is illustrated as being connected between conductors 106 and 127. The voice-responsive relay AV is of a type well known in the electrical recording and radio arts which is responsive solely to alternating currents bearing the characteristics of sound. It has been shown that speaking into the microphone 100 will cause speech potentials to appear between the conductors 106 and 127, and it follows, therefore, that these speech potentials will also be impressed on the coil of the relay AV connected between these wires. We prefer to make the relay AV of such type and sensitivity that the normal speech-sound emitted into the microphone 100 will energize the coil of this relay sufficiently to operate its contacts. Inasmuch as the relay AV is of necessity a very sensitive relay and includes very delicate mechanism, we prefer to provide the heavier and more rugged auxiliary relay AVX for performing the actual switching operations in response to the operation of the relay AV.

We have accordingly connected normally-open contacts AVa of the relay AV in a circuit extending from the battery negative L- by means of conductor 133 to the coil of the auxiliary voice-operated relay AVX which is in turn connected to ground so that when relay AV is energized and closes its contacts AVa the relay AVX will be energized. Thus whenever the dictator A speaks into the microphone, the relay AVX will be energized so as to close its previously described contacts

AVXa and complete the circuit between conductors 129 and 130 so as to connect the secondary winding of the transformer ADR to the input of the recording amplifier ARA as has been previously described.

In order that the relay AVX may be maintained in an energized condition during the extremely short pauses which frequently occur in the normal dictation of material, we prefer to make the contacts AVa of the relay AV which are included in circuit 133 of the instantaneously closing, time-delay opening type; so that even though the relay AV may be momentarily de-energized as the result of the dictator A hesitating in his dictation, the contacts AVa thereof will be kept closed for this brief instant.

Inasmuch as the following explanation of the operation of machine 1 when being controlled by a dictator, such as dictator A, depends upon certain dictating control relays 1D and 1DX associated with the mechanism of machine 1 and which operate a large number of contacts which appear in various machine-unit control circuits, we will at this time describe the manner in which the relays 1D and 1DX are energized so as to condition machine 1 for operation by a dictator, as distinguished from the operation of this machine-unit by a transcriber. We accordingly attach a wire GA (see Figs. 4D and 4E) to the battery negative L- and continue this wire to a wiper e of the dictator's selector AS. Inasmuch as this wiper, together with all of the other wipers of the selector AS, has been assumed to be contacting the first point of this selector corresponding to machine 1, it follows that battery negative is now applied to a wire G1 attached thereto.

Tracing the wire G1 through Figs. 4D, 4E, 4J, 4I, 4H, 4G and 4F through the machine-multiple group of conductors to machine 1, it will be seen that wire G1 extends unbroken into the mechanism of machine 1 (see Fig. 4G), at which point it is connected to the coil of the relay 1D. Hence, as soon as the dictator A removes the handset from the cradle relay 1D will be energized when the dictator's line selector AS has selected machine 1 as the machine upon which he will record his dictation. An auxiliary relay 1DX is included in a circuit 134a which extends from the battery negative L- through a normally closed contact 1DSXa of a locking relay 1DSX and through normally open contacts 1Db of the relay 1D to coil of the relay 1DX and then to ground in such manner that when relay 1D is energized and closes its contacts 1Db, (the contacts 1DSXa included in circuit 134a are closed, as will be pointed out hereinafter) circuit 134a is therefore completed to energize the relay 1DX.

The relay contacts associated with relays 1D and 1DX control the various functions of machine 1 which will more fully appear from a consideration of these separate functions.

For example, as it has been pointed out in connection with the description of the machine units, we prefer to alternately stop and start the rotation of the recording medium 14 in accordance with the periods of dictation and pauses occurring in normal dictation. As one means of accomplishing this result we arrange the record revolving motor 1RM under control by the voice-responsive relay AV (and AVX) so that the motor is started and continues to run whenever the dictator A is speaking and stops whenever the dictator pauses. For this purpose we have connected a normally-open contact AVXb of the relay AVX (see Fig. 4D) in a circuit which ex-

tends from the battery negative L— through a conductor FA to wiper b of the dictator's selector AS. As was the case with the wire EA, the wire FA includes also a normally-closed contact of the relay AEL. For the time being it will be assumed that the relay AEL is de-energized so that this circuit is completed. In order that energization of the relay AVX (as the result of the dictator A speaking into the microphone 100) and the 10 closing of the contacts AVXb to connect the battery negative L— to wiper b of the dictator's line selector AS may be effective in starting the rotation of the recording medium of machine 1, we have connected a wire F1 to the first point (corresponding to machine 1) on level b of the selector AS so that the wiper b completes the circuit between wires FA and the wire F1 which extends to the record rotating mechanism of machine 1.

20 Tracing the wire F1 through the machine multiple group through Figs. 4D, 4E, 4J, 4I, 4H, 4G and 4F, to machine 1 will show that the wire F1 extends unbroken through to the equipment of machine 1. Within the mechanism of machine 1 the wire F1 (see Fig. 4G) is connected through a normally open contact 1Da of the relay 1D by means of a conductor 134 to one side of a relay 1VR, the other side of which is connected to ground.

30 Hence, energization of the relay AVX resulting from the dictating operator A speaking into the microphone 100 will complete the circuit to energize the coil of the relay 1VR. The relay 1VR will therefore be alternately energized and de-energized in accordance with the periods of dictation and pauses resulting from the dictating operation of the dictator A. In order that the energization and de-energization of the relay 1VR may be used to alternately stop and start 35 the rotation of the recording medium we have accordingly connected a contact 1VRa of this relay in a circuit supplying the record rotating motor 1RM which circuit includes a conductor 135 which in turn is connected to the battery negative L— through normally-open contacts 1DXa of the auxiliary relay 1DX and extends through a conductor 136 which is connected to normally-closed contacts 1SBa of a relay 1SB. A conductor 137 extends from the contacts 1SBa 40 to normally-closed contacts 1SAa of a relay 1SA and a conductor 138 extends therefrom to the field and armature of a record rotating motor 1RM. The other terminal of the record rotating motor 1RM is connected through normally-closed contacts 1REa of a relay 1RE to ground.

45 We have connected a brake coil 1RB parallel with the motor 1RM so that whenever the motor 1RM is de-energized, as is the case when it is desired to stop the rotation of the recording medium, the brake 1RB will also be de-energized so as to allow the spring actuated mechanism normally included therein to engage the shaft of the recording medium and instantly stop the rotation. While whenever the record rotating motor 1RM is energized, the coil 1RB of the brake mechanism will also be energized so as to release the brake from the shaft of the recording medium.

50 Summarizing briefly at this point, it will be seen that whenever the dictator A speaks into the microphone 100 the recording medium will be rotated and the speech will be recorded thereon, while whenever the dictator pauses the recording medium will be stopped, subject to restarting 55 upon resumption of speech to be recorded.

Hence, the recorded material will be substantially continuous upon the record 14.

5 In order to reduce the number of mechanically actuated contacts, such as the limit switch contacts and the contacts of the point defining means PDM, and to simplify their operation, we prefer to relay all such mechanical contacts. We have accordingly included a relay 1ES (see Fig. 4F) in a circuit 139 which extends from the battery negative L— through the coil of the relay 1ES 10 to ground and includes therein the normally open limit switch contacts ES. We have included the limit switch contacts RS in a circuit 140 with a coil of a relay 1RS, the other side of the relay 1RS being connected to ground. We have also 15 connected the coil of a relay 1RE in a circuit 141 extending between the battery negative L— and ground and including normally open contacts of the recording end limit switch RE. In a similar manner a relay 1EE is connected in a circuit 142 20 extending between battery negative L— and ground and including normally open contacts of the information end limit switch EE.

25 We likewise connect the movable arm 43 of the point defining mechanism PDM to the battery negative L— and provide a circuit 143 extending from the contact segment 44 to the coil of a relay 1PDB while a circuit 144 extends from the other contact segment 42 of the point defining device to the coil of a relay 1PDA. The coils of the relays 30 1PDB and 1PDA are also connected to ground.

Dictator controls equipment to "play-back" previously dictated material

35 Let us at this time assume that dictator A has recorded a considerable amount on the recording medium and that at this time desires to play back a portion of that dictation occurring near the beginning of the dictated material. In order that the dictator may accomplish this, we prefer that 40 he use the impulsing device or dial 105 incorporated as a part of the standard handset provided for him. We have arranged the equipment in such manner that dictator A may dial any one of the numbers from "three" to "nine" and thereby 45 cause the recording and reproducing device 17 to travel back toward the forepart of the record and reproduce to the dictator A the material recorded at a corresponding point. We prefer to arrange this equipment so that by dialing "three" 50 on the dial 105 the dictator causes the recording and reproducing device 17 to move back a very short distance along the recording medium so as to pick up only the last few words which he recorded previously. The subsequent numbers 55 "four, five, six, seven, eight and nine" we prefer to arrange in such manner as to cause the recording and reproducing device 17 to travel back toward the forepart of the recorded dictation in increasingly greater amounts so that by dialing 60 "nine" the dictator causes the recording and reproducing device 17 to reproduce from the portion of dictation recorded a considerable time before the operation is started which is to result in the reproduction of this previously recorded dictation.

65 As will be understood by those skilled in the telephone art, the operator dials "three" by inserting index finger in the corresponding hole in the plate, pulling the dial around to the hook, 70 and releasing it, and the dial will be spring returned so as to interrupt the contacts 108 in such manner as to momentarily interrupt three times the circuit through which the relay AL is energized. This causes the contacts of the relay 75

AL to also be momentarily operated the same number of times as the number dialed on the impulsing device 105.

In order that these dialing operations may be utilized to perform the desired machine operations, we provide a control selector ACS for dictator A (see Fig. 4D), and connect the operating equipment therefor in circuits which are responsive to operation of the dictator A's impulsing device 105. We have accordingly connected a normally-open contact ALb of the dictator's line relay AL in a circuit which extends from the battery negative L— through said contacts and through a conductor 145 to the motor magnet ACS—M of the control selector ACS.

It will be seen that if the dictating operator dials "three" for example, the motor magnet ACS—M will be interrupted three times so as to cause the wiper associated with relay ACS to be moved to the third point on its level. To hold the selector wiper on this third point we have included a release magnet ACS—R for the control selector ACS and provide therefor a holding relay ACS—H in a circuit 146 which also extends from the battery negative L— through the normally open contacts ALb but includes a normally closed "off-normal" switch of the control selector ACS so that whenever the contacts ALb of the relay AL are closed as by removing the handset from the cradle provided therefor, the relay ACS—H will be energized. The circuit for release magnet ACS—R extends from the battery negative L— through contacts ALb, thence by way of conductor 147, normally open time-delay contacts ACS—Ha of the holding relay ACS—H and continues through a conductor 148 to the release magnet ACS—R of the control selector ACS.

It will be observed that, whenever the motor magnet ACS—M of this selector is operated to move the wiper a off of the first point, circuit 146 energizing the coil of the relay ACS—H is opened and said relay is immediately de-energized. The circuit 147 provides a holding circuit through normally open (now closed) contacts of the relay ACS—H to the release magnet ACS—R so as to maintain the wiper of the control selector ACS in the position to which it was dialed by the dictator. In view of the fact, however, that the coil of the relay ACS—H is de-energized as soon as the control selector ACS is moved, it follows that after the elapse of the predetermined time for which the operation of the contacts ACS—Ha are set, the circuit 147 to the release magnet ACS—R will be interrupted to allow the wiper of the selector ACS to be spring returned to its "home" position. The manner in which the advancing of the control selector ACS to the desired position, holding it there momentarily and allowing it to return to its "home" position is effective in causing the recording and reproducing device 17 of the machine 1 to move back toward the forepart of the record and reproduce material therefrom will now be described.

It will be noted that we have connected the battery negative L— directly to the wiper of the dictator's control selector ACS so that when said wiper moves to the previously described third point on said selector, a circuit 149 will be completed from said third point to the coil of one of a group of time delay relays ATD2, ATD3, etc., to ATD9 inclusive, the particular relay energized by this circuit 149 being relay ATD3. The time delay relays ATD2, ATD3, etc., are of the self timing type and are each provided with a self holding circuit, the self holding circuit for the

relay ATD3 extending from the battery negative L— through normally open contacts ATD3a of the relay ATD3, conductor 150, normally closed contacts ATD3b, to the coil of the relay ATD3.

It will also be noted that the normally open contacts ATD3a are arranged with a time-delay in the closing direction, while the normally closed contacts ATD3b are arranged with a time-delay in the circuit opening direction. It will be noted that if the contacts ATD3b remain closed upon the energization of the relay ATD3, the relay will be maintained energized through circuit 150 by the closing of the normally open contacts ATD3a. We prefer to make the time of closing of the contacts ATD3a of just sufficient length of time so that the momentary energization of the coil ATD3 resulting from the wiper of the selector ACS travelling past the third terminal thereof in its travel toward a subsequent terminal will not cause the relay ATD3 to complete its self holding circuit 150 as in normal operation. We also prefer to cause the wiper of selector ACS to remain upon its selected contact a sufficient length of time to allow the contact ATD3a to close and thereby complete the self holding circuit 150 to 25 the coil of said relay.

The contact ATD3b, also included in the self holding circuit 150, is provided with a time-delay in accordance with the amount of time required to move the reproducing and recording device 30 17 back toward the forepart of the recording medium a distance corresponding to that represented by dialing of the number "three." It will be observed by inspection of the self holding circuit 150 that as soon as this time-delay imposed on the contacts ATD3b has elapsed, the self holding circuit 150 will be interrupted by the opening of these contacts. Interruption of the self holding circuit 150 obviously de-energizes the coil of the relay ATD3 allowing the contacts thereof to assume their previously de-energized positions.

In order that the timing operation provided by the relay ATD3 may be utilized to move the recording and reproducing device 17 back toward the forepart of the record we have included normally open time operated contacts ATD3c of the relay ATD3 in a circuit which extends from the battery negative L— to a wire HA, so that the wire HA may be connected to the battery negative L— for a length of time corresponding to the time for which the relay ATD3 is set. In a like manner we also connected in parallel with the contacts ATD3c the corresponding contacts of relays ATD4, ATD5, ATD6, ATD7, ATD8, and ATD9, so that operation of any of these time-delay relays will cause the conductor HA to be connected to the battery negative L— for the corresponding time.

We continue the conductor HA to the wiper f of the dictator's selector AS through normally closed contacts of the relay AEL so that negative battery potential is supplied to the wiper f of the dictator's selector AS and therethrough to a wire H1 connected to the first point of the level f of the selector AS. Tracing the wire H1 through machine multiple group down to the machine 1 (through Figs. 4E, 4J, 4I, 4H, 4G and 4F), it will be observed that wire H1 continues in an unbroken fashion into the mechanism of machine 1 where it is connected to a conductor 151 through normally closed contacts 1REd of limit relay 1RE. The conductor 151 continues to the coil of a relay 1SB and thence through a conductor 152 to a contact 1ESb of the limit relay 1ES and then 75

- to ground. In view of the fact that the limit relay 1ES is energized only at such time as the information reproducer 19 is at the start of the recording medium, it follows that relay 1ES is de-energized and that contacts 1ESb and 1REd occurring in circuits 152 and 151 are closed.

It therefore directly follows that as soon as the dictating operator A dials "three" the relay 1SB will be energized. The relay 1SB is a shift-back relay for causing the recording and reproducing device 17 to go back toward the forepart of the record.

Whenever the relay 1SB is energized by an operation of the dictator in the manner previously described, contacts 1SBb (see Fig. 4G) of this relay will complete a circuit 153 extending from the battery negative L — to the shifting solenoid 1SS on machine 1 . As has been previously pointed out in connection with the mechanical equipment of the dictating machine unit employed in the system of our invention, energization of the solenoid 1SS will cause the feed nut 19 to be removed from the normal recording feed screw 18 and will cause feed nut 28 to be connected to the high speed advancing and retracting feed screw 26 . If the feed screw 26 is rotated in the proper direction, the reproducing device 17 will accordingly be moved toward the forepart of the record.

In order that energization of the relay 1SB in accordance with the operator A's desire to move the recording and reproducing device 17 back toward the forepart of the record may cause the motor 1HSM for machine 1 which rotates the high-speed advancing and retracting screw 26 to be energized in the proper direction, contacts of the relay 1SB are included in a reversing circuit for this motor in the following manner. Normally open contacts 1SBc of the relay 1SB are connected in a circuit 154 extending from the battery negative L — and through normally closed contacts 1ESA of the limit relay 1ES to the "reverse terminal" of the motor 1HSM . The motor 1HSM is illustrated as being a common split-series-field type, provided with a "forward," a "reverse" and a "common" terminal. Closing the contacts 1SBc then allows current to flow from the battery negative L — through the conductor 154 and the motor 1HSM in such direction as to cause the motor to rotate the high-speed advancing and retracting screw 26 to move the recording and reproducing device 17 back toward the forepart of the record.

It is apparent from the manner in which these connections are established that such movement of the recording and reproducing device 17 will continue as long as the relay 1SB is maintained energized or a time equal to the setting of the self timing relay ATD3 .

If it is desired to run the recording-reproducing device 17 further back to listen to material further back along the record, the number "four," "five," etc., may be dialed to bring into action the respective relays ATD4 , ATD5 , etc., each of which is so differently timed as to cause the high-speed motor HSM to operate for a corresponding time.

It will be noted also that inasmuch as circuits 136 and 137 include contacts 1SBa of the relay 1SB , these circuits feeding the record rotating motor 1RM are interrupted so that the recording medium will not be rotated during the travel of the recording and reproducing device 17 back toward the forepart of the record. As soon, however, as this travel is completed the de-

energization of the relay 1SB restores circuits 136 and 137 to their normal complete condition through the closing of the normally closed contacts 1SBa .

Point defining mechanism "counts-back" amount of rearward travel

It will be remembered in connection with the description of the point-defining mechanism PDM employed in the system of our invention that said point defining mechanism operates to measure the amount the reproducing and recording device 17 is moved from the point of last recording or transcription. In the case under consideration it measures the distance the recording and reproducing device 17 moves toward the forepart of the record as a result of the previously described operation. It will be further remembered in connection with the mechanical description of this device that such measurement will not be made unless the magnetic clutch 1PDC associated therewith (for machine 1) is de-energized during such time as the recording and reproducing device is caused to move from the point of last recording and is kept energized at other times. In accordance with this arrangement we have therefore included the magnetic clutch 1PDC (see Fig. 4F) in a series circuit 154a which extends from the battery negative L — through normally open (now closed) contacts 1Dc of the relay 1D and includes also normally closed contacts of the following relays: 1PDA , 1PDB , and 1SB connected in series relationship. It will be noted that the opening of the normally closed contacts 1SBd included in the circuit 154a will cause the clutch 1PDC to be de-energized as soon as the relay 1SB is energized to cause the recording and reproducing device to move back toward the forepart of the record. In view of the de-energization of the clutch 1PDC the operation of the point defining mechanism during the retracting movement will cause the arm 43 thereof to engage the contact segment 44 corresponding to the part of the record previously recorded. Referring to circuit 143 previously described, it will be noted that this will complete circuit 143 so as to energize the relay 1PDB .

Referring now to circuits 135 and 136 which include normally open contacts 1VRa of the voice operated relay 1VR , it will be seen that we have provided a shunt circuit around said contact and have included therein normally open contacts 1PDBb of the relay 1PDB so that as soon as the recording and reproducing device 17 is moved toward the forepart of the record away from the point of last recording, the shunt circuit just described will be completed and short out the normally open contacts 1VRa of the voice operated relay 1VR .

In view of the previous description relating to the energization and de-energization of the record rotating motor 1RM it will be seen that the closing of the contacts 1PDBb will perform the same operation as the closing of the contacts 1VRa would under normal circumstances. It has also been pointed out however that as long as the relay 1SB is energized the circuit through the record rotating motor 1RM is interrupted between conductors 136 and 137 . It is therefore apparent that, inasmuch as the contacts 1PDBb of the relay 1PDB are closed, as soon as the recording and reproducing device 17 in its movement back toward the forepart of the record has arrived at the desired point (such point being

indicated by the de-energization of the relay 1SB) the closing of the contacts 1SBa will complete the circuit represented by conductors 135, 136, 137 and 138, so as to cause the record rotating motor 1RM to rotate the recording medium to reproduce material recorded at this point and to advance the recording and reproducing device 17 at reproducing speed toward the point of last recording.

10 *Dictator listens to playback of previously dictated material*

In order that the subsequent forward movement of the recording and reproducing device 17 over the previously recorded portion of the recording medium may result in such previously recorded material being reproduced as sound in the dictator's sound responsive device 101, we have provided the necessary mechanism, equipment and connections for accomplishing this result. The reproduction is accomplished by transmitting the reproduced sound from the recording and reproducing device 17 back to the dictator's local equipment over a wire J1 extending therebetween.

The wire J1 is connected to the recording and reproducing device 17 by means of a pair of conductors 155 and 156. The conductor J1 extends through a normally open contact 1PDBc of the point defining relay 1PDB and thence through conductor 156 and a normally closed contact 1SAb of the relay 1SA, through conductor 155 and a normally closed contact 1SBe of the relay 1SB to conductor 132 and the recording and reproducing device 17. It will be observed that speech voltages generated in the recording and reproducing device due to said device moving back over the previously recorded material at reproducing speed will be transmitted from conductor 132 through conductors 155 and 156 to conductor J1 providing the aforementioned relay contacts are closed. It will be assumed that the normally closed contacts 1SAb of the relay 1SA included between conductors 155 and 156 will be in the closed position. The contacts 1PDBc of the point defining relay 1PDB are closed by the energization of relay 1PDB in the manner previously described. The normally closed contacts 1SBe inserted in the circuit between conductors 132 and 155 will be open during such time as the recording and reproducing device 17 is being moved back toward the forepart of the record and closed during the time the recording and reproducing device is being re-advanced along the previously recorded material in the manner previously shown.

It is therefore apparent that the voltages described as being induced in the winding of the recording and reproducing device 17 and impressed upon the conductor 132 will consequently occur also upon the conductor J1. Tracing the conductor J1 it will be found to continue through the multiple group through Figs. 4F, 4G, 4H, 4I, 4J, 4E and 4D to the first point on level a of the dictator's selector AS. Inasmuch as the wiper a on this selector is connected to the first point in the manner previously described, conductor J1 is thus coupled to a conductor JA which is also connected to this wiper through a normally closed contact of the relay AEL. The conductor JA connects to the input circuit of a dictator's playback amplifier APA through a normally closed contact ATD2d of the self timing relay ATD2. It will be remembered that since the self timing relays ATD2, ATD3, etc., are responsive only to

dial operations by the dictating operator A, the normally closed contacts ATD2d occurring in the conductor JA will be closed so that an electrical circuit will be completed over conductor JA to the input of the amplifier APA.

It will be seen that, in view of the connections established at this time, speech voltages induced in the recording and reproducing device 17 will be impressed over the previously described circuit on the input of the dictator's reproducing amplifier APA. The output of this amplifier is preferably connected by means of conductors 157 and 158 to the primary of a dictator's playback transformer ADP. Secondary windings of this transformer are connected to the conductors 107 and 126 so that the amplified voltage reproduced at this point will exist between conductors 107 and 126. Inasmuch as conductor 126 is connected to conductor 106 through the primary winding of the dictator's recording transformer ADR, it follows that the reproduced speech voltages will appear across conductors 106 and 107 and will therefore be transmitted through circuits 114, 115 and 116 (see Fig. 4C) to the dictator's sound responsive device 101 so as to reproduce as sound the previously recorded material over which the recording and reproducing device 17 is being moved.

The amplifier APA may be supplied with power required for its operation through connection to the previously described conductor 131a so that the amplifiers APA and ARA are connected in parallel between the battery negative L— and ground.

It will be further observed that although the reproduced speech sounds are caused to pass through primary winding of the dictator's recording transformer ADR, such sounds are not impressed upon the input of the dictator's recording amplifier ARA because the normally open contacts AVXa of the relay AVX included between conductors 129 and 130 are open.

It should be pointed out at this time that although speech voltages appearing across the wires 106 and 107 as a result of sound impressed upon the microphone 100 will operate the voice responsive relay AV and subsequently connect the secondary of the dictator's recording transformer ADR to the input of the recording amplifier ARA, speech sounds originating at the secondary of the dictator's playback transformer ADP and impressed across conductors 107 and 126 will not cause the operation of the voice operated relay AV.

To accomplish this the voice operated relay AV is connected as the balance responsive device in a Wheatstone bridge circuit in which the series resistances R1 and R2 associated with conductor 127 forms one leg and the equipment at the dictator's recording station and the primary of the transformer ADR comprise the other leg. It will be further noted that the application of the speech sound to the bridge at the conductors 107 and 126 causes the current resulting from these potentials to flow uniformly down each leg of the bridge and that, if the impedances of the various elements forming the bridge are properly proportioned, as is well known in the art, the voltage between conductors 127 and 106 (the conductors supplying the voice operated relay AV), will be zero and that although voltages appear between conductors 106 and 107 to operate the sound responsive device 101, no voltage appears across the terminals of the voice operated relay AV. On the other hand, voltages originating from the dictator's equipment and impressed across conduc-

tors 106 and 107 do not establish a uniform flow of current down either of the two legs of the bridge so as to give a zero potential across the voice operated relay AV. It is apparent then 5 from the foregoing description that whenever the voltages corresponding to speech sounds originate at the dictator's control station as the result of the dictator speaking into the microphone 100, the voice operated relay AV will be operated there- 10 by, while if the previously described voltages originate as the reproduction of material from the machine to which the control station is connected, the voice operated relay AV will not be operated. 15

Summarizing briefly, it will be remembered that 15 we have shown how the dictating operator, having been automatically connected to machine 1 for the purpose of recording dictation and after having recorded dictation thereon in the manner described, wishing to play back a portion of the 20 previously recorded material, may accomplish such reproduction by dialing a number, for example "three," on the dialing device 105. It has been shown that this operates in such fashion as to cause the recording and reproducing device to 25 move back toward the forepart of the recording medium to a point corresponding to the time required for the self timing relay actuated by dialing "three" to operate and at that point causes the reproduction of previously recorded material 30 as sound in the presence of the dictator.

Dictator resumes dictation

After having listened to a portion of the previously recorded material, the dictator may wish 35 to return the recording and reproducing device to the point where he discontinued recording and to continue recording his dictation, or he may desire to listen to all of the material which has been recorded between that point and the point 40 where he left off dictation.

For the purpose of illustration let us consider the latter case, in which case the reproduction of the material continues in the manner previously described until the point-defining mechanism 45 PDM is actuated to recondition the machine for recording at the point at which the recording was interrupted. It will be remembered in connection with the mechanical discussion of the point-defining equipment that inasmuch as the 50 arm 43 of the point-defining-mechanism is contacting the segment 44 corresponding to the recorded portions of the record, advancement of the recording and reproducing device toward the point of last recording also advances this arm 55 43 over that contact segment 44. The gearing arrangements are so established that the contacting arm 43 leaves the contact segment 44 at a point corresponding to the point of last recording at the time the recording and reproducing 60 device 17 has been advanced to the point of last recording (see Fig. 4F) at which time the point defining relay 1PDB will be de-energized. De-energization of this relay thereupon opens contacts 1PDBb and stops the rotation of the recording medium, thus stopping further advance 65 of the recording and reproducing device 17 toward the end of the record and places the record rotating motor 1RM again under the control of the voice operated relay 1VR.

70 Reference to the circuit supplied by wires E1 and J1 (see Fig. 4G) will indicate that the de-energization of the relay 1PDB will interrupt the circuit J1 at contacts 1PDBc over which the previously recorded material was transmitted to 75 the reproducing device at the dictator's control

station and will re-establish circuit E1 at contacts 1PDBa so that resumption of the recording of dictation may take place. In order that the dictator A will be apprised of the fact that the equipment is now in a condition for recording further dictation and for continuously apprising the operator that this condition exists during such time as the equipment is in a condition for recording dictation, we provide an "O. K. tone" generator (see legend Fig. 4I) 10 which is connected to the supply conductors 111 and 112 and is preferably so constructed as to generate a soft, smooth hum which we prefer to reproduce in the sound reproducing device 101 of the dictator's equipment during such time as 15 the dictator is not dictating but the equipment is ready to record dictation.

For this purpose we extend a wire OK from this tone generator to a wire KA (see Fig. 4D) through a normally-closed contact AVXc of the voice operated auxiliary relay AVX so that whenever the voice operated relay is energized, as the result of the dictator speaking into the microphone 100, the connection between the wire OK and the wire KA will be interrupted. The wire 20 KA (as will be described in detail hereinafter) is extended to one of the machines 1 to 10 which is in operation and is controlled thereby to complete or interrupt said wire in terms of whether or not the machine is in a condition to record 25 additional dictation. The circuit is extended from the machine to the dictator's sound reproducing device 101 so as to reproduce the characteristic tone in the dictator's ear whenever the machine is in a condition for recording additional dictation and when the dictator is not 30 actually dictating.

We therefore extend the wire KA to the wiper c of the dictator's selector AS through normally-closed contacts of the relay AEL. As has been 35 pointed out, the wiper c, as is common with all the other wipers, now is connected to the first selector point corresponding to the operation of machine 1. We therefore extend a wire K1 (see Fig. 4D) from this point which may be traced 40 through the machine-multiple group as extending (through Figs. 4D, 4E, 4J, 4I, 4H, and 4G) into the dictating machine 1 where it is connected to the reproducing wire J1 by means of a normally-closed contact 1PDBe of the point defining relay 1PDB. 45

It will be observed that during the operation of the machine by the dictator A that the energized condition of the relay 1PDB indicates that the machine is not in a condition to record subsequent dictation and that as a result of such energization the normally-closed contacts 1PDBe thereof will be open so as to interrupt the connection between the wires K1 and J1. On the other hand the de-energization of the relay 1PDB 50 so as to close the normally-closed contact 1PDBe and connect wire K1 to J1 indicates that the machine is in a condition to record further dictation. Inasmuch as the OK tone is impressed on the wire K1, the connection by the contact 55 1PDBe of the wire K1 to J1 allows such tone to be transmitted back over the reproducing wire J1 and be reproduced in the sound reproducing device 101 of the dictator A's equipment in the same fashion as speech sound were transmitted 60 over the wire J1 and reproduced thereby.

It is therefore apparent that whenever the dictating operator hears the characteristic tone in his ear as reproduced by the reproducing device 101 he is assured that the machine is in a 75

condition to record his dictation. It will also be observed that the contact AVXc connecting wire OK to wire KA (see Fig. 4D) operates so that whenever the dictator begins speaking for the purpose of recording dictation, the OK tone which is reproduced by the sound reproducing device 101 will be interrupted so as to not distract the dictator and confuse and interrupt his dictation.

10 Assuming however that, after having listened to only a portion of the material recorded at the forepart of the record, dictator A wishes to immediately resume his dictation at the point on the recording medium at which he last dictated 15 without listening to the remainder of the material. All that is required of the dictating operator is that he speak into the microphone 100 as by saying "I want to dictate" or "all right" or any other sound which actuates the voice responsive relay AV and the recording and reproducing device 17 will be immediately advanced at high-speed to the point of last recording. It has been previously shown how actuation of the voice responsive relay AV in turn operates the relay 1VR 20 associated with machine 1 (see Fig. 4F).

We therefore connect a normally open contact 1VRb of the relay 1VR in a circuit 159 which supplies a relay 1SA. The relay 1SA is operative to cause the recording-reproducing device 17 to 25 advance toward the point of last recording at high speed. The circuit 159 extends from the battery negative L— through a normally-open contact 1Dd of the relay 1D (now closed) and through the conductor 159 to a normally-open contact 1PDBf of the relay 1PDB and then via a conductor 160 through the normally-open contact 1VRb of the relay 1VR and thence through a conductor 161 to the coil of the relay 1SA. The other side of the coil of relay 1SA is connected by means of a conductor 162 through a normally-closed contact 1REb of the limit relay 1RE to ground. It will be noted that whenever the machine is in such condition as to be producing material previously recorded, the contacts 40 45 1Dd are closed in a manner previously described, contact 1PDBf is closed as the result of the recording and reproducing device being toward the forepart of the recording medium from the point of last recording, and energization of the relay 1VR so as to close the contacts 1VRb between conductors 160 and 161 will energize the relay 1SA. We include a normally-open contact 1SAc in a circuit 163 (see Fig. 4G) extending from the battery negative L— through said contact and by 50 55 means of conductor 163 through a normally closed contact 1REC of the limit relay 1RE to the "forward" terminal of the high speed motor 1HSM, so that (providing of course the limit relay 1RE is not energized) the energization of the relay 1SA will complete a circuit from the battery negative L— through conductor 163 to the "forward" terminal of the motor 1HSM so as to cause the motor 1HSM to rotate the high speed advancing screw 26 in such direction as to 60 65 move the recording and reproducing device 17 rapidly toward the point on the recording medium at which the recording was left off.

In order that the rotation of the high speed advancing screw resulting from the energization 70 of the motor 1HSM may cause the recording and reproducing device to advance in the desired manner, we include a normally open contact 1SAd of the relay 1SA in a circuit between the battery negative L— and the previously 75 scribed conductor 153 so that energization of

the relay 1SA to close the associated contact 1SAd will complete the aforementioned circuit and energize the shifting solenoid 1SS. As previously described, the energization of the shifting solenoid 1SS causes the feed nut 28 associated with the recording and reproducing device 17 to engage the high speed advancing screw 26 so as to transform the rotation of said advancing screw to a high speed translatory movement of the recording and reproducing device 17 toward 10 the point of last recording.

This forward movement will continue until the point of last recording is reached, at which time the relay 1PDB will be de-energized and open contacts 1PDBf to interrupt the circuit supplying relay 1SA, so that the high speed motion toward the point of last recording is automatically arrested.

During the time required for the recording and reproducing device to move forward to the point of last recording, relay 1SA is held energized through self holding contacts 1SAe operated by this relay and which are connected in a shunt circuit about contacts 1VRb of the voice relay 1VR. This self holding circuit established 20 by the closing of the contacts 1SAd maintains the relay 1SA energized until the circuit is opened by the opening of the contact 1PDBf of the point defining relay 1PDB when the recording and reproducing device has reached the point of last 30 recording.

Thus, it is seen that if the dictator A has caused the machine to play back material previously recorded and desires to advance the recording and reproducing device to the point of last recording so that he may resume dictation, all that is required is to direct a sound into the microphone 100 sufficiently loud to actuate the voice responsive relay AV. As will be understood by those skilled in this art, the rapid advance may 40 be accomplished at a sufficiently high speed as to require substantially little pause between the announcement by the dictator that he wants to resume dictation and the production of the "OK" tone signalling that the machine is ready there- 45 for.

Dictator denotes errors or instructions for transcriber

To illustrate the further operation of the dictating system of our invention, let us assume that the dictating operator wishes to indicate to the transcribing operator the location of an "error" or other instruction. We prefer that the dictator A accomplish the transmission of instructions to the transcribing operator through use of the dial or impulse device 105. For this purpose we have selected the dial numeral "two" to energize the time delay relay ATD2 (see Fig. 4D) in a manner identical to that described in connection with the time delay relay ATD3. The timing operation of this self-timed relay, however, is arranged in such length as to record a characteristic sound upon the recording medium of a sufficient duration to guarantee its being 60 65 heard and understood by the transcribing operator.

In order that the energization of the relay ATD2 may perform the required recording operation we provide an information tone generator 70 (see legend Fig. 4I) which is supplied by power from conductors 111 and 112 and which is adapted to generate a tone which may have a peculiar sound so as to be recognized readily as that corresponding to an "error" or instruction 75

indication. We ground one side of the information tone generator and extend the other side by means of wire ET to a normally open contact ATD2c of the time delay relay ATD2. The 5 circuit then continues from this contact to connection with wire 130 so that whenever the time delay contact ATD2c is closed, the wire ET will be connected to the conductor 130 so as to impress the error tone upon the input of the recording 10 amplifier ARA. If this operation is performed at the time the machine is conditioned for recording dictation it is apparent that the amplified tone will be transmitted from the amplifier to the recording device 17 of machine 15 1 in a fashion exactly the same as that described in connection with the recording of speech.

If, however, the operator desires to indicate the instruction to the transcriber at a time when the dictating machine is not in a condition to record, 20 he may do so. In order that this may be accomplished, we have provided another normally open contact ATD2e in a circuit extending between wires EA and JA so that whenever the time delay relay ATD2 is actuated in response to the 25 dictator's attempt to record an instruction on the recording medium, the recording wire EA and the reproducing wire JA will be connected together. In order that the amplified sound of the "error" tone will not be re-amplified by the 30 reproducing or playback amplifier APA and cause a blast in the dictator's ear through reproduction by the sound reproducing device 101, we have included an aforementioned normally closed contact ATD2d of the relay ATD2 in the wire JA 35 between the point of application of the "error" tone thereto and the input of the amplifier APA, so that at the time the tone is applied to the wire JA, the wire JA is disconnected from the amplifier, thereby preventing the reproduction of the 40 "error" tone in dictator A's ear. It will be observed that, as previously described, the wires EA and JA, after passing the dictator's selector AS, become wires E1 and J1 respectively. Inasmuch as wires E1 and J1 are connected to the recording 45 and reproducing device 17 in terms of whether or not the machine is in condition for recording or reproducing, it is obvious that by applying the instruction tone to both wires simultaneously, the circuit will be completed to the recording and 50 reproducing device 17 through one or the other, depending upon the operative condition of the machine at the time the operation is performed.

It is seen then that whenever the dictator A desires to indicate to the transcribing operator 55 the location of certain instructions or other information he may do so regardless of whether the machine is in the recording or reproducing condition by merely dialing "two" on the dialing or impulsing device provided for his use.

60 It will be noted that we have included normally closed contacts of the relays 1ES, 1RS, 1RE and 1EE in strategic points in the circuits, such as in the circuit 138 for the record motor 1RM, the circuit 152 for the travel relay 1SB, and the circuit 162 for the travel relay 1SA in such a manner that should the recording and reproducing device 17 be caused to traverse the entire limit of its travel in either direction, the limit 65 relays will operate in connection with the equipment in such a manner as to prevent any further travel of the recording and reproducing device 17.

Dictator automatically transferred from one machine to next in sequence

75 As was hereinbefore stated, whenever a par-

ticular piece of dictation to be recorded by dictator A is so long as to exceed the capacity of the recording medium on machine 1, a new then idle machine will be selected for the dictator A and the control devices for dictator A will be transferred to the new machine. This is accomplished through the operation of the machine selector for machine then being dictated to which, as the recording-reproducing device on that machine nears the finish end of its record, brings into action 5 circuits which start the machine selector (1S for machine 1) to "hunt" for a new idle machine, and when one is found it passes the control circuits previously used to control the first machine on to the newly selected machine. 15

We have illustrated the machine-multiple group of conductors and cables as extending to all of the machines 1-10 inclusive, it being understood by those skilled in the art that each line in this representing a conductor or cable on the 20 drawings, particularly in the machine-multiple group, actually may represent not only a single conductor but may represent a cable including a plurality of associated conductors which may be taken out of the cable at various points at 25 which these conductors must be distributed for proper connection to the various selectors AS, BS, XS and selectors RSA' to RSX'' inclusive and to the several machine-selectors for machine units 1-10 inclusive. 30

At this point attention should be called to the fact that in the foregoing description with regard to the wiring of machine 1, the several conductors have been assumed to have been "fanned" 35 out of the cables as individual conductors and are shown in their full line connections to the various points on the various levels of dictator's selector AS and on the various levels of machine selector 1S associated with machine 1. It will be understood from an inspection of the writing 40 diagram shown in Figs. 4A to 4J inclusive, one of such cables or lines, which may be referred to as "group e conductors," extends from all of the several contact points on level d of dictator A's selector AS and into connection with all of the 45 contact points on the level f of the machine-selector 1S, as shown particularly in Fig. 4G. At the dictator's selector AS it will be observed that this cable or "group of conductors" actually includes a different conductor for each of the ten 50 machines associated with our system and that each of the individual conductors is connected respectively to the first, second, third, fourth, etc., points on the level d of selector AS. Similarly by referring to Fig. 4G it will be noted 55 that as the cable enters and is connected to the level f of the machine selector 1S, these individual conductors which have extended from the first, second, third, fourth, etc., points of selector AS are correspondingly connected to the first, sec- 60 ond, third, fourth, etc., points on the level f of machine selector 1S. Such individual conductors are also connected in parallel with the respective contact points on each of the machine 65 selectors 2S, 3S, 4S, etc., for all of the machines 1-10 inclusive. It should be understood that although we have only shown a single line E extending from the cable into the machine 2, this line actually represents ten separate conductors 70 which will be connected respectively to the ten points on the level f of the selector 2S for machine 2. Similar multiple connections are illustrated for the remainder of the machines merely by indicating a single line bearing the legend E 75 extending to the selectors of these machines and

it will be understood that each of these lines actually represents ten individual separate conductors.

In connection with that part of the wiring diagram which has been described in full up to this point we have referred to the conductor E1, this conductor representing one of the E group of conductors and which will extend to and be connected to the first contact point on the levels f of all of the selectors 1S, and to corresponding points respectively on the levels f of selectors 2S, 3S, etc. Again referring to Fig. 4G it will be noted that the remaining conductors in the group are shown as being connected respectively to the second, third, fourth, fifth, etc., points on the machine selector 1S and these individual conductors are identified with the reference characters E2, E3, E4, E5, E6, E7, E8, E9 and E10 respectively. Since the conductor E1 is the conductor over which the actual speech currents are transmitted to machine 1 for recording this speech on machine 1, this conductor is peculiarly associated with machine 1 and this peculiar association consists in the fact that the conductor E1 not only contacts the first point on the selector 1S but actually extends beyond this point and into machine 1 where it is connected to the various relays and circuits over which the speech currents pass and are distributed within the machine 1. Similarly conductor E2 being the speech recording conductor peculiarly associated with machine 2 extends not only into connection with the appropriate contact point on the level f of machine selector 2S but continues beyond this point and into machine 2, where it connects with the various relays, relay contacts and devices within that machine by which speech is recorded upon that machine.

The wiper f on machine selector 1S is adapted to be selectively brought into contact with any of the points on the level f of that selector and this wiper is permanently connected to the conductor 1E so that if the wiper f is moved into contact with any one of the group of conductors such as the conductor E3, the conductor E1 will be directly connected to the conductor E3 through the wiper f on machine selector 1S and will thus extend the circuit connections, which have theretofore been established over the conductor E1, now on through the conductor E3. As previously mentioned the conductor E3 extends into direct connection with machine selector 3S for machine 3 and into connection with the various relays and circuits associated peculiarly with machine 3. It is apparent therefore that all that is required in order to transfer operations of the dictator A from machine 1 to another machine is to cause the machine selector 1S to rotate to select a vacant machine at such time as the recording and reproducing device 17 reaches the end of the record. The operation of machine selector 1S will then cause the control functions initiated by the dictator A to be performed upon whatever subsequent machine is automatically chosen by the machine selector 1S.

In addition to the previously described interconnection of the various selector switches, we employ a "PW" group of wires (PW1, PW2, etc., through PW10, PWAB and PWEX) which are used for "busying" each of the dictators' selectors, machine selectors, and transcribers' sequence remembering selectors. Reference to Fig. 4E will show that we have connected the wire PW1 to the first point of level g of the dictator's selector AS and arranged the controls for that selector in

such a fashion that the battery negative L- is connected thereto as soon as machine 1 is selected by the selector AS. Wires PW2 through PW10 are connected to succeeding points on level g of the selector AS so that whenever dictator A is connected thereby to any of the machines 1-10 the corresponding PW wire will be connected to the battery negative L-. The PW wires are extended to and connected to a level on each of the machine selectors and dictators' selectors and to various other selectors to be described herein-after and operate (when connected to the battery negative L-) to prevent these selectors from connecting to a "busy" machine.

In order to describe the transfer operation in detail, let us assume that the dictating operator A is dictating upon machine 1 and continues to dictate while the recording and reproducing device 17 of machine 1 approaches and reaches the end of the recording medium. It will be remembered from the description of the mechanical equipment that as the recording and reproducing device 17 advances toward the end of the record, the first limit switch that is operated is the limit switch 1EE which is operated at the time the "error" reproducing device 29 reaches the end of the recording medium. It will be noted that we have connected a normally open contact 1EEa (see Fig. 4F) in a circuit which connects the wire PW1 to the first point on level a of the machine selector 1S. Inasmuch as at this time, as has been pointed out in the preliminary assumption, the machine selector 1S is resting on its "home" or first position, power will flow from the wire PW1 through the contact 1EEa and thence to the wiper a when the recording and reproducing device 17 has been advanced sufficiently far along the record for the "error" reproducing device 29 to reach the end of the recording medium.

In order that power transmitted over the wire PW1 may then be used to operate the machine selector 1S to choose a machine to which the operations will be transferred when the end of the recording medium is reached by the recording and reproducing device 17, we have connected the wiper a of the machine selector 1S to the motor magnet 1S-M for the machine selector 1S by means of a circuit 164 which includes normally closed contacts of the "off-normal" switch 1S and the interruptor springs 1S-I of the machine selector 1S.

As soon as the relay contact 1EEa closes, power will be conducted from the wire PW1 through the wiper a and normally closed "off-normal" contacts and the interruptor springs 1S-I to the motor magnet 1S-M of the machine selector 1S so as to cause the machine selector 1S to move to its second position.

We have also extended a conductor 165 from the off or "home" terminal normally contacted by wiper a to a release magnet 1S-R of the selector 1S so that as soon as the contacts 1EEa of the limit relay 1EE are closed, the release magnet 1S-R will be energized so as to permit the operation of the motor magnet 1S-M to move the wiper a to its second position.

Let us assume that machine 2 is in operation. As has been previously pointed out, the fact that another dictator is dictating on machine 2 will cause the wire PW2 thereof to be energized. As the wiper a moves to the second point and contacts wire PW2, power will again be supplied to the wiper a to cause the selector 1S to advance another notch. It will also be noted that we

have extended circuit 164 to a holding relay 1S-H connecting said relay in parallel with the motor magnet 1S-M of machine selector 1S and have provided a normally open contact 1S-Ha thereof in a circuit in parallel with the normally closed "off-normal" contacts so that after relay 1S-H is energized along with the motor magnet 1S-M and power is supplied to the wiper a from the wire PW2, a current may flow through the contacts 1S-Ha and thence through the interruptor springs 1S-I of the motor magnet 1S-M to cause the motor magnet to move the wiper to the next position.

It will also be noted that as soon as the wiper a moves off of the normal or "home" position, normally open "off-normal" contacts provided in a circuit 164a extending from wire PW1 to the release magnet 1S-R close so as to maintain the release magnet 1S-R in an energized condition and prevent the return of the wipers to the "home" position.

Let us assume that the private wire PW3 associated with machine 3 is not energized and that that machine is available for dictation. Power which has been supplied previously by wires PW1 and PW2 to the motor magnet 1S-M and the holding relay 1S-H is therefore interrupted when the wiper is moved into contact with the de-energized wire PW3 and the motor magnet 1S-M will no longer operate to notch the selector 1S to other points. The holding relay 1S-H is de-energized at the same time so that contacts 1S-Ha will open and permanently interrupt the circuit between wiper a and the paralleled relay 1S-H and motor magnet 1S-M. It is desired, however, at this time to energize the wire PW3 so as to indicate to other machines, transcribers and dictators that the machine 3 is "busy" and to interlock that machine against operation from any other source. We accordingly provide a normally closed contact 1S-Hb of the holding relay 1S-H in a circuit which extends from conductor 165 previously mentioned to the wiper a, so that de-energization of the holding relay 1S-H will connect conductor 165 to wiper a and supply power to the wire PW3 from the wire PW1 through the normally open "off-normal" contacts (now closed) in circuit 165 through the normally closed contacts 1S-Hb in the circuit between conductor 165 and the wiper a and thence to wiper a. The wire PW3 in presenting an energized condition to all other machine selectors, and dictators' selectors, prevents their connecting to machine 3 and interfering with the operation thereof by the dictator A.

In order that the proper sequential operation of machine 1 and machine 3 may be carried out as soon as the "error" or instruction reproducing device 29 reaches the end of the recording medium as indicated by the operation of the limit switch 1EE, the recording and reproducing devices 17 of machine 1 and machine 3 are arranged to both advance simultaneously so that when the recording and reproducing device 17 of machine 1 reaches the end of its recording medium, the recording and reproducing device 17 of machine 3 will just reach the beginning of its recording medium.

It has been previously shown in connection with the operation of machine 1 how the wire F1 was effective in controlling the operation of the relay 1VR to cause the record rotating motor 1RM to rotate to advance the recording and reproducing device 17 along the recording medium. Inasmuch as the machine selector 1S is now in

a position where its wiper contacts the third point corresponding to machine 3, reference to level b of the selector 1S (see Fig. 4F) will indicate that the wire F1 is now connected to the wire F3, and bearing in mind that machine 3 is wired in accordance with the wiring shown in detail for machine 1, it will be apparent that the same source of power which energizes the relay 1VR will also energize the corresponding relay VR (associated with machine 3), thereby causing the record rotating motor RM for machine 3 to revolve and advance the recording and reproducing device 17 thereof along the recording medium.

In the same way the wire E1 is connected to the wire E3 so that the speech sounds supplied by the dictator's recording amplifier ARA are supplied to the recording and reproducing device 17 of machine 3, as soon as the recording device of machine 1 reaches the end of its record, and the dictation will then be recorded on machine 3. Note at this point that the recording device of machine 3 has advanced along the recording medium 17 thereof during the time which was taken for the recording device 17 on machine 1 to completely reach the end of its record and hence limit switch RS on machine 3 will be open and contacts RSy on machine 3 will now be closed. The speech sounds transmitted over the wires E1 and E3 will be recorded on the recording medium of machine 3.

It is apparent that the recording operation may continue in an uninterrupted manner and that the recording will begin on machine 3 as soon as the recording and reproducing device 17 of machine 3 has advanced to the beginning of the recording medium on machine 3. It is also apparent that the recording on the recording medium of machine 1 will automatically cease as soon as the recording and reproducing device 17 thereof has advanced to the point where the limit switch 1RE is operated, or when the recording and reproducing device 17 has reached the end of the record. When this point is reached, energization of the limit relay 1RE will open the normally closed contact 1REa included in the circuit supplying the record rotating motor 1RM so as to stop the rotation of the recording medium and halt the recording process.

Assuming that the dictating operator has recorded a considerable amount on the third machine, it will be apparent that he may playback any portion of the material recorded on machine 3 in the same fashion as was described in detail in connection with the operation of machine 1.

Dictator may playback from record on preceding machine

Suppose, for example, that now the dictator A desires to playback a portion of the material recorded on machine 1. In order that this may be readily accomplished we have provided a system of transfer circuits which are established from machine to machine through the "inter-machine group" (see Fig. 1) as the machine selector establishes the paralleled control connections between the various machines. To cause this playback operation, the dictating operator may, as previously described, dial on the dialing device 105 a number corresponding roughly to the length of time required to record the amount of material lying between the point he wishes to hear reproduced and the point at which he is recording.

Referring to the drawing of the wiring of machine 1 (Figs. 4F, 4G, and 4H) and imagining (inasmuch as the wiring on all machines is iden-

tical) that we are referring to the wiring of machine 3, it will be seen that the operations for causing the recording and reproducing device 17 of machine 3 to move back toward the forepart of the record is accomplished by energizing wire H1 (see Fig. 4E), and hence through the interconnections of wires H1 and H3 by means of the machine selector 1S, the wire H3 of machine 3.

By referring to the drawings it will be observed that energization of the wire H3 will energize the relay SB associated with machine 3 to cause the recording and reproducing device 17 of machine 3 to move in a direction toward the forepart of the record at a relatively high speed. It will be remembered that we have included in the circuit which supplies and controls the relays SB, a pair of normally closed contacts of the limit relays ES and normally closed contacts of the relay RE.

With respect to the operation of machine 1, it will be seen that as the recording advanced and the transfer between machine 1 and machine 3 occurred, the recording and reproducing device 17 of machine 1 advanced to the point where said device was at the end of the recording medium at which time the limit relay RE was energized and by so doing interrupted the circuit between the control wire H1 and the relay 1SB so that during the time the dictator A is causing the recording and reproducing device 17 on machine 3 to return toward the forepart of the record, such control is not effective in moving the recording and reproducing device 17 of machine 1 since the opening of contact 1REd of relay RE in circuit 151 prevents actuation of the relay 1SB to cause this operation. It will be noted, however, that the wire H3 of machine 3 is connected to a wire TS1 associated with machine 3 by means of a normally open contact RSa of the limit relay RS associated with machine 3 so that whenever the recording and reproducing device 17 of machine 3 is retracted to the point where the said device is at the beginning of the recording medium, the relay RS will be energized and close the contacts RSa so as to connect the wire H3 to the wire TS1. The wire TS1 is connected to the third point of level 1 of the machine selector 3S (see Fig. 4H). It therefore follows that energization of the wire H3 in an attempt to cause the recording and reproducing device 17 to move back toward the forepart of the record will at this time energize the wire TS1.

The wire TS1 connects directly to a wire 3T1 occupying the "home" position on the selector 3S.

By referring to the machine multiple group it will be observed that the wire 3T1 also appears on the third position on the level 1 of the machine selector 1S and that inasmuch as the machine selector 1S is in the third position, the wiper 1 thereof is connected to wire 3T1. Referring to Fig. 4H of the drawing, and considering this figure with respect to the operation of machine 1, it will be observed that the wiper 1 is attached to a wire 1TE1 and that this wire is connected to the conductor 151 (see Fig. 4F) which in turn establishes the connection to the relay 1SB.

In reviewing the aforementioned described connections and the manner in which they operate, it will be seen that the potential impressed upon the conductor H1 by the dictating operator A in an attempt to move the recording and reproducing device 17 back over the forepart of the record is applied also to the wire H3, and that the wire H3 has been connected to the wire TS1 by the closing of the limit relay RS of machine 3 at the time the recording and reproducing devices

17 of machine 3 reached the beginning of the recording medium. At this time power flows from the wire H3, through the wire TS1 associated with machine 3 to the wire 3T1 and from the wire 3T1 on machine selector 1S through the 5 wiper 1 and over the wire 1TE1 to the conductor 151 so as to energize the relay 1SB. As has been previously shown, energization of the relay 1SB causes the recording and reproducing devices 17 of machine 1 to retract toward the forepart of 10 the recording medium.

It is apparent that whenever the dictating operator wishes to playback material which may be sufficiently far toward the forepart of his dictation as to occur on a machine different from 15 the one on which he is then operating, the operation so far as the dictating operator is concerned is unchanged. The dictating operator merely dials a number corresponding to the point along 20 the recorded dictation which he wishes to hear reproduced and the recording and reproducing devices 17 of the machine then in operation travel back to the beginning of their recording medium, the operation then being transferred to the next 25 previous machine in the sequence, the recording and reproducing devices 17 of that machine then travelling back toward the forepart of that record. As is apparent from the foregoing description, this operation may be continued indefinitely 30 through as many machines as have been connected together in a sequence by operation of the machine selectors.

Let us now consider the first case of operation as discussed previously in connection with the operations on machine 1. That is to say, let us 35 assume that the dictating operator, having arrived at the point on machine 1 at which he wishes to playback recorded material, desires to continue the reproduction of the recorded material until such time as the recording and reproducing devices 17 arrive at the point on machine 3 at which he last recorded material. It has been pointed out in connection with the machine 1 how the reproducing operation is performed automatically as soon as the recording 45 and reproducing devices 17 are moved back to the desired point in the previously recorded material.

It has also been pointed out in connection with machine 1 that the transfer to machine 3 was 50 effective in paralleling the various controlling connections so that whenever machine 1 operates to cause the reproduction of the previously recorded material the same operation would occur simultaneously on machine 3 unless means were 55 provided for causing these devices to properly operate in sequence. We have provided such sequencing equipment which operates in connection with the dictator's relay 1D included in circuit with the wire G1. It has been pointed 60 out hereinbefore how the relay 1D is energized as soon as machine 1 is picked up by the dictator A, the energization of the relay 1D being intended to properly sequence the operation of machine 1 for control by a dictating operator. 65

Referring to circuit 134a through which the relay 1DX is energized as a result of the closing of contacts 1Db of the dictator's relay 1D, we have included therein a normally closed contact 1DSxa of the dictator's locking relay 1DSX. We 70 have however provided a circuit which parallels this contact and which may also energize the relay 1DX. This circuit may include a conductor 165a which extends between the battery negative L— and the aforementioned contact 1Db and 75

includes a normally open contact IDS_a of a dictator's sequencing relay IDS . The relay IDS is connected directly to a wire ITS_2 which connects to the first point on level m of the machine selector IS to which the inter-transfer wire IT_2 is connected. We have also provided a wire ITE_2 which is connected to the battery negative L — through a normally open contact IEE_b of the limit relay IEE and extends to the wiper m of the dictator's selector IS . It will be observed that whenever the recording and reproducing device 17 of machine 1 has travelled to the right sufficiently far for the "error" reproducer to reach the end of the recording medium, limit relay IEE will be energized and will connect the conductor ITE_2 to the battery negative L — and will supply power thereover through the wiper m of the selector IS to the conductor $3T_2$ with which the wiper m is in contact. The conductor $3T_2$ extends into the selector $3S$ for machine 3 where the wire changes its reference character and becomes wire TS_2 of machine 3 .

The wire TS_2 on machine 3 is extended in the same manner as is the wire ITS_2 on machine 1 so that energization of the wire TS_2 on machine 3 will cause immediate energization of the dictator's sequencing relay DS in machine 3 .

Referring to the wiring for machine 1 with respect to the relays IDX and IDS and bearing in mind that the wiring for the equipment associated with machine 3 is identical, it will be seen that energization of the relay DS in machine 3 will complete circuit $165a$ (see Fig. 4G) which supplies the relay DX associated with machine 3 through normally open contacts DS_a of the relay DS , so that power flows from the battery negative L — through circuit $165a$ and through the normally open contact Db of the relay D associated with machine 3 to the coil of the relay DX of this machine. It follows then that whenever the recording and reproducing devices 17 of machine 1 have advanced to the right sufficiently far for the instruction reproducing device 29 to reach the end of the recording medium and close contacts IEE_b of the limit relay IEE , the relay DX of machine 3 will be energized so as to establish the proper condition thereon for recording under the control of a dictating operator.

By providing the normally open contacts DX_a (see Fig. 4F) of the relays DX in the circuits (such as circuit 135) supplying the record rotating motors RM , the individual record motors RM of the machines will be caused to operate in a true sequence and not simultaneously even though the machine control wires have been all connected together in parallel through the interconnecting operations of the various machine selectors. In the condition under consideration at this time, if the dictating operator has moved the recording and reproducing device 17 back to such a point that he is reproducing material from machine 1 , the equipment is so arranged that although the controls of machine 1 and machine 3 are connected in parallel, the only reproducing that will be done will be done by the recording and reproducing device 17 of machine 1 and this condition will persist until the recording and reproducing device 17 of machine 1 has travelled along its recording medium and arrived at the end thereof, at which time control will then be transferred through the operation of the relays DS and DX in machine 3 to start the reproduction of the dictated material from the recording medium included in machine 3 . In establishing

this sequential type of operation, a means must be provided for energizing the relay DX of whichever machine is first of the sequence. We have shown how the relays DX may be energized by the limit relay of the machine next preceding in sequence.

We have provided locking relays DSX also for the sequencing relays DS and have interlocked these relays to control the energization of the relay DX when there is no machine next preceding in sequence to cause this energization.

Considering the case of machine 1 we have provided a circuit $165b$ (Fig. 4H) which extends from the battery negative L — to the coil of the locking relay DSX and include therein a normally closed contact IEa of an erasing relay IE , and a normally open contact IDS_b of the dictator's sequencing relay IDS . Assuming that the erasing relay IE is de-energized so that the contact IEa thereof is closed and remembering that energization of the relay IDS to close its contacts IDS_b occurs only when the machine is not first in a sequence, it will be seen that the relay DSX will remain de-energized and that as soon as the dictating operator is connected to machine 1 circuit $134a$ will be completed through the normally closed contacts IDS_a to energize the relay IDX . We provide a self holding circuit $165c$ for the relay DSX which includes a normally open contact IDS_b of the relay DSX and parallels contacts IDS_b in circuit $165b$ so that if the relay DSX is energized, circuit $165c$ will be completed to lock the relay DSX in an energized position independent of subsequent operations of the relay IDS .

It will of course be observed that the locking relays DSX in all of the other machines in the sequence will be initially energized and locked in through their self holding circuits $165c$ and will therefore of course interrupt circuits $134a$ to prevent energization therethrough of the relays DX associated therewith. It therefore follows that on machine 1 the relay IDX will be energized as soon as the dictating operator gains control of that machine and will remain energized as long as the machine is being controlled by the dictating operator, and that on subsequent machines in the sequence, the DX relays will be sequenced by operation of the sequencing relays DS in accordance with the position of the recording and reproducing device 17 of machine next preceding them in sequence.

As was referred to in the description of the mechanical arrangement of the machine unit, the "error" or information reproducing device 51 is arranged somewhat in advance of the recording and reproducing device 17 so as to pick up and transmit to the transcriber the fact that an "error" is to occur at some point in advance of the arrival of the recording and reproducing device 17 at the point at which said "error" is actually made on the record. It will be apparent, therefore, that as the dictator is transferred from one machine to the next machine in sequence and makes an "error" near the forepart of the record on the subsequent machine such "error" would not be picked up and transmitted to the transcriber until after her control devices had been transferred to this subsequent machine and at such time the "error" or information reproducing device would be considerably beyond the point at which the "error" occurred and hence she would not receive this information.

However, in view of the fact that as hereinbefore described, the relays DS and DSX are em-

ployed to distinguish between whether or not the particular machine is the first machine in the sequence of a predetermined dictation or is a subsequent machine in such sequence, we may 5 readily employ contacts on the relay DSX to distinguish between whether or not the machine upon which the transcriber is then transcribing is the first in the sequence or is some subsequent machine in the sequence.

10 Again it will be noted that should the recording-reproducing device 17 on machines other than the first machine in the sequence start their recording operations, as soon as the record revolving motor RM of the subsequent machine was 15 placed into operation there would be a dual or double recording, once upon the end portion of the preceding machine and again upon the first portion or "start" portion of the succeeding machine. Unless some means is provided to avoid 20 this dual recording it would follow that as the transcriber is transferring from one machine to another she will be listening to the same dictation recorded in two places, which, however, may not be entirely synchronized with each 25 other. To avoid this operation we have employed the contacts on the relay DSX to permit the starting of the recording operation at the extreme "start" end of the record 14 only upon the first machine in the sequence, and employ the 30 contacts on the relay DSX for the remaining machines to interrupt this circuit until the recording and reproducing devices on those machines have been moved across their respective records to a distance at least equal to the spacing between the recording-reproducing device 17 and 35 error and information reproducing device 29 associated with those machines. This is illustrated particularly in Fig. 4G wherein it is noted that the circuit including the speech recording line E1 extends through the normally closed contacts 1PDBa of the point defining relay 1PDB and thence through conductor 132 whereupon the circuit branches, one portion of the same extending through the normally closed contacts 1DSXy on relay 1DSX and the other portion extending in parallel relation through the contacts 1RSy on the starting limit switch relay 1RS associated with machine 1, and only after the circuit passes through both of these contacts does it reach the 40 recording and reproducing device 17.

Assuming that machine 1 is the first machine in the sequence, relay 1DSX will not have been energized as was hereinbefore pointed out and for that reason the circuit will be established irrespective of the position of the recording-reproducing device 17 at the extreme "start" end of 45 the record. However, upon machine 3, when the transfer thereto is made, the relay DSX for this machine will have been energized and the contacts thereof associated with that machine will now be open; hence the circuit to the recording-reproducing device can only be established through the contacts of the relay RS on machine 3, which it will be remembered will not be closed 50 until the recording-reproducing device 17 has traversed that portion of the beginning of the record 14 on machine 3 equal to the advance spacing between the recording-reproducing device 17 and the information or error reproducing device 29 on that machine. Only then will it be possible to establish a complete circuit to the recording-reproducing device 17 on machine 3 and the first recorded material on machine 3 will take place after this initial traversing of the 55 forepart of the record on machine 3.

We have shown, therefore, how the dictating operator may by dialing the appropriate number with his impulsing device 105 cause the recording and reproducing device 17 on machine 3 upon which he was last dictating to move back 5 toward the forepart of the record to the starting end thereof and then automatically transfer control to machine 1 and cause the recording and reproducing device 17 thereon to move back toward the forepart of the recording medium of machine 1. We have shown how the sequencing relays operate to allow the equipment to automatically reproduce all of the desired material on machine 1 and after the completion of the reproduction of this material transfer the control back to machine 3 and continue the reproduction of the dictated material from the recording medium of machine 3 until the point of last recording is reached. It has been previously shown how reaching the point of last recording on machine 3 will apprise the operator that the machine is ready for recording additional dictation through the reproduction of the O. K. tone.

Let us now consider the operation in the case where the dictating operator after having listened to a portion of the previously recorded material on machine 1, wishes to immediately resume dictation at the point at which he last dictated material on machine 3. The operation, as has been previously described in connection with machine 1, is to merely direct into the microphone a sound of sufficient intensity to actuate the voice operated relay AV. It will be observed, by studying the wiring diagram of machine 1 with the viewpoint that it may be the wiring of machine 3 and realizing that energization of wire F1 as the result of speech is effective in energizing the relay VR associated with machine 3, that energization of this relay VR occurs simultaneously with energization of the relay 40 FVR of machine 1 inasmuch as the wires F1 and F3 which control these relays are inter-connected at level b of the machine selector 1S.

Referring to the circuit controlling the relay 1SA which includes conductors 159, 160, 161 and 45 162, it will be seen that energization of the relay VR associated with machine 3 will close the contacts between conductors corresponding to conductors 160 and 161 so as to immediately energize the relay SA associated with machine 3. 50 At the same time, however, the energization of the relay 1SA on machine 1 occurs so as to cause both of the recording and reproducing devices 17 associated with these two machines to simultaneously advance at high speed toward the end 55 of their respective recording media. The recording and reproducing device 17 associated with machine 1 will of course advance to the end of the recording medium at which point the advance will be halted by the actuation of the 60 limit switch at that point, while the recording and reproducing device 17 associated with machine 3 will advance to the point of last recording at which time the operation of the point defining relay PDB associated with machine 3 will 65 stop the advance of the recording and reproducing device 17 and reproduce the characteristic O. K. tone to the dictating operator.

Dictator interrupts normal dictation to dictate "rush" material

Another important operation which is provided by the dictation system of our invention is the interruption of one piece of dictation in order to dictate "rush" material. Let us assume that a 75

dictator is dictating upon the machine in the usual course of business, dictating a brief or specification or some more or less lengthy piece of work and an occasion arises which demands 5 that he immediately dictate a letter or telegram for immediate transmittal to the person for whom it is intended. In accordance with the object of our invention we have provided a means whereby a dictator may thereupon perform a 10 single control operation and transfer his controls to an emergency machine and thereon dictate the "rush" material. As he is dictating this material, the control of the machine on which he was previously dictating, for example, machines 15 1 and 3, is held so as to prevent any one else from interrupting his work on those machines. The system is further arranged so that as soon as the dictating operator has completed his work on the emergency machine he may immediately 20 resume operation on the normal machines upon which he was previously operating. In order to accomplish this we have provided an emergency line relay which, for dictator A, we have designated as AEL and which is responsive to the 25 operation of dialing "zero" on the dialing or impulsive device 105.

Recalling the manner in which the dictator's control selector ACS (see Fig. 4D) operated, it will be observed that by dialing "zero" on the 30 dialing device 105, the wiper of the control selector ACS will be caused to complete a circuit and energize the tenth or "zero" position on the dictator's control selector ACS. We prefer to connect the last or "zero" point of the control selector ACS to the coil of the emergency line relay AEL by means of a conductor 166 which includes a normally closed contact AEL0a of an emergency lockout relay AELO. Assuming that the emergency lockout relay is de-energized, the 35 energization of the "zero" point on the control selector ACS will immediately energize the dictator's emergency line relay AEL. We provide a self holding circuit for the relay AEL which includes a conductor 167 extending from the battery negative L- to the conductor 166 and including therein a normally closed contact AETa of an emergency trip relay AET and a normally open contact of the emergency line relay AEL. As long as the trip relay is de-energized so as 40 to maintain the contacts AETa in the closed position, the emergency line relay AEL will be maintained energized through its self holding circuit.

The previous discussion with regard to the 45 control of the dictating machine 1 by means of the dictator A has indicated that the various control wires E, F, H, J and K are connected to their wipers of the dictator's selector AS through normally closed contacts of the relay AEL. It will therefore be observed that energization of the relay AEL will disconnect the control wires from the machine upon which they are being used at the time the relay was energized. It will be noted also that we have connected each of these various control wires by means of normally open contacts of the relay AEL to a group of control wires EEAB, FEAB, etc., in the machine multiple group.

Tracing these various wires through the machine multiple group through Figs. 4D, 4E and 50 4J will show that they terminate in the machine EAB which is the emergency machine available for dictator A and B. Inasmuch as the machine EAB is wired in the same manner as the previously described machine 1 with the exception that no machine selector is provided and no

transfer circuits going from machine to machine are provided, it is readily apparent that the dictating operator may dictate at will on the emergency machine EAB.

It should be noted at this point, however, that 5 when the dictator transferred his controls over to the emergency machine for the purpose of dictating the emergency message or piece of dictation, he did not release the "sequence" of the machines upon which he had previously been 10 dictating and he may therefore immediately return to that same "sequence" of machines and resume the interrupted dictation at the point on that machine in the "sequence" at which he left off dictating. This holding of the "sequence" is 15 accomplished by reason of the fact that the PW wire which has been selected for the first machine in the "sequence" is, as hereinbefore described, fed through the circuit 118 and it will be noted that circuit 118 does not pass through 20 the contacts of the emergency line relay AEL.

Hence though this relay operates to switch the controls to the emergency machine as regards the speech transmission wires and the machine operation control wires, it does not disturb the 25 completed circuit through the PW wire for the first machine in the sequence. Hence the selector for the machine which is first in that particular "sequence" will be maintained in the position to which it has been moved upon the initial selection of that machine and the only way in which this selector can be released is by the completion of the transcription of this piece of material and the reconditioning of the machines of the entire "sequence" by the transcriber at the end of such 30 transcription, as will be hereinafter more fully described with reference to the operation of our system by the transcriber.

As soon as the dictating operator has completed his dictation on the emergency machine, 35 the operation of dialing "zero" a second time is effective in disconnecting the temporary connection with the machine and re-establishing the original connection with the machine upon which he was dictating at the time he decided to dictate 40 the "rush" material.

Referring to the "zero" point on the dictator's control selector ACS (see Fig. 4D) it will be noted that we have provided a conductor 168 which extends this point to the emergency trip 50 relay AET. It will be observed that the circuit 168 is completed to the trip relay through the closing of normally open contacts of the relay AEL contained therein and that inasmuch as the dictator is at this time controlling the emergency 55 machine these contacts will be closed. It is therefore apparent that when the dictating operator dials "zero" the second time the emergency trip relay will be energized. Energizing the emergency trip relay AET will thereupon interrupt 60 circuit 167 (the self holding circuit for relay AEL), de-energizing the relay AEL and interrupting circuit 168 so as to de-energize the emergency trip relay AET. De-energization of the relay AEL also disconnects all of the control wires EA, FA, 65 HA, etc. from the emergency machine and re-establishes the normal connection of these wires through the wipers of the dictator's selector AS to the normal machine units.

In order that another dictating operator may 70 not attempt to operate the emergency machine EAB during such time as the dictating operator A is controlling said machine, we provide a private wire PWEAB (see Fig. 4E) for the emergency machine EAB, and arrange to energize 75

the wire from the negative battery L— by means of a normally open contact of the relay AEL. Whenever the relay AEL is energized the private wire PWEAB is connected to the battery negative L—. Reference has been made hereinbefore to the emergency lockout relay AELO, the coil of which is connected in a circuit 169 extending from the aforementioned private wire PWEAB and including a normally closed contact of the emergency relay AEL. Let us assume that the emergency machine EAB is being used by another dictator at the time the dictating operator A wishes to use it. It will be observed that inasmuch as the private wire PWEAB is energized as the result of the emergency machine being used by another dictator and inasmuch as the normally closed contact of the dictator's emergency line relay AEL is closed, circuit 169 will be completed and the emergency lockout relay AELO will be energized. It will be further observed that energization of the relay AELO will interrupt circuit 166 so as to prevent the energization of the emergency line relay AEL upon the operation of the dictator's control selector ACS in response to the dictator dialing "zero." In order that the dictating operator may be apprised of the fact that the emergency machine is "busy" and that he will be unable to use it, we have provided a busy signal generator (see legend, Fig. 4I) which is supplied from the general source of power by wires 111 and 112.

The busy signal generator is a device which preferably generates an interrupted modulated tone which may be readily recognized as indicating that the machine to which the dictator is attempting to connect his control devices is in operation and control of such is impossible. We ground one side of the output of the busy signal generator and extend the other by means of a wire BT to the input of the dictator's playback amplifier APA (see Fig. 4D) by means of a circuit 170 which includes a normally open contact AEBa of a "busy" relay AEB so that whenever the dictating operator attempts to select the emergency machine and that machine is busy circuit 170 will immediately be completed through energization of the relay AEB and place the busy signal on the input of the dictator's amplifier causing the same to be reproduced in the dictator's ear by means of the sound reproducing device 101.

In order to perform the previously described operation we have included the coil of the emergency busy relay AEB in circuit 169a which extends from the "zero" point of the dictator's control selector ACS and includes a normally open contact AELOb of the emergency lockout relay AELO. It is therefore apparent that whenever the emergency machine EAB is busy and the emergency lockout relay AELO is energized as a result thereof, the energization of the "zero" point through operation of the control selector ACS will energize the busy relay AEB. Energization of the busy relay AEB will therefore complete circuit 170 to reproduce the busy tone in the manner previously described.

At this point attention should be called to the fact that the "busy" signal or "busy" tone will also be transmitted to the dictator A should he attempt to start any piece of dictation when all of the machines in the system are then "busy" (that is, all of the machines in the entire system are then being dictated upon or are awaiting transcription).

75 This is accomplished by connecting the last

point on the level g of the dictator's selector directly to a "busy" relay AS—B so that should the dictator A attempt to select a machine to start his dictation and find that none of the machines are available, he will receive a "busy" 5 signal, that is, by connecting the last point on the level g of the dictator's selector directly to the "busy" relay AS—B, the selector AS will step from point to point throughout the entire number of points allotted to the full number of 10 machines and the last point on the relay or the eleventh point, being one more than there are machines, will energize the "busy" relay AS—B. This relay is provided with contacts AS—Ba (see Fig. 4D) arranged in a shunt or parallel 15 circuit 170a paralleling the just previously described circuit 170 controlled by the emergency machine busy relay AEB.

It will be understood, however, that the occasion for such busy signal to a dictator will seldom 20 arise if an appropriate number of machines has been provided to adequately take care of the total demand upon the system.

Dictator completes one piece of dictation and 25 sequence of machines therefor is identified and "remembered" for transcriber

As hereinbefore stated with respect to the general description of our system, it is contemplated herein that any one of the dictators in dictating 30 a piece of dictated material may extend such material over a sequence of several machines, the first machine of the sequence being automatically selected for him from any one of a number of 35 idle machines at the time he starts dictation, while the remaining machines upon which the continuation of the dictation extends will be automatically selected for him from any one of the then idle machines. Hence, since there is 40 no way in which the dictator determines or knows 45 which one of the machines this particular piece of dictation was started on, it is necessary that some device be provided which will identify and remember the particular machine which was first in the sequence upon which this particular piece 45 of dictation was recorded so that the transcriber in transcribing this material may be initially connected to the beginning of the dictation.

Assuming now that the particular piece of 50 dictation material that dictator A was assumed to be recording extends through machine 1 and then to machine 3 but is completed before the entire capacity of machine 3 has been used up. It follows, therefore, that this particular sequence of machines allotted or used in this particular piece of dictation includes only machines 55 1 and 3 and in that order. To identify this first piece of dictation completed by dictator A and permit a transcriber to readily select this first sequence of dictator's dictation, we provide the 60 following described sequence identifying and remembering apparatus.

Recalling the operation of the equipment from the dictator's control station, it will be remembered that whenever the dictating operator completes the circuit between conductors 106 and 107, the dictator's selector AS is operated to rotate the wipers thereof until said selector establishes connections to a vacant or idle machine. It will be observed, for example, that when the dictator's selector AS selected machine 1, the motor magnet AS—M thereof was impaled once. We prefer to use the impaling of the motor magnet AS—M as means for operating this sequence identifying apparatus and indexing for 75

the transcriber which machine is the first of that particular sequence of dictation. For this purpose we have attached a conductor SA (see Fig. 4E) to the conductor 121 supplying the motor magnet AS-M so that the circuit between the conductor SA and the battery negative L- is interrupted the same number of times as the dictator's selector AS is notched around in seeking this first idle machine and the number of 10 interruptions of the circuit to the conductor SA will represent the number of the machine to which the dictator's selector is finally connected.

The conductor AS may be traced through control group through Figs. 4D, 4C and 4B to a sequence remembering selector RSA', where it is shown connected to a conductor 222 by means of normally closed contacts RSA'-Ha of a holding relay RSA'-H for the transcriber's remembering selector RSA' for sequence A'.

20 The conductor 222 is attached to one terminal of the motor magnet RSA'-M of the transcriber's remembering selector RSA'. The other terminal of said motor magnet is connected to ground. It will thus be observed, assuming that 25 the normally closed contacts RSA'-Ha connected between conductor SA and the conductor 222 is closed, that the motor magnet RSA'-M will be impelled the same number of times as the motor magnet AS-M of the dictator's selector AS. It is therefore apparent that the sequence remembering selector RSA' will be advanced the same number of points as the dictator's selector AS so that the remembering selector RSA' is connected to the same machine as 30 35 is the dictator's selector AS.

In order that a release magnet RSA'-R may be energized at the time the motor magnet RSA'-M is impelled the first time, we have inter-connected the motor magnet RSA'-M and 40 the release magnet RSA'-R by means of a conductor 223a so that the energy which is applied to the motor magnet RSA'-M is also applied to the release magnet RSA'-R.

It has been pointed out previously in connection with the dictating equipment that the dictator's holding relay AS-H is energized as long as the dictator's selector AS is connected to a machine. It is therefore apparent that the inclusion of normally open contacts AS-Hb in a circuit 223 which extends from the battery negative L- through the normally open "off-normal" contacts to the coil of the release magnet RSA'-R will operate to maintain the release magnet energized when the remembering selector RSA' moves off of the first or "home" position.

It will be noted that the circuit 223 including the normally open contacts AS-Hb also include normally closed time operated contacts CSA'-ETa and that if we assume these contacts to be closed, the release magnet RSA'-R will be continuously energized regardless of the condition of the holding relay AS-H associated with the dictator's selector AS.

65 In order that a holding relay RSA'-H may be utilized to transfer the control wire SA from the sequence selector RSA' to the second sequence selector RSA" and used to busy the first machine of this sequence after the dictating operator has disconnected therefrom, we include the holding relay RSA'-H in a circuit 224 which includes a normally open contact RSA'-RRa of a release magnet relay RSA'-RR which is connected in parallel with the release magnet RSA'-R, and a normally closed time operated

contact AS-Hc of the dictator's holding relay associated with the dictator's selector AS extending from the battery negative L- to the coil of the holding relay RSA'-H, the other terminal of said relay coil being connected to 5 ground.

The provision of such circuit allows the holding selector RSA' so as to place the battery dictator's holding relay AS-H is de-energized at the end of dictator A's first completed piece 10 of dictation as by the dictator placing the handset in the cradle so as to operate the cradle switch. Whenever this occurs, the holding relay RSA'-H establishes its own holding circuit through normally open contacts RSA'-Hb connected in parallel with the normally closed contacts AS-Hc.

We have included a normally open contact RSA'-Hc in a conductor 225 extending from the battery negative L- to the wiper g (see Fig. 20 4G) of the first sequence remembering selector RSA', so that as soon as the dictator's line selector AS is disconnected from the private wire corresponding to the machine upon which the dictator was recording his material, the closing 25 of the contact RSA'-Hc will connect the battery negative L- to the wiper g of the remembering relay RSA'-H to be energized as soon as the negative on that particular private wire. Assuming, for example, that the dictating operator was controlling machine 1, it has been shown that the private wire PW1 associated therewith would be energized from the battery negative and that as soon as the dictating operator is disconnected therefrom as by placing the handset 30 in the cradle so as to operate the cradle switch associated therewith, private wire PW1 will be de-energized. It will be noted that operation of the contact RSA'-Hc would therefore re-establish the connections between the battery 35 negative L- and the private wire PW1 so that the machine 1 would be "busy" to any other dictating or transcribing operator. It will also be noted that at the same time the connection between the conductor SA and conductor 222 40 (see Fig. 4B) to the motor magnet RSA'-M will be interrupted by the opening of the normally closed contacts RSA'-Ha so that subsequent operation of the dictator's selector AS will no longer operate the first sequence selector RSA' 45 50

At the same time closing associated normally open contacts RSA'-Hd will transfer the conductor SA from conductor 222 to a conductor 226 which extends to the operating mechanism for the second sequence selector RSA". The wire 55 226 bears the same relation to the sequence selector RSA" as does the wire SA to the sequence selector RSA' so that upon subsequent impulsive operation of the dictator's selector AS, the second sequence selector RSA" will be notched around 60 in accordance with the impulsive operation of the dictator's selector AS, and the second selector RSA" will then be held in a position contacting the machine comprising the first machine of a new sequence which the dictating operator controls 65 during the dictation of the second sequence of dictation.

We have provided a number of such sequence remembering selectors which are associated with 70 the various dictating operators and which include a sequence remembering selector for the first, second and third sequences of dictator A and a similar set for the first, second, and third sequences of dictator B. In a similar manner the 75

first, second and third sequences of dictator X are also remembered for transcriber Y.

As has been pointed out hereinbefore, the system of our invention includes not only the provision of machines and equipment for recording an operator's dictation but includes also means whereby such dictation may be transcribed, this means including many novel features as regard methods of control and specific operations which may be performed upon the recording and reproducing machine units.

TRANSCRIBING.

Let us, therefore, at this time consider the operation of the aforementioned equipment from the transcriber's view point and for the sake of simplifying such description let us again make certain assumptions as regard operating conditions.

In order to properly and completely describe the construction and operation of the transcriber's equipment and the cooperation of the various parts of the system therewith, we will therefore assume that the dictator A has dictated on machine 1 and machine 3 and that the equipment is otherwise idle, that is to say, that no dictators are at the time under consideration dictating and that no transcribers other than the transcriber under consideration is transcribing. Inasmuch as all of the transcribing equipment is identical we will at this time describe the equipment associated with and operated by the transcriber C. In accordance with one of the objects of our invention, we prefer to arrange the transcribing equipment in as simple a manner as possible and so arrange it that it may be connected to the central station equipment by a single pair of wires.

Referring to Fig. 4A, we have illustrated the transcribing equipment as including a well known set of telephone equipment which may comprise a microphone 200, an impulsing device 201, a sound responsive device 202, an induction coil 203, a capacitor 204, and hook operated switch 205. This equipment is inter-tied between a pair of incoming wires 206 and 207 in such a manner that the transcription of the material and all of the operative functions on the various remote machines may be caused by equipment operating over the pair of wires 206 and 207. In order that the transcriber may hear the reproduction of the transcribed material, we extend the wire 206 to the capacitor 204 and thence through conductor 208 and the induction coil 203 to one terminal of the hook switch 205. From there a conductor 209 may be traced as going through a sound reproducing device 202 and from there through a conductor 210 through the induction coil 203 and out on the line 207. It is apparent that if the speech potential is impressed across the wires 206 and 207 that such potential will appear across the sound responsive device 202 to cause said sound to be reproduced thereby.

The transcriber's impulsing circuit may be traced as extending from wire 206 through another set of contacts of hook switch 205, via conductor 211 to contacts 211a of a transcriber's foot operated impulsing device 212, the construction of which will be described hereinafter. From the contacts 211a a circuit extends by means of a conductor 213 to contacts 214 of the impulsing device 201, then through the sound reproducing device or microphone 200 and return via conductor 210, induction coil 203 and the second incoming conductor 207.

Referring to Fig. 4A, conductor 206 is connected directly to the battery negative L- and conductor 207 is attached to one terminal of the transcriber's line relay CL, the other side of which is connected to ground, so that as soon as the receiver or sound reproducing device 202 is lifted from the hook, operation of the hook switch 205 will complete the circuit from conductor 206 through the impulsing contacts 211a and 214 to the coil of the transcriber's line relay CL and thence to ground. It will be remembered that the positive battery terminal is grounded and that therefore operation of the hook switch 205 will energize the transcriber's line relay CL. It is further apparent that momentary interruptions of the circuit due to the operation of the impulsing device 201 or 212 to operate the impulsing contacts 214 or 211a will momentarily interrupt the supply to the transcriber's line relay CL and cause that relay to open and close its contacts in accordance with the impulsing operation performed by either of the impulsing devices.

The impulsing device 212 is constructed in the preferred form of our invention in a manner as is illustrated in Fig. 6. In the preferred form of our invention, the transcriber's foot operated impulsing device may include three pedals, 215, 216 and 217, each of which is slidably guided in a suitable supporting frame 218. The pedal 215 is slideable in an up and down direction while the pedals 216 and 217 are slideable right and left. Each of the pedals is provided with a compression spring 219 arranged to restore the pedal to its normal extended position.

Pedals 215, 216 and 217 are so arranged that the transcribing operator may operate the pedal 215 by raising or lowering her foot, while the pedal 216 is operable by moving the foot to the right, and the pedal 217 is operable upon a leftward movement of the transcriber's foot.

Associated with each of the pedals 215, 216 and 217 is an impulsing device arranged to interrupt a circuit a different number of times depending upon which of these pedals is actuated. For example, the pedal 215, which is adapted to be operated whenever the transcriber presses downwardly with her foot, is arranged to actuate the impulsing device 215a to interrupt its impulsing circuit two times. While the particular form of impulsing device which may be employed may be varied, we have illustrated the impulsing device 215a as corresponding in structure to the impulsing devices commonly employed in fire alarm systems, such as a disc of suitable insulating material having a number of cam points 215b upon its periphery and adapted to engage the contact finger 215c to open a pair of switch contacts indicated at 215d. The impulsing device 215a may be suitably rotated about an axis 215e by means of a quadrant lever 215f, geared as indicated in Fig. 6 to the impulsing device 215a, the quadrant lever 215f being pivoted at 215g and having its outer end connected by means of a spring 215h to the stem 215k of the foot pedal 215. The quadrant lever (and the impulsing device 215a) are normally held in their "off" position and are normally returned to this position by means of a return spring 215m.

It will be understood therefore that immediately upon the depression of the pedal 215 the spring 215h will be tensioned urging the quadrant lever 215f in a counterclockwise direction and transmitting power to the impulsing device 215a tending to rotate this device in a clock-

wise direction to move the cams 215b beneath the switch finger 215c and cause interruptions of the circuit controlled by the switch 215d. As will be understood by those skilled in the telephone art, this interruption of the circuit twice will accomplish the same result as though in a standard telephone dial set the number "two" had been dialed.

Again as will be understood by those skilled in the telephone art, the interruption of the circuit by the impulsing device 215a would cause a clicking noise in the sound reproducing device 202, and therefore we provide suitable short circuiting device on each of the impulsing devices of the trans-

5 scriber's foot switch.

By referring to Fig. 6 it will be noted that associated with the impulsing device 215a is a short circuiting switch 215n arranged to be closed by an auxiliary cam 215p on the impulsing device 215a, so arranged with respect to the cams 215b that the switch 215n will be closed during the entire time that the cams 215b are performing their impulsing or dialing operation.

For purposes of simplicity of illustration here-
25 in we have shown the same character of impulsing devices, switches, cams, springs, levers and operating mechanism associated with each of the pedals 216 and 217, the impulsing devices associated with the pedal 216 bearing the reference character 216a adapted to interrupt the impulsing circuit four times, while the impulsing device 217a associated with pedal 217 interrupts the circuit three times upon each operation of the pedal.

35 Each of the impulsing contacts associated with the pedals 215, 216 and 217 are connected in a series circuit so that whenever any of the pedals are operated the single series circuit extending therethrough will be impulsed, while on the other hand the short circuiting contacts for each of the three pedals are connected in parallel so that if any one of the three pedals is operated the short circuiting circuit will be completed.

40 For the sake of simplifying the wiring diagram, the series circuit including the impulsing devices for each of the three switches of the three foot pedals, 215, 216 and 217 is shown merely as single impulsing contact 211a, while the short circuiting contacts of the three pedals which are connected in parallel are shown as short circuiting contacts 220. It will be noted in reference to the wiring diagram in Fig. 4A that short circuiting contacts 220 and similar short circuiting contacts 221 associated with the hand operated impulsing device 201 are so arranged as to provide a short circuiting circuit across the sound reproducing device 202, so that during the operation of the impulsing circuit represented by conductors 206 and 207 the impulsing sound will not be reproduced in the transcribing operator's ear.

Transcriber's selection of sequence

45 In view of the fact we began this description by assuming that the dictating operator A had recorded a single sequence starting on machine 1, the sequence being automatically extended by machine 1 to machine 3, we will now describe the equipment by which the transcribing operator is able to select at will the sequence 50 she first wishes to transcribe. For this purpose we have made available to transcribing operators C and D the first, second and third sequences of dictator A and the first, second, and third sequences of dictator B. Let us for the sake of this 55 explanation assume that the transcribing opera-

tor C wishes to transcribe the first sequence of dictator A, which sequence has been labeled for the sake of convenience as A'. We prefer to allow the transcriber to select the sequence she will transcribe by dialing an appropriate number with the dialing or impulsing device 201, and have accordingly assigned "two" on the impulsing device 201 to the sequence A'.

60 It will be remembered that the operation of the impulsing device 201 causes the transcriber's line relay CL to alternately open and close its contacts in accordance with such dialing impulses. For the selection of the chosen sequence we provide a transcriber's sequence selector CS (see Figs. 4A and 4B) the motor magnet CS-M which is connected in a circuit 227 extending between the motor magnet and the battery negative L— and including a normally open contact CLa of the transcriber's line relay CL. It is apparent that the operation of the dialing or impulsing device 201 to cause the alternate opening and closing of the transcriber's line relay CL will alternately complete and interrupt circuit 227 to motor magnet CS-M and thereby cause the transcriber's sequence selector CS to notch around in accordance with the impulses dialed by the dialing device 201.

65 Dialing "two" on the dialing device 201 will therefore cause the transcriber's sequence selector CS to move to the second notch or the contact associated with the first sequence A'.

An auxiliary control buss 228 (see Fig. 4A) is provided for operating the auxiliary control relays for the selector CS and is connected to the battery negative L— through normally open contacts CLb of the transcriber's line relay CL so that whenever said line relay CL is energized by the completion of the circuit thereto through the closing of the hook switch 205 as when the transcriber removes the sound reproducing device 202 therefrom, the auxiliary control buss 228 will be connected to the battery negative L—. We include a selector control relay CS-S for controlling the operation of a release magnet CS-R and connect the coil of the relay CS-S to the conductor 228 so that as soon as the dictator's line relay CL is energized the control relay CS-S is also immediately energized. We include normally open time operated contacts CS-Sa of the selector control relay CS-S in a circuit 229 which extends from the control buss 228 to the coil of the sequence selector release magnet CS-R so that whenever the line relay CL is energized in the aforementioned manner the control relay for the selector CS will be energized to complete circuit 229 and energize the release magnet CS-R to maintain the sequence selector CS in whatever position it may be operated by the transcriber's impulsing device 201.

In order that the movement of the transcriber's sequence selector CS to the aforementioned position in connection with the first sequence A' will thereupon busy that sequence against all other transcribers, we have provided a system of sequence interlock wiring which includes a holding relay CS-H (see Fig. 4B) in a circuit 230 which extends from the auxiliary control buss 228 to the coil thereof through normally open contacts of the "off-normal" switch for the sequence selector CS and through a normally closed contact CS-La of a lockout relay CS-L. Assuming that the lockout relay CS-L is de-energized so that the circuit 230 is completed whenever the sequence selector CS moves off of the first point to allow closing of the normally open "off-nor-

mal" contacts included therein, the holding relay CS—H will be energized.

Energizing the holding relay CS—H will then complete the connection between the auxiliary control buss 228 and a conductor 231 through normally open contacts CS—Ha included therebetween. The conductor 231 is extended to the wiper b of the sequence selector CS (See Fig. 4A) so that energization of this relay will cause the wiper b to be connected directly to the battery negative L—. We prefer to connect the various terminals of the level b of the sequence selector CS with corresponding terminals on level b of the other sequence selectors associated with transcriber C and any and all other transcribers who may have access to material dictated and recorded by the dictators A and B by means of wires SW2, SW3, etc., and use these wires to prevent other transcribers from operating on a sequence simultaneously with another transcriber.

For this purpose we include the transcriber's lockout relay CS—L in a circuit 234 (see Fig. 4B) which extends between the conductors 231 and the coil of the relay CS—L and include therein a normally closed contact CS—Hb of the holding relay CS—H so that whenever the holding relay CS—H is energized, the circuit 234 supplying the lockout relay CS—L will be interrupted, thereby preventing operation of the lockout relay CS—L. Assuming that the holding relay CS—H is not energized and that the circuit between the conductor 234 and conductor 231 is completed, it will be observed that should the wiper b come to rest upon one of the SW wires which is energized from the battery negative, such circuit from the battery negative will thereby be completed through conductors 231 and 234 to the lockout relay CS—L. Energization of the lockout relay will then open contacts CS—La included in the circuit 230 to the holding relay CS—H and prevent its energization.

An inspection of the contact symbols of the contacts CS—Ha, CS—Hb and CS—La will reveal the fact whenever the wiper b comes to rest on a particular selected point there will be sufficient time allowed for the lockout relay CS—L to "try" the wire and to "see" if it is energized and if so, prepare the necessary "lock-out" by interrupting circuit 230 before contacts of the relay CS—H will be operated. If after an appreciable time the contacts of the relay CS—L are not operated, contacts of the relay CS—H will be operated so as to establish a "busy" circuit to the particular "SW" wire to which the wiper b of the transcriber's sequence selector is connected.

In order that the operation of the transcriber's foot operated impulsing device 212 may be effective in causing the necessary control operations upon the machine to which the equipment will be connected when the appropriate sequence is selected in the manner just described, we have included a connection extending from the conductor 231 to the wiper c of the transcriber's sequence selector CS through a conductor 233 which includes a normally closed contact CT—Ta of the transcriber's trip relay CT—T and a normally open contact CS—Hc of the holding relay CS—H. Assuming that the contact CT—Ta is closed and remembering that the contacts CS—Hc of the holding relay CS—H will, under normally operating conditions, be closed, it will be seen that we have in this manner connected the battery negative L— to the wiper c through

normally open contacts CLb of the transcriber's line relay CL.

We have connected a plurality of operating wires "OW" (OW1, OW2, OW3, etc.), to corresponding points on the level c of the selector CS. The wire OW2 is connected to level c in a position to be contacted by wiper c when the selector CS is operated by the transcribing operator dialing "two" and notched to the second point so that the wire OW2 will be energized from the battery negative L— through normally open contacts CLb of the transcriber's line relay CL and so that alternate opening and closing of these relay contacts as the result of dialing operations performed by the foot operated impulsing device 212 will cause the wire OW2 to be alternately energized and de-energized in accordance therewith.

Tracing the wire OW2 through the sequence operating wire group it will be observed that the wire OW2 is directly connected to a motor magnet CSA'—M (see Fig. 4A) of a control selector CSA' associated with the first sequence A'. It, therefore, follows that the control selector CSA' will be notched in accordance with the dialing impulses impressed upon the wire OW2 in accordance with operations of the foot operated impulsing device 212 associated with the transcriber C's control equipment.

We have provided a means for maintaining the control selector CSA' in an operated position for a short time and then allowing said selector to return to its "home" or off position, this means comprising a holding relay CSA'—H which cooperates with a release magnet CSA'—R and which is connected in a circuit 235 which extends from the operating wire OW2 to the coil of the relay CSA'—H and includes a normally closed "off-normal" contact of the sequence control selector CSA' so that the coil of the relay CSA'—H is normally energized and will be de-energized as soon as the sequence control selector CSA' is moved off of its normal or "home" position. We extend a circuit 236 from the battery negative L— to the coil of the release magnet CSA'—R and include therein a normally open time operated contact CSA'—Ha of the holding relay CSA' which is time-delayed in the circuit opening direction so that since the coil of the relay CSA'—H is normally energized a time delay will be allowed after de-energization of the relay CSA'—H during which the release magnet CSA'—R will remain energized.

Whenever a dialing impulse is transmitted to the motor magnet CSA'—M from the transcriber's foot impulsing device 212, the control selector CSA' will be operated to notch forward a number of notches corresponding to the number of impulses transmitted from the impulsing device 212 and the selector will remain in that position until such time as the time operated contacts CSA'—Ha are operated. Upon operation of these contacts the release magnet CSA'—R will be de-energized allowing the control selector CSA' to return to the normal or off position.

In order that operation of this control selector may be used to control the operation of the first sequence A' we include three groups of control relays, namely, "start-stop," "go back" and "go ahead." Inasmuch as these relays are all similar in operation and the manner of their connection to the control selector CSA' is identical, we deem it sufficient to describe the operation of but one of these relays. For this purpose we will recite the operation of the start-

stop relay, namely, CSA'-S and the trip relay therefore CSA'-ST. We prefer to employ two dialing impulses resulting from the operation of the foot operated impulsive device 212 as the 5 number of impulses required to effect the start-stop operation of the record motor RM included in the machine equipment.

We accordingly connect the wire OW2 to the wiper and a wire 237 to the second terminal of 10 the control selector CSA' so that the operating wire OW2 will be connected to the wire 237 whenever the selector CSA' is moved ahead two notches in accordance with two dialing impulses transmitted from the foot operated dialing device 212. We connect the wire 237 to the coil 15 of the relay CSA'-S and include in the circuit a normally closed contact CSA'-Sa of the relay CSA'-S. Inasmuch as the operating wire OW2 is normally energized except at such times as it 20 is being impelled, as soon as connection is established between the wiper of the control selector CSA' and wire 237 the relay CSA'-S will be energized through its own normally closed contacts CSA'-Sa.

25 We provide a self holding circuit for the relay CSA'-S which includes a conductor 238 which is extended between the coil of said relay and the battery negative L- and includes a normally open contact CSA'-Sb of said relay 30 and a normally closed time operated contact CSA'-STa of the trip relay CSA'-ST associated therewith so that as soon as the relay CSA'-S is energized it will complete its own self holding circuit through the conductor 238 35 and interrupt the circuit 237 between the second control point of the selector CSA' and the coil of the relay CSA'-S.

In order that energization of the relay CSA'-S may be used to control the stop-start 40 operation of the record motor RM of the first machine of the sequence A', we provide a conductor 239 which is extended between the battery negative L- and the wiper a of the sequence remembering selector RSA' and includes a normally 45 open time operated contact CSA'-Sc so that whenever the relay CSA'-S is energized as by dialing "two" a connection will be established between the battery negative L- and the wiper a of the selector RSA' (see Fig. 4F).

50 We connect to the various points on level a the wires F1, F2, F3, etc., which are common to the corresponding points on level b of the machine selector 1S and corresponding points on level b of the dictator's selector AS.

55 In reviewing the operation of machine I from the dictator's viewpoint, it will be remembered that energization of the wire F1 will energize the relay 1VR of machine I so as to cause the record rotating motor 1RM thereof to be energized so as to rotate the recording medium. Inasmuch as we have assumed that the transcribing operator selected the first sequence of dictator A, namely, sequence A' and therefore is connected to the first sequence selector RSA', and that machine I represented the first machine of the first sequence dictated by dictator A, it follows that operation of the transcriber's foot operated impulsive device 212 will cause the wire F1 of the machine multiple group to be 60 energized from the battery negative L- and that such energization of the wire F1 will cause the recording medium rotating motor RM of machine I to operate to rotate the recording medium.

70 75 It has been previously shown in connection

with the inter-relation between the sequence remembering selector and the dictator's selector how the sequence remembering selector is caused to rest upon the contacts corresponding to the first machine in a particular sequence. Assuming that the connections are established as previously described to cause the record rotating motor RM to revolve the recording medium of machine I as the result of the transcriber operating the foot operated dialing device 212 by placing her foot thereon, and further assuming that the transcribing operator now wishes to pause and stop the rotation of the recording medium, it is only necessary for her to remove her foot from the foot pedal 215.

In connection with the foot operated dialing device 212 it has been shown how removal of the foot from the pedal 215 will cause the device 212 to again transmit two impulses. It will be further remembered that the sequence control selector CSA' advances two notches in accordance with the first impulsive operation and then returns to the "home" position. The second impulsive as the result of the transcribing operator removing her foot from the pedal 215 will therefore cause the sequence control selector CSA' to again move up two notches so as to complete the circuit between the wire OW2 and the wire 237 (see Fig. 4A) and thereupon connect the wire 237 to the battery negative L-. It will be noted, 30 however, that the circuit to the coil of the relay CSA'-S has been interrupted by its own contact CSA'-Sa included therein.

In order that the relay CSA'-S may be de-energized by the second operation of the control 35 selector CSA', we have included the trip relay therefor CSA'-ST in a circuit 240 which connects to the wire 237 and includes therein a normally open time operated contact CSA'-Sd. We prefer to make the time of operation of the contacts CSA'-Sd of the relay CSA'-S sufficiently long so that the control selector CSA' will have returned to its home position before the circuit 240 is completed so that upon the second operation of the control selector CSA' to energize the wire 237, the trip relay CSA'-ST will be energized. Energization of the trip relay will thereupon operate the normally closed contacts CSA'-STa included in the self holding circuit 238 for the relay CSA'-S and cause its de-energization. Inasmuch as the circuit 240 is completed through normally open contacts of the relay CSA'-S the trip relay will also be de-energized.

50 De-energization of the relay CSA'-S will interrupt the circuit 239 to the wiper a and cause the de-energization of the machine multiple wire F1 and thereby cause the de-energization of the relay 1VR of machine I. As will be remembered in connection with the operation of the dictating 60 machine I as controlled by the dictating operator A, the de-energization of the relay 1VR will cause the circuit to the record rotating motor 1RM to be interrupted and cause the motor to instantly stop its rotation of the recording medium.

65 It has been mentioned hereinbefore, in connection with the operation of the system when controlled by dictator A, that the machine includes a relay system by which the machine is conditioned for either dictation or transcription, depending upon whether a dictating operator or a transcribing operator is controlling the machine. It has also been shown, in connection with the dictating operation, how the machine is conditioned 70 75

for recording dictation through a pair of relays 1D and 1DX, which are arranged to be energized whenever the machine is being controlled by the dictating operator. We provide a similar system 5 for conditioning the machine for operation by a transcribing operator.

This system includes a relay CSA'-G which is connected between the previously mentioned operating wire OW2 and ground. Whenever the 10 operating wire OW2 is connected to the battery negative L— the relay CSA'-G will be energized. We include normally open time operated contacts CSA'-Ga of the relay CSA'-G in a circuit 250 which extends between the battery negative L— and wiper f of the remembering selector RSA' (see Fig. 4G). It will be seen that energization 15 of the relay CSA'-G by the energization of the wire OW2 from the battery negative L—, in the manner hereinbefore described, will cause the wiper f of the remembering selector RSA' to be connected to the battery negative L—. It will also be seen that the contacts CSA'-Ga of the relay CSA'-G are arranged in a normally open fashion, with a time delay applied to the circuit 20 opening operation so that the circuit 250 and the wiper f will be continuously connected to the battery negative L—, even though the relay CSA'-G may be momentarily de-energized by the previously described impulsive operations performed for 25 the purpose of controlling the operation of the machine on which the transcriber is operating. The wiper f of the remembering selector RSA' is at the time of consideration connected to the point on level f connected to machine 1 and to 30 which is attached a wire L1. Tracing L1 through the multiple group we find that it extends unbroken into the mechanism of machine 1, where it is connected to the coil of a relay 1T (see Fig. 4H), the other side of which is connected to 35 ground, so that whenever the remembering selector RSA' is connected to machine 1, and to a transcriber's control equipment, the relay 1T will be energized.

We also include in machine 1 an auxiliary relay 1TX, which is connected in a circuit 151 extending between the battery negative L— and ground and which includes a normally closed contact 1DSXc of the relay 1DSX and normally open contacts 1Ta of the relay 1T so that as soon 40 as the relay 1T is energized, the relay 1TX may also be energized.

This transcriber's sequencing equipment also includes a parallel circuit 151a for supplying the relay 1TX which circuit may include a normally open contact 1TSa of a transcriber's sequencing relay 1TS. The transcriber's sequencing relay 1TS is connected, by means of conductor 1TS3, to an inter-transfer conductor 1T3, and is arranged to operate in connection with contacts of 45 the limit relays EE of the various machines in exactly the same manner as that previously described in connection with the relay 1DS and the wires 1TS2 and 1T2 of the dictating equipment. It will be remembered in connection therewith 50 that the relay 1D was continuously energized as long as the dictating machine was controlled by the dictating operator, while the auxiliary relay 1DX was energized as the machines were operated in sequence. A similar method of operation is provided by the relays 1T and 1TX.

It was pointed out a few paragraphs hereinbefore how the wire F1 was energized by the transcribing operator in an attempt to start the rotation of the recording medium of machine 1. Referring to circuit 134 (see Fig. 4G) which sup-

plies the relay 1VR, it will be seen that completion of circuit 134 is performed by means of normally open contacts 1TXa of the relay 1TX. This contact is connected in parallel with the previously described contacts 1Da of the dictating relay 1D.

In order that the alternate energization and de-energization of the relay 1VR may operate to stop and start the rotation of the record rotating motor 1RM in accordance with the operation of 10 the transcriber's foot operated impulsive device 212, we have connected a normally open contact 1VRc (see Fig. 4F) of the relay 1VR and normally open contacts 1TXb of the relay 1TX in a circuit 252 which extends from the battery negative L— to the conductor 136 which energizes the record rotating motor 1RM, so that energization of the relay 1VR will, as the result of the energization of relay 1TX, complete circuits 252, 136, 137 and 138 to the record motor 1RM and 20 make said record motor responsive to the operation of the relay 1VR.

Assuming that the transcribing operator has successfully performed the stopping and starting operation on the recording medium of machine 1, let us now investigate the manner in which speech sounds picked up by the recording and reproducing device 17 associated with said machine are transmitted back to the transcribing operator for reproduction. In order that the 25 reproducing operation of the transcriber will not in any manner be limited by the operation of the point defining means we include a normally open contact 1Tb of the relay 1T (see Fig. 4G) connected in parallel with the normally open contact 1PDBc in circuit 156 so that whenever the machine is controlled by the transcribing operator the conductor 156 will be continually connected to the previously described wire J1. Voltages which are generated between conductor 132 30 connected to the recording and reproducing device 17 and ground will therefore be transmitted through conductors 155 and 156 to wire J1 so that 35 such speech voltages will appear between the wire J1 and ground.

Tracing the peregrinations of wire J1 as it leaves the dictating machine 1, we find that it continues uninterruptedly into the machine multiple group where it may be also traced (through Figs. 4G and 4F) to level e of the transcriber's sequence remembering selector RSA'. Inasmuch as this selector is in a position to contact the wire J1, a wire JA' connected to the wiper e will therefore be connected to the wire J1. The wire JA' is also connected to the second point on the 45 level a of the transcriber's sequence selector CS (see Fig. 4A). Remembering that this selector CS has been moved to the second point by the transcribing operator C in order that she may transcribe the first sequence of dictator A, it will be seen that the wiper connected thereto will, by means of the previously described circuit, be connected to one side of the recording and reproducing device 17 of machine 1. A conductor is attached to wiper a and extended to one input 50 terminal of a transcriber's reproducing amplifier CPA, the other terminal thereof being connected to ground. The output of said amplifier is connected by means of conductors 253 and 254 to the primary of a transcriber's playback transformer CPT, the secondary of which is connected to the previously described wires 206 and 207 through a capacitor 255.

The amplifier CPA may derive power from a circuit 255a extending between the battery nega- 75

5 tive L— and a power input terminal of the amplifier CPA and including a normally open contact CLE of the transcriber's line relay CL. The other power terminal of the amplifier CPA is connected to ground. The contacts CLE in circuit 255a are made time delay operating in the opening direction so that dialing impulses which momentarily de-energize the relay CL will not de-energize the amplifier CPA.

10 Summarizing the operation it will be seen that voltages corresponding in character to the speech recorded on the recording medium of machine 1 will be transmitted over conductor J1 through the machine selector 1S, the remembering selector RSA', the sequence selector CS, and applied to the input of the amplifier CPA. The greatly 15 amplified output of the amplifier CPA will thereupon be impressed across conductors 206 and 207 through the operation of the playback transformer CPT. As has been previously shown the speech voltages appearing between conductors 206 and 207 will be reproduced a sound by the transcriber's sound reproducing device 202.

20 In order that the relatively low direct current 25 resistance of the secondary of the playback transformer CPT may not operate as a short circuit across the conductors 206 and 207 we connect one terminal of said transformer secondary to conductor 207 through the capacitor 255 which 30 has a very low impedance to the ordinary voice frequencies but will present an open circuit to direct current so as to avoid any difficulty in the operation of the transcriber's relay CL.

35 It has been shown how the transcribing operator may, by pressing the foot pedal 215 cause the operating wire OW2 to be impelled twice so as to cause the transcriber's control selector CSA' to move up to the second point and thereupon operate the stop-start relay CSA'-S and the trip relay CSA'-ST in such a manner 40 as to effect the start-stop operation on the machine 1.

45 In order that the operation of the foot pedals 216 and 217 may perform similar operations with respect to causing the recording and reproducing device 17 to move back toward the forepart of the record or move forward toward the end thereof, we include a system of relays CSA'-GB (see Fig. 4A) and CSA'-GBT which are 50 arranged to operate in the same fashion as that described in connection with the stop-start relays so that the wiper of level b of sequence remembering device RSA' will be energized from the battery negative L— whenever the foot impelling device 212 is actuated to transmit three impulses. In a similar manner go-ahead relays CSA'-GA and CSA'-GAT are connected to be 55 operated whenever the impelling device 212 transmits four impulses so as to connect the wiper c of the remembering selector RSA' to the battery negative L—. In order that the operation 60 of the relay CSA'-GB and the subsequent connection of the wiper b to battery negative L— may cause the recording and reproducing device 17 of machine 1 to be retracted toward the forepart of the record, we connect the previously 65 described conductor H1 to the first point of the level b of the remembering selector RSA' (see Fig. 4F). It will be seen that the attachment of the wiper b to the battery negative L— will 70 energize the wire H1 therefrom. Tracing the wire H1 through the machine multiple group, it will be seen that this will energize the go-back relay 75 1SB in a manner identical with that described in connection with the operation of the equip-

ment from the dictator's control station. Energization of the relay 1SB will energize the shifting solenoid 1SS and the high speed motor 1HSM in such fashion as to cause the recording and reproducing device 17 to be retracted toward the 5 forepart of the record.

Subsequent de-energization of the wire H1 resulting from the removal of the transcriber's foot from the transcriber's foot pedal 216 and thus impelling the wire OW2 three times again will 10 therefore cause the de-energization of the relay 1SB and the cessation of the movement of the recording and reproducing device 17 back toward the forepart of the recording medium. We connect a conductor M1 to the first point of level 15 c of the remembering selector RSA' so that connection of the wiper c to the battery negative L— will connect wire M1 to said battery negative L—.

20 Tracing the wire M1 through the machine multiple group (through Figs. 4F and 4G) it will be found to continue unbroken to the equipment of machine 1 where it connects to the conductor 161 (see Fig. 4F) supplying the go-ahead shift relay 1SA so that the previously described 25 operation by the transcriber C in an attempt to cause the recording and reproducing device 17 to advance toward the end of the record will immediately energize relay 1SA. Energization of the shift relay 1SA will energize the shifting solenoid 1SS to cause the recording and reproducing device 17 to be attached to the high speed feed screw and will also energize the high speed motor 1HSM to rotate said feed screw in the proper 30 direction for advancing the recording and reproducing device 17 toward the end of the record at high speed. A subsequent de-energization of wire M1 by the transcribing operator removing her foot from the foot pedal 215 in the manner previously described will cause a cessation of this 35 advancing movement.

40 It will be remembered in connection with the operation of the dictating system from the dictator's control station that dictator A, for example, may hook together a considerable number 45 of machines in a sequence during the process of recording his dictation, and it has also been shown that whenever the dictating operator completes a sequence as by placing his handset in the cradle therefor and operating the cradle switch 50 associated therewith, the recording and reproducing devices 17 are left at points corresponding to the point of last dictation. In order that the transcribing operator will not have to manually return these devices to the beginning of the recorded dictation and thus waste a considerable 55 amount of her time, we have provided an automatic means for returning the recording and reproducing devices 17 to the forepart of their respective recording mediums and to reset the point defining means associated with each machine to that point so that said point defining means may 60 be operated in conjunction with the transcriber's equipment. For this purpose we include in the equipment of machine 1 a dictator's reset relay 65 1RD (see Fig. 4G) which is connected in a circuit 254 between the battery negative L— and ground. Circuit 254 includes a normally closed contact 1De of the dictator's relay 1D and a normally closed contact 1Td of the transcriber's relay 70 1T so that during the time between the disconnection of the dictator A from machine 1 and the connection of the transcriber C thereto, the circuit 254 will be completed so as to energize the relay 1RD. We include a normally open contact 75

1 RD_a of the relay 1RD and a normally closed contact 1PDB_b of the point defining relay 1PDB in a circuit 255 which extends between the battery negative L₋ and the previously described 5 conductor 154. Assume that the dictating operator A, after having completed the recording of his dictation, disconnected from the machine without causing the recording and reproducing devices 17 to be shifted from their point of last 10 recording. It is therefore apparent that the normally closed contacts 1PDB_b included in circuit 255 will be closed at this time and that energization of the relay 1RD will complete circuit 255 from the battery negative L₋ to the previously 15 described conductor 154 and cause the dictator's high speed motor 1HSM to rotate in such direction as to cause the retraction of the recording and reproducing devices 17 back toward the fore-part of the record.

20 In order that the rotation of the high speed motor 1HSM may cause the retraction of the recording and reproducing device 17 we provide a circuit 256 between the battery negative L₋ and the conductor 153 and include therein a normally 25 open contact 1RD_b of the dictator's resetting relay 1RD so that energization of the relay 1RD will cause the energization of the shifting solenoid 1SS connected to conductor 153.

Energization of the shifting solenoid 1SS causes 30 the nut 28 associated with the recording and reproducing device 17 to contact the high speed feed screw and cause the retraction of the recording and reproducing device 17 along the record. In order that the measuring point from 35 which the "point-defining-means" operates may coincide with the new reset position of the recording and reproducing devices 17 we include a circuit 257 (see Fig. 4F), which extends from the battery negative L₋ to the previously described 40 conductor 154a and include a normally open contact 1RD_c of the dictator's resetting relay 1RD and a normally closed contact 1SA_e of the shifting relay 1SA. Inasmuch as the shifting relays 1SA and 1SB and the point defining relays 1PDA and 1PDB are all de-energized at the time of the 45 resetting operation, energization of the relay 1RD will connect the battery negative L₋ through contact 1RD_c in circuit 257 and through conductor 154a to the clutch 1PDC of the point defining equipment so that the zero or measuring point from which the point defining equipment 50 operates will be reset along with the recording and reproducing device 17 during such times as these devices are being retracted toward the fore-part of the record. This retraction operation will 55 continue on all machines in this sequence until each of the recording and reproducing devices 17 has arrived at the beginning of the recording medium, at which time the limit switches ES will cause the de-energization of the high speed travel 60 motors HSM.

As soon as the transcribing operator is connected to machine 1 to start the transcription of the recorded dictation, the subsequent energization 65 of the relay 1T dependent thereupon will de-energize the relay 1RD and thus restore the normal operating condition of machine 1.

In order to complete the description of the resetting operation, let us assume that the dictating operator A, after having completed the recording of his dictation, decided to play back a certain portion thereof and after having listened to some portion occurring before the end of the recorded dictation, disconnected from the machine so as 75 to leave the recording and reproducing devices 17

retracted from the point of last dictation. Referring to the circuit associated with the point defining means, it will be observed that such a condition will cause the energization of the point defining relay 1PDB. We therefore include a 5 normally open contact 1PDB_j (see Fig. 4G) of the relay 1PDB and a normally open contact 1RD_d of the dictator's resetting relay 1RD in a circuit 255a which extends between the battery negative L₋ and the conductor 163 so that energization of the 10 10 resetting relay 1RD in the manner previously described will energize the high speed motor 1HSM to cause it to rotate in the opposite direction to that previously described and will therefore cause the recording and reproducing device 17 to be advanced toward the point of last recording. This advance will be continued until the point defining means operates to de-energize the point defining relay 1PDB when the recording and reproducing device 17 has been advanced to 20 the point of last dictation. De-energization of the relay 1PDB will therefore interrupt circuit 255a to stop the operation of the high speed travel motor 1HSM. The recording reproducing device 17 being now at the point of last recording the 25 return of the device 17 to the beginning of the record is identical with that just described in connection with the resetting operation when the recording and reproducing device 17 was left at the point of last recording. Circuit 255 will 30 be completed to rotate the high speed motor 1HSM in such direction as to start the retraction of the recording and reproducing devices 17 while the point of operation from which the point defining means operates to define the point of last 35 recording or transcription will also be re-indexed to coincide with the new location of the recording and reproducing devices 17.

We also provide a point-defining operation for the transcribing operator such that whenever the 40 transcribing operator advances or retracts the recording and reproducing device 17 from the point of last transcription, the equipment will operate to return the recording and reproducing device 17 to the point of last transcription whenever the transcribing operator ceases performing other operations upon the machine. For example, suppose the transcribing operator finds it necessary to listen to some material further along in the dictation beyond the point at which she 50 is then transcribing. In order to permit this she presses the "go ahead" foot pedal 216 and causes the recording and reproducing device 17 to advance toward the end of the record in a manner previously described. This high speed advance 55 will continue until the transcribing operator removes her foot from the foot pedal. If she then prefers to listen to material recorded at this point the depression of the stop-start pedal will cause the recorded dictation to be played back to 60 her. If, however, she removes her foot from the stop-start pedal at the completion of the listening operation the equipment is so connected as to cause the recording and reproducing device 17 to immediately be retracted at high speed to the 65 point where she left off the original transcription.

This equipment is also arranged in such fashion as to bring the recording and reproducing device 17 to the point of last transcription even though she may have gone the opposite direction or back 70 toward the forepart of the recording medium in order to listen to material recorded at this point.

In order to better understand the operation of the equipment associated with this feature, assume that the transcribing operator C is con- 75

5 nected to machine 1 and is transcribing material
6 recorded on the recording medium thereof and
7 after transcribing a considerable portion she de-
8 sires to listen to a part of the recorded dictation
9 occurring near the first portion of the recording
10 medium. In order to permit this the transcribing
11 operator presses the go-back foot pedal 216
12 which causes the energization of the relay 1SB
13 in a manner described heretofore. Energization
14 of the relay 1SB will open the normally closed
15 contact 1SBd included in circuit 154a so as to
16 cause the de-energization of the point defining
17 clutch 1PDC.

18 As pointed out in connection with the descrip-
19 tion of the mechanical equipment, de-energiza-
20 tion of the clutch 1PDC will cause the point de-
21 fining means to measure the distance the record-
22 ing and reproducing devices 17 are moved back
23 toward the forepart of the record from the point
24 at which the retracting operation was started. It
25 has also been pointed out hereinbefore how such
26 operation will energize the relay 1PDB through
27 circuit 143.

28 This retracting operation may then continue
29 within the limits of travel afforded by the re-
30 cording medium or until such time as the trans-
31 cribing operator removes her foot from the go-
32 back pedal. In order to provide for immediate
33 return of the recording and reproducing device
34 17 to the point of last transcription as defined
35 by the point defining means we provide a circuit
36 260 which extends between the battery negative
37 L- and conductor 161 supplying the go-ahead
38 relay 1SA. Circuit 260 includes a normally open
39 contact 1TXc of the transcriber's auxiliary relay
40 1TX, normally closed contacts 1SBf of the go-
41 back relay 1SB, a normally closed contact 1VRd
42 of the relay 1VR and a normally open contact
43 1PDBk of the point defining relay 1PDB. Inas-
44 much as the contacts 1TXc are closed due to the
45 machine being operated by a transcribing oper-
46 ator and inasmuch as the normally open contact
47 1PDBk will at this time be closed due to the fact
48 that the recording and reproducing devices 17
49 are retracted from the point of last transcrip-
50 tion, circuit 260 may be maintained in an inter-
51 rupted condition either by opening the normally
52 closed contacts 1VRd of the relay 1VR (as in the
53 case where the relay 1VR is energized to cause
54 the record rotating motor 1RM to operate) or
55 by opening the normally closed contacts 1SBf of
56 the shifting relay 1SB (as is the case whenever
57 the relay 1SB is energized to cause the recording
58 and reproducing devices 17 to be retracted toward
59 the beginning of the recording medium). As soon
60 as the operation of retracting the recording and
61 reproducing devices 17 toward the forepart of
62 the record is stopped, the closing of the contacts
63 1SBf will complete circuit 260 so as to energize
64 the relay 1SA and cause the immediate return
65 of the recording and reproducing device 17 to
66 the point of last transcription unless the relay
67 1VR is energized by the transcribing operator
68 attempting to reproduce the material at this
69 point by starting the rotation of the record motor
70 1RM. The transcribing operator, therefore, may,
71 after having moved the recording and reproduc-
72 ing devices 17 back to the desired point, cause
73 them to advance at slow speed while reproduc-
74 ing material recorded at that point by depressing
75 the stop-start foot pedal. As soon as she has
76 listened to the desired portion of the recording
77 at that point, removal of her foot from the stop-
78 start foot pedal and the subsequent de-energiza-
79 tion of the relay 1VR will complete circuit 260

80 so as to energize the shifting relay 1SA and cause
81 the immediate return of the recording and re-
82 producing devices 17 toward the point of last
83 transcription. This advance will continue until
84 the point of last transcription is reached, as iden-
85 tified by the de-energization of the point defining
86 relay 1PDB. De-energization of the relay 1PDB
87 will thereupon open the normally open contact
88 1PDBk in circuit 260 and de-energize the shifting
89 relay 1SA. De-energization of the shifting relay 10
90 1SA stops the high speed advance and restores
91 the equipment to the normal stop-start operating
92 condition.

93 This system is also operative in the opposite
94 direction, in which the transcribing operator, 15
95 after having transcribed a portion of the material
96 recorded on the recording medium of machine 1,
97 advances the recording and reproducing device
98 17 to a point considerably beyond the point of
99 last transcription. As pointed out hereinbefore 20
100 this may be accomplished by depressing the foot
101 pedal 211 and causing energization of the relay
102 1SA to cause the high speed advance of the re-
103 cording and reproducing devices 17 toward the
104 end of the recording medium. 25

105 We provide normally closed contacts 1SAe in
106 the circuit 258 which supplies the point defining
107 clutch 1PDC so that energization of the relay
108 1SA will de-energize the clutch mechanism and
109 cause the point defining equipment to measure
110 how far the reproducing device 17 is advanced
111 beyond the point of last transcription. Such ad-
112 vance will cause the arm on the point defining
113 means to move in a counter clockwise direction
114 and complete the previously described circuit 144 35
115 so as to energize the point defining relay 1PDA.
116 Energization of the point defining relay 1PDA
117 in turn interrupts the circuit 258 to the point
118 defining clutch 1PDC so that whenever the subse-
119 quent de-energization of the relay 1SA occurs, 40
120 the circuit to the point defining clutch 1PDC will
121 not be completed until such time as the recording
122 and reproducing devices 17 are moved back to the
123 point of last transcription. In order that the
124 equipment may operate in a manner similar to 45
125 that described in connection with the operation
126 of moving the reproducing device 17 toward the
127 forepart of the record, we include a circuit 261
128 which extends between the battery negative L-
129 and the conductor 151 which is connected to the 50
130 shifting relay 1SB.

131 Circuit 261 includes normally closed contacts
132 1SAf of the shifting relay 1SA, normally closed
133 contacts 1VRc of the relay 1VR, and normally
134 open contacts 1PDAb of the point defining relay 55
135 1PDA and 1TXd of the transcriber's auxiliary
136 relay 1TX.

137 The relay 1TX is energized and the relay 1PDA
138 is also energized inasmuch as the recording and
139 reproducing device 17 has been moved ahead of 60
140 the point of last transcription. The remaining
141 relay contacts which operate to complete or in-
142 terrupt circuit 261 are the normally closed con-
143 tacts of the relays 1VR and 1SA. As soon as
144 the advancing of the reproducing device 17 is 65
145 completed by the de-energization of the relay
146 1SA, circuit 261 will be completed to energize
147 the relay 1SB and cause the immediate retraction
148 of the recording and reproducing device 17 toward
149 the forepart of the record. 70

150 The inclusion, however, of the normally closed
151 contacts 1VRc of the relay 1VR in circuit 261
152 allows the interruption of said circuit by the
153 transcribing operator placing her foot on the
154 start-stop pedal in order to reproduce the re- 75

corded dictation at this advanced location to prevent the return of the recording and reproducing device 17 to the point of last transcription. Such reproduction may be continued as long as 5 desired at this point, but as soon as the reproduction is stopped by the transcribing operator de-energizing the relay 1VR, circuit 261 will be completed to energize shifting relay 1SB and cause the reproducing device 17 to be retracted. The 10 retraction of the reproducing device 17 will continue until the relay 1SB is de-energized by the interruption of circuit 261 when the reproducing device 17 arrives back at the point of last transcription through the opening of contacts 1PDA_b included therein. These contacts open when the 15 relay 1PDA is de-energized by the point defining means indicating that the reproducing device 17 has arrived again at the point of last transcription.

In connection with the dictating equipment 20 and the operation of the machine by the dictator A we have shown how the dictator may record on the recording medium a characteristic tone intended to indicate to the transcribing operator instructions or the location of errors, end of letters, etc. As described in connection with the 25 description of the mechanical equipment, we have provided an instruction reproducer 29 which is caused to traverse the recording medium a short distance in advance of the recording and 30 reproducing device 17. Since the "information" tone was recorded by the dictator through the use of the recording and reproducing device 17, the information reproducer 29, which is in advance of the speech reproducer during the traversal of the recording medium, will reproduce such "information" to the transcribing operator prior to the time that she transcribes the recorded dictation at that point. Inasmuch as the 35 information reproducer is being excited not only by the characteristic tone of the information mark but also by the speech recordings thereon and in order to prevent the information reproducer from reproducing said speech, we connect the information reproducer in a circuit such that one side of the reproducer is connected to ground and the other is extended by means of a 40 circuit 262 (see Fig. 4A) to a band pass filter 263. Band pass filter 263 is tuned to the characteristic "information" frequency and operates to prevent 45 the transmission over circuit 262 of the speech recording, and operates in a manner well known in the electrical art to allow the passage only of the frequency characteristic of the information tone. We connect the circuit 262 to 50 the conductor 156 through a normally open contact 1T_c of the transcribing relay 1T so that the reproduction of the "error" tone occurring on circuit 262 will be transmitted by means of conductor 156 to the wire J1 in a manner identical 55 with that described in connection with the transmission of speech currents generated by the reproducing device 17. Inasmuch as the voltages appearing between the wire J1 and ground have been shown to operate the transcriber's sound 60 reproducing device 202, it will be apparent that whenever the information reproducer encounters a point at which the dictating operator indicated an "information" notation, such characteristic "information" sound will be reproduced in the 65 transcribing operator's ear prior to the time the transcriber will reproduce and transcribe the material recorded at that point.

As a brief summary, it has been shown how the transcribing operator may, after removing the sound reproducing device from the hook switch 70

205 provided therefor, operate the hand operated impulsive device 201 to choose that sequence of dictation which she wishes to transcribe and how, after having operated the impulsive device 201 to establish the desired connection, she may then 5 perform all of the required transcribing operations on the machine to which she is then connected through suitable operations of the foot operated impulsive device 212. It will be understood without referring to a detailed description 10 at this point how, when the transcribing operator has transcribed all of the material occurring on the first machine of a particular sequence the controls will be automatically transferred to the next machine in the sequence inasmuch as 15 this transfer is precisely identical with that described in connection with the transfer operation during the reproducing of the sequence by the dictating operator.

It was pointed out in connection with the 20 transcriber's sequence selector CS how the level b thereof operated to energize the wires SW2, SW3, etc., so as to busy other transcribers against the sequence which the transcriber may be controlling and how, when the sequence selector CS 25 encounters a busy sequence, the equipment is locked out to prevent the transcribing operator from interfering with operations which may be then in progress by another transcribing operator. We have provided additional equipment 30 such that when this condition occurs, the transcribing operator will be apprised of the fact that that particular sequence is busy and that her equipment is therefore locked out. We accordingly provide a circuit 263a (see Fig. 4A) which 35 extends between the previously described busy signal wire BT and the input of the transcriber's playback amplifier CPA and includes a normally open contact CS—L_b of the previously described lockout relay CS—L. It has been pointed out 40 hereinbefore how the relay CS—L will be energized whenever the wiper b of the sequence selector CS encounters a busy sequence. It therefore follows that the circuit 263a will be completed between the input of the amplifier CPA 45 and the wire BT bearing the busy signal, so that such busy signal will be reproduced as sound by the sound reproducing device 202.

Another busy or lockout condition occurs 50 which should be described at this time. The transcribing operator C may attempt to select a sequence which is not necessarily in use by another transcriber but which may be busy since the dictator A may still be dictating that sequence. We provide a circuit 264 (see Fig. 4B) 55 which extends from the wiper of level g of the remembering selector RSA' to the sequence interlocking wire SW2 and includes a normally closed contact RSA'—H_e of the sequence remembering selector holding relay RSA'—H. It will be remembered that the relay RSA'—H is energized at the time the dictating operator completes a particular sequence of dictation and that therefore during the time the dictating operator is dictating upon the sequence A', the connection will be established over circuit 264 through the wire SW2 and the wiper g of the remembering selector RSA'. 60 65

Inasmuch as the remembering selector RSA' 70 is connected to the first machine of this particular sequence and since the private wire PW1 thereof (to which the wiper g is connected) is energized from the battery negative L—, the wire SW2 will be connected to the battery negative 75

L. We have, therefore, provided a busy and interlocking system for the sequence selector CS such that the transcribing operator is not only prevented from operating upon sequences which 5 are being controlled by another transcribing operator, but is prevented from connecting to those which are in the process of dictation by a dictating operator, and have provided a busy signal which will indicate to the transcribing operator 10 that such is the present condition of the sequence.

We have also arranged the equipment in such a manner that the transcribing operator, while transcribing a chosen sequence, may interrupt her transcription on that sequence and transfer 15 her transcribing operations to another sequence, or to the emergency record, as she desires or as conditions may require, in the meantime causing the sequence upon which her operation was interrupted to be busied to all other transcribers 20 so that at the completion of the interruption she may return to the first sequence in an uninterrupted manner and continue with the transcription of said dictation. Such equipment may include a holding and tripping selector CT (see 25 Fig. 4B) which is provided with a motor magnet CT-M, a release magnet CT-R and a holding relay CT-H. The holding relay CT-H is connected in parallel by means of a circuit 265 including a normally open contact of the off-normal 30 switch with the motor magnet CT-M. The motor magnet CT-M is connected to the auxiliary control bus 231 by means of a conductor 265a in such a fashion that the circuit 265 is also supplied from the auxiliary control bus 231 35 through the previously described normally closed contact CT-Ta of the tripping relay CT-T. It will be observed that as long as the normally closed contact CT-Ta is closed the motor magnet CT-M will be responsive to the impulsing of 40 the auxiliary control bus 231 which occurs through the normally open contacts CLb of the transcriber's line relay CL supplying said control bus 231.

The transcriber's tripping selector CT is 45 notched around the same number of points as is the transcriber's sequence selector relay CS. In order that at the end of each dialing operation the transcriber's tripping selector CT may return to its home position, we include a normally closed contact CT-Ha in circuit with the release magnet CT-R so as to extend the circuit 50 265 through said contacts to energize the release magnet CT-R. We prefer to make the time of the opening operation of the contacts CT-Ha, 55 after energization of the coil CT-H through the closing of the off-normal contacts, sufficiently long to allow the transcriber's tripping selector CT to be notched around to its last point when sufficient dialing impulses are supplied, 60 and to maintain it at such last point for a brief instant before the release magnet CT-R is de-energized by the opening of the contacts CT-Ha. We prefer to use the last or "zero" position of the 65 trip selector CT as a means of transferring the transcriber's operations from the chosen sequence represented by the position of the sequence selector CS to another sequence or the emergency record.

In order to cause this operation, the transcribing operator may dial "zero" on the hand operated impulsing device 201 and thereby cause the transcriber's tripping selector CT to advance to the last terminal or "zero" point. In order that the connection between the wiper and the "zero" 75 point of the transcriber's tripping selector CT

may be operative to cause said transfer we connect the wiper by means of a conductor 286 to the auxiliary control bus 231 and the point on the contact thereof by means of a conductor 267 to the aforementioned sequence tripping relay CT-T. It therefore follows that whenever the tripping selector CT is caused to move to the "zero" point by dialing "zero" on the hand impulsing device 201, a connection will be established extending from the control bus 231 through 10 the wiper of the selector CT and thence over conductor 267 to the sequence tripping relay CT-T, causing said relay to be energized. Energization of this relay will then open the aforementioned normally closed contacts CT-Ta 15 thereof so as to disconnect the operating wires connected by means of circuit 233 to wiper c of the sequence selector CS and prevent further operation on that sequence. In order that energization of the tripping relay CT-T may cause 20 the transfer of the dialing control circuits through an auxiliary sequence control selector CSX we include a normally open contact CT-Tb between the auxiliary control bus 231 and an alternative control bus 268 so that since the control bus 231 is energized from the battery negative L- in a manner previously described, as soon as the relay CT-T is energized the alternate control bus 268 will be immediately energized from the battery negative L- and momentarily disconnected therefrom by means of the 25 operation of the transcriber's line relay CL whose normally open contacts CLb supply the control bus 231 and the alternate control bus 268. 30

In order that a dialing operation by means of 35 the hand operated impulsing device 201 subsequent to the operation of dialing "zero" just described, (such secondary dialing operation being with the intention of selecting the next or alternative sequence to be transcribed) may operate 40 to cause an auxiliary sequence selector CSX to be connected to said alternate sequence, we connect the motor magnet CSX-M thereof in a circuit 45 269 which extends from the battery negative L- and includes a normally open contact CLc of the 50 transcriber's line relay CL and normally closed contacts CT-Tc of the transcriber's sequence trip relay CT-T. Whenever the tripping operation occurs as by energizing the transcriber's sequence tripping relay CT-T in the manner just 55 described, circuit 269 will be completed through the normally open contacts CLc of the transcriber's line relay CL and that subsequent dialing operation will momentarily interrupt the circuit 269 through the operation of these contacts so as to cause the motor magnet CSX-M to notch the alternate sequence selector CSX around in correspondence with such impulses. 60

The holding and the interlocking equipment associated with the auxiliary sequence selector CSX is connected with respect to the alternate control bus 268 in a manner identical with that described in connection with the sequence with the sequence selector CS. We also provide a tripping selector CXT which is associated with 65 the auxiliary sequence selector CSX and operates in conjunction therewith in exactly the same manner as the tripping selector CT operates in conjunction with the sequence selector CS. Whenever the tripping selector CXT is advanced 70 to the "zero" position however, it energizes the tripping relay CXT-T therefor. In order that energization of this relay may re-establish the operation of the transcribing equipment through the first sequence selector CS we provide a cir- 75

cuit 270 which extends from control bus 268 to the coil of the transfer relay CXT-T which is supplied by conductor 267. The circuit 270 includes a normally closed contact CXT-Ta 5 therein so that as the transfer relay CXT-T is energized through conductor 267 and energizes the alternate control bus 268 it establishes its own holding circuit therefor through circuit 270 which circuit is maintained until interrupted by 10 the opening of the contact CXT-Ta as the result of the second dialing of "zero" by the transcribing operator in order to allow her to return to the first selected sequence. In order to insure that the operation of the sequence selector CS 15 and the auxiliary sequence selector CSX will not be disturbed by subsequent dialing operations such as operation of the foot controlled impulsing device 212, we provide holding circuits for the motor magnets thereof. The holding circuit for 20 the motor magnet CS-M of the selector CS includes a normally open contact CS-Hd (see Fig. 4B) of the holding relay therefor connected in parallel across the normally open contacts CLa of the transcriber's line relay CL which is included in circuit 227 supplying the motor magnet CS-M, so that as soon as the selector CS has been advanced to a point corresponding to the desired sequence, the holding relay CS-Hd will prevent the motor magnet CS-M from being 25 additionally impelled. In the same manner we include normally open contacts CSX-Hc which connect directly between the motor magnet CSX-M and the battery negative L- so as to prevent subsequent dialing operations from interrupting circuit 269 and additionally operating the motor magnet CS-M.

It will be observed that the holding relays CS-H and CSX-H will be de-energized whenever the equipment is released as by the transcriber hanging up or as in the case of the selector CSX whenever the transfer is made back to the original sequence.

In order that a transcribing operator or a supervisor of a plurality of transcribing operators 45 may be apprised at any time of the total number of machines which are in use and which represents the total amount of dictated material to be transcribed, we provide an annunciator or totalizing indicator (see Fig. 4J) which may comprise a common form of indicating board with a plurality of numbered lights numbered in correspondence with the number of machines provided and which may be connected between ground and independently to private wires PW1 to PWEX inclusive. It will be remembered that inasmuch as each of the PW group of wires is individually energized whenever the machines are busy and not completely idle, the number of lights lighted thereby will indicate the total number of machines which are being dictated upon or which have material dictated thereon or which are being transcribed from.

It is of course obvious that the annunciator board may be placed in a location designed to be the most useful and that additional boards may be connected in parallel with the one just described, so that such indication may be provided at more than one place. For example, such annunciator boards may be placed at the location 65 of the dictating operators to apprise them of which of the plurality of machines they may be connected. This may be observed by closely watching the annunciator board and observing which light comes on as soon as the dictator's handset is removed from the cradle. In the same

manner the annunciator board may be placed at the location of any or all of the various transcribers or in a private office used by a supervisor of transcription.

It has been stated hereinbefore that the cycle 5 of operations through which the dictating machines associated with this system are operated includes: first, the recording thereon of dictated material through operations performed by the dictating operator; second, the transcription 10 and removal of said material from the dictating machine as the result of operations performed thereon by the transcribing operator; and third, the erasing of the material from the various recording media of the machines of the sequence 15 and the complete re-conditioning of the machine preparatory to receiving and recording further dictation by dictating operators. In order that this may be accomplished by operations performed by the transcriber, it being understood 20 that the transcriber is the only person who is in a position to know whether or not such recorded dictation may be destroyed, we provide suitable equipment responsive to the transcriber's operation for performing this function. We prefer 25 to have the transcriber use the manually operable equipment provided at her station for accomplishing this result and have therefore chosen "nine" dialed by the hand impulsing device 201 as the operation which will cause the complete 30 destruction of the material recorded on the recording media of all of the machines which are tied together in the particular sequence to which the sequence selectors CS and CSX are connected at the time the aforementioned operation is performed.

Referring again for the sake of explanation to the sequence represented by the sequence selector RSA' it will be observed that the dialing of "nine" on the hand operated impulsing device 201 will 40 cause the control selector associated therewith CSA' (see Fig. 4A) to notch up nine points so that the wiper thereof will connect the energized operating wire OW2 to a conductor 275. The conductor 275 is connected to the coil of the erasing relay CSA'-E through normally closed contacts CSA'-Ea thereof so that energization of the wire 275 in the manner just described will cause the energization and operation of the relay CSA'-E. We provide a self holding circuit 276 50 for the relay CSA'-E which extends from the battery negative L- and includes a normally closed contact CSA'-ETb of a trip relay CSA'-ET and a normally open contact CSA'-Eb of the relay CSA'-E so that energization of 55 the relay will cause the contact CSA'-Eb to close and thereby establish its self holding circuit and maintain the relay CSA'-E in an energized condition even though the circuit 275 may be interrupted by operation of the normally closed contacts CSA'-Ea contained therein.

Reference to the contact symbols employed in the drawings for these contacts will indicate that the contact CSA'-Ea is timed in its opening operation so as to allow sufficient time for the 65 contact CSA'-Eb to establish the self holding circuit before the relay CSA'-E is de-energized by the interruption of circuit 275.

The energization of relay CSA'-E will complete a circuit 278 which extends from the battery negative L- to wiper d of the sequence remembering selector RSA' and includes a normally open contact CSA'-Ed of the relay CSA'-E so that as soon as the relay CSA'-E is energized the wire to which the wiper d is con- 75

nected will be energized directly from the battery negative L_—. Through the operation of the transcribing operator dialing "nine" on the hand operated impulsive device 201 the wiper d and 5 the wire of the machine multiple group connected thereto will be energized for a predetermined length of time and then subsequently de-energized. The manner in which this energization is used to eliminate or erase the recording on the 10 recording medium of the dictating machines will now be described.

Assuming that the first machine representing sequence A' is machine 1, it will be seen that the wiper d of the sequence remembering selector RSA' (see Fig. 4F) will energize from the battery negative L_— a wire N1 in contact with said wiper. Tracing the wire N1 through the machine multiple group through Figs. 4F, 4G and 4H it will be found to continue unbroken into the interior of the mechanism of machine 1. The wire N1 in machine 1 connects to a transcriber's erasing relay 1E so that the energization of the wire N1 will operate the erasing relay 1E during the predetermined length of time that the wire 25 N1 is energized. We include the coil 1Ec of the erasing mechanism (described in connection with the mechanical equipment) in a circuit 279 which extends from the battery negative L_— and includes a normally open contact 1Eb of the erasing relay 1E so that as long as the erasing relay 30 1E is energized the coil 1Ec of the erasing equipment will be energized from the battery negative L_—. In order that the erasing operation may be properly conducted it is essential that the coil 35 1Ec of the erasing equipment be energized while the recording medium of the machine is rotating and also that the equipment associated therewith, namely, the recording and reproducing device 17 and the point defining mechanism be restored to the beginning of the recording medium. In order that during the energization of 40 the coil 1Ec, the recording medium may be revolved as required we include a circuit 281 (see Fig. 4F), which extends from the battery negative L_— to the conductor 136 which supplies the record rotating motor 1RM so that as soon as the 45 relay 1E is energized the closing of the contacts 1Ec included in circuit 281 will energize the record motor 1RM and cause the rotation of the recording medium. It will also be noted that we 50 include normally open contacts 1Ed, 1Ee, 1Ef and 1Eg in parallel with normally open contacts of the dictator's resetting relay 1RD in such fashion that energization of the relay 1E will operate to energize the high speed motor 1HSM to 55 rotate in the proper direction to cause the point defining means to move to its zero position, and then operate the high speed drive motor 1HSM in the proper direction to return the recording and reproducing devices to the forepart of the record. These contacts also operate to energize 60 the shifting solenoid 1SS and the point defining clutch 1PDC so that proper operation of the equipment is secured.

65 Since the wire N1 is connected to wiper k of the machine selector 1S, and since wiper k is connected to the third terminal and the wire N3 of machine 3, the previously described operations will be simultaneously performed on machine 3 and all other machines which may be included 70 in this sequence.

Assuming that the relay CSA'—E is kept energized sufficiently long to allow all of the recording and reproducing devices to reach the beginning of the recording media of the various

machines connected in a sequence, such movement toward the forepart of the record being arrested by operation of the limit switch associated therewith, it is required at this time that the individual sequence be interrupted and the 5 machine selectors and sequence remembering device associated with this sequence be all returned to their "home" positions so the machines may be independently selected and looped together in sequences in response to the operation of a dictating operator.

A trip relay CSA'—ET is accordingly connected in a circuit 277 which extends from the battery negative L_— to the coil thereof and includes a normally open time operated contact CSA'—Ec 15 of the erasing control relay CSA'—E. The time of operation of this contact is made sufficiently long for the completion of the above described erasing and resetting operations. At the end of this time lapse, contacts CSA'—Ec will close and 20 energize the trip relay CSA'—ET. The contact CSA'—ETb incorporated in the self holding circuit 276 for the relay CSA'—E will thereupon open and de-energize the relay CSA'—E. De-energization of this relay will instantly open the 25 circuit 277 supplying the relay CSA'—ET so that it is also de-energized at this time. The contacts CSA'—Ed of the relay CSA'—E included in circuit 278 are therefore opened to de-energize all of the erasing equipment in the various machines. 30

Referring to the control mechanism for the sequence remembering selector RSA' (see Fig. 4B) we have included a normally closed contact CSA'—ETa in a circuit 223 which supplies the release magnet RSA'—R for the sequence remembering selector RSA'. This contact will open 35 after the resetting operations on the machines of the sequence are completed and de-energize the release magnet RSA'—R and allow the remembering selector RSA' to return to its home 40 or off position. This will interrupt the energization of the private wire PW1 (see Fig. 4A) through the wiper g of this selector and will cause the de-energization of the release magnet 1S—R (see Fig. 4F) of the machine selector 1S and in a 45 similar manner will cause the de-energization of the release magnets of all other machine selectors which are interconnected in the sequence which is supplied and controlled by the private wire PW1. Completion of the resetting operation as 50 defined by the ultimate operation of the contact CSA'—Ec will therefore cause all of the machines to be placed in an available condition for dictating operations with the recording and reproducing devices thereof returned to the fore- 55 part of the record, the point defining means conditioned for operation therewith and all the recorded material erased or eliminated from the recording medium. Furthermore, the sequence remembering selector associated with the erased sequence will be in a position to respond to operation by the dictating operator to record or 60 remember the new sequences of dictation.

In summarizing, it will be seen that we have provided a system and have described the operation of the system so that it is readily seen where-in the dictating operator A may be automatically connected to an available dictating machine whenever he removes the handset from the cradle associated with his control equipment. This machine has been illustrated as machine 1 in which the wiring has been illustrated in full and complete detail. Inasmuch as the wiring of all the other machines is identical it is readily understood that should machine 1 be busy the dictating op- 75

erator can control any of the available machines to which his selector AS connects him in the manner identical to that described in connection with machine 1. It has also been shown how the 5 dictating sequences are established through the operation of the dictating machine selectors to loop or hook together the various available machines as they are required and to maintain that connection during both the dictating and transcribing operations. It has also been shown how the interruption of the dictating control circuit as by the dictator placing the handset in the cradle and operating the cradle switch associated therewith will disconnect his control from that sequence and require the establishment of a new 10 sequence of dictation should he resume dictation. We have also shown how one of the transcribers, namely transcriber C, may operate to use any of the sequences which are available and operate 15 the machine in such a manner as to perform all of the required transcribing operations thereon. It has also been shown how the transcriber is able to follow the sequence of the dictator's dictation in travelling from machine to machine through 20 the interlocking and intertiming operations of the machine selector.

It has been further shown how the transcribing operator, if she is interrupted, may hold one of the sequences which she may be transcribing 25 against operation by another transcribing operator and transcribe emergency work which may appear on another sequence or on an emergency record.

We have also shown how the transcribing operator may, after completing a particular dictated sequence, cause the recording to be erased from the recording medium of the machines comprising the sequence, cause the machines to be reset for further dictating by a dictating operator 30 and cause all of the equipment associated therewith to assume a normal condition ready for subsequent dictating operations. All of the transcribing operations have been described in connection with the transcriber C. It is to be understood that the equipment associated with transcriber D is identical and reference to the drawings will indicate that the six sequence remembering selectors RSA', RSA'', RSA''', and RSB', RSB'' and RSB''' are available as desired along 35 with the emergency machine EAB to transcribers C and D. In a similar manner, the transcriber Y, although located at a different location and associated with a different office so that she may not transcribe material dictated by either dictator 40 A or B, has access to the three sequences dictated by dictator X and indexed by the sequence remembering selectors RSX', RSX'' and RSX'''. It will be noted that the control wires associated with the transcriber's sequence selecting equipment for transcriber Y are connected (independently of those associated with the transcribers C and D) to the sequence remembering devices RSX', RSX'', RSX''' and to the emergency record associated with dictator X, namely EX. 45

In order to aid in the summarizing and complete understanding of the operation of the machine it will be pointed out at this point the operations that may be performed and the manual operations required to accomplish these control operations by the dictating and transcribing operators.

In studying the operation of the machine from the viewpoint of a dictating operator, it will be remembered that all that a dictating operator is 50 required to do in order to place a vacant machine,

out of the plurality of machines provided, in suitable connection for operation and recording of his dictation is to remove the handset provided for his use from the cradle on which it is rested. After thus being connected to a vacant machine 5 he may record thereon his dictation merely by speaking into the microphone provided. If he wishes to have any of the material played back he may dial any number from "three" to "nine" inclusive, each of the increasing numbers from 10 "three" to "nine" representing an increasing distance back toward the forepart of his dictation from the point of last dictation.

Whenever the dictating operator, after having moved the recording and reproducing device back 15 toward the forepart of the record to reproduce material recorded thereon, wishes to cause the resumption of his dictation he may do so by merely speaking into the microphone, and he will be notified when the equipment is ready to record 20 further dictation by the reproduction of an O. K. tone. In case he discovers an error and wishes to call the same to the transcribing operator's attention he may do so by dialing "two." If during the course of a considerable sequence of dictation 25 he is required to dictate "rush" matter he may do so without interrupting his sequence of dictation by dialing "zero" and then operating on the emergency machine which is at that time connected to his control equipment in the usual manner. When he is finished with the rush dictation he may resume the original sequence of dictation 30 by dialing "zero" a second time. At the completion of the dictation he may route the same to a transcribing operator automatically by 35 "hanging-up" or placing the handset in the cradle provided. With respect to the operation of the equipment from the transcriber's viewpoint it will be seen that the transcriber is able to select any of the available sequences for transcription. In 40 the case of transcribers C and D there are six sequences provided, three for dictator A and three for dictator B. In the case of transcriber Y there are three sequences for dictator X and in the case of all three transcribers an emergency machine 45 is also available for transcription whenever it is recorded upon.

In order for the transcribing operator to choose the sequence upon which she wishes to transcribe, she removes the headset receiver from the hook 50 switch provided therefor and dials a number on the dial corresponding to the sequence desired. In the case of transcribers C and D the numbers "two" to "seven" inclusive represent respectively the sequences A' through B''', while the number 55 "eight" represents the emergency machine. The control operations on the machines are performed by the use of the three foot pedals, one in the center being provided for the stop-start operation on the machine, the right hand one for causing the recording and reproducing device to advance at high speed along the record and the left hand one for causing the recording and reproducing device to retract toward the forepart of the recording medium. Should the operator desire to hold a sequence she may be transcribing, she may do so by dialing "zero." A subsequent dialing of any of the numbers from "two" to "eight" will connect her to a corresponding sequence or emergency machine from 60 which she may transcribe material in the manner just described. Whenever she is through with the emergency transcription and wishes to return to the first sequence from which she was transcribing, a second dialing of "zero" will cause 65 70 75

this transfer back to the original sequence. Whenever she is through transcribing a particular sequence she may cause the material recorded thereon to be erased and the equipment reset for further dictation by dialing "nine." Busy tones are also provided for both the dictating and transcribing operators and an "error" or "information" tone for the use of the transcribing operator is provided as a means of pointing out to her the location of the point to which the dictating operator wishes to call her attention.

It will, therefore, be observed that we have provided a dictation system which is peculiarly flexible in its adaptation to either handle the work at relatively small cost of a small office which may not require the full time services of a stenographer or transcriber, or to provide dictation and transcription service for a relatively large office employing a great number of dictators and a great number of transcribers.

It will further be observed that we have provided a system by which a relatively small number of machines, located at a central location, is rendered available to a large number of dictators and transcribers by making any "non-busy" machines available at any time to any of the dictators or any of the transcribers.

While in the foregoing description and in the accompanying drawings we have illustrated one preferred embodiment of our invention and for simplicity in illustrating and describing the many operations which may be performed in our system we have selected for use in this disclosure the particular embodiment set forth, it will be understood by those skilled in the art that not only the mechanical arrangement of the various machine units and their component parts may be varied without departing from the spirit of our invention but that the particular switching mechanism and the particular circuit connections illustrated herein may also be varied within relatively wide limits without departing from the spirit of our invention. It is to be further understood that we do not limit ourselves to any of the details described or illustrated herein except as defined in the appended claims.

We claim:

1. In a dictation recording system, the combination of: a plurality of recording machine units, each of which includes a recording medium and a recording means for recording material for record on said recording medium; a dictator's station remote from all of said machine units and having actuating means thereat for controlling recording operations on any of said machine units when connected thereto; a selecting means responsive to operation of said actuating means for connecting said actuating means to any one of said machine units; and means for each machine unit actuated in response to the recording upon that unit of material equal to the capacity of said unit for automatically selecting any other one of said units and connecting said actuating means thereto.

2. In a dictation recording system, the combination of: a plurality of recording machine units, each of which includes a recording medium and a recording means for recording material for record on said recording medium; a dictator's station remote from all of said machine units and having actuating means thereat for controlling recording operations on any of said machine units when connected thereto; a selecting means responsive to operation of said actuating means for connecting said actuating means to any one of said machine units; means for each unit

actuated in response to the recording upon any unit of material equal to the capacity of said unit for automatically selecting any other of said units not previously selected and for connecting said actuating means thereto; and means for maintaining the connections between said actuating means and all of the selected units in the same sequence as they were selected.

3. In a dictation recording system, the combination of: a plurality of recording machine units, each of which includes a recording medium and a recording means for recording material for record on said recording medium; a dictator's station remote from all of said machine units and having actuating means thereat for controlling recording operations on any of said machine units when connected thereto; a selecting means responsive to operation of said actuating means for connecting said actuating means to any one of said machine units; means for each unit actuated in response to the recording upon any unit of material equal to the capacity of said unit for automatically selecting any other of said units not previously selected and for connecting said actuating means thereto; means for interconnecting the selected machines into a group in the same sequential order as that in which said machines are selected; and means for releasing the connection between said first named selecting means and the machines of said group, whereby subsequent actuation of said selector may start the selection of a new group.

4. In a dictation recording system, the combination of: a plurality of recording machine units, each of which includes a recording medium and a recording means for recording material for record on said recording medium; a dictator's station remote from all of said machine units and having actuating means thereat for controlling recording operations on any of said machine units when connected thereto; a selecting means responsive to operation of said actuating means for connecting said actuating means to any one of said machine units; means for each unit actuated in response to the recording upon any unit of material equal to the capacity of said unit for automatically selecting any other of said units not previously selected and for connecting said actuating means thereto; means for interconnecting the selected machines into a group in the same sequential order as that in which said machines are selected; means for releasing the connection between said first named selecting means and the machines of said group, whereby subsequent actuation of said selector may start the selection of a new group; and registering means for denoting the particular machine first selected in each group.

5. In a dictation recording system, the combination of: a plurality of recording machine units, each of which includes a recording medium and a recording means for recording material for record on said recording medium; a dictator's station remote from all of said machine units and having actuating means thereat for controlling recording operations on any of said machine units when connected thereto; a selecting means responsive to operation of said actuating means for connecting said actuating means to any one of said machine units; means for each unit actuated in response to the recording upon any unit of material equal to the capacity of said unit for automatically selecting any other of said units not previously selected and for connecting said actuating means thereto; means for

- interconnecting the selected machines into a group in the same sequential order as that in which said machines are selected; means for releasing the connection between said first named 5 selecting means and the machines of said group; means actuated by said actuating means for connecting said actuating means to a machine unit other than those previously selected, and for disconnecting said actuating means therefrom for holding said group for reconnection to 10 said actuating means; and means actuated in response to the disconnection of said actuating means from said last named unit for reconnecting said actuating means to the held group and 15 to the last selected machine in that group.
6. In a dictation recording system, the combination of: a plurality of recording and reproducing machine units, each of which includes a recording medium and translation means for recording material upon said medium and for reproducing recorded material therefrom; a dictator's station remote from all of said machine units and having dictating actuating means thereat for controlling recording operations on 20 any of said machine units when connected thereto; a selecting means responsive to operation of said dictating actuating means for connecting said dictating actuating means to any one of said machine units; means for each unit actuated in 25 response to the recording upon any unit of material equal to the capacity of said unit for automatically selecting any other of said units not previously selected and for connecting said dictating actuating means thereto; means for interconnecting the machines selected into a group in 30 the same sequential order as that in which said machines are selected; a transcribing station remote from all of said machine units and having transcribing actuating means thereat for controlling reproducing operations on any of said 35 machine units; and means for coupling said transcribing actuating means to the machine units in said group in the same sequential order as said units were selected for said dictator.
- 40 7. In a dictation recording system, the combination of: a plurality of recording and reproducing machine units, each of which includes a recording medium and translation means for recording material upon said medium and for reproducing recorded material therefrom; a dictator's station remote from all of said machine units and having dictating actuating means thereat for controlling recording operations on any of said machine units when connected thereto; a selecting means responsive to operation of said dictating actuating means for connecting said dictating actuating means to any one of said machine units; means for each unit actuated in 45 response to the recording upon any unit of material equal to the capacity of said unit for automatically selecting any other of said units not previously selected and for connecting said dictating actuating means thereto; means for interconnecting the machines selected into a group in 50 the same sequential order as that in which said machines are selected; means for releasing the connection between said first named selecting means and the machines of said group, whereby subsequent actuation of said selector may start the selection of a new group; a transcribing station remote from all of said machine units and having transcribing actuating means thereat for controlling reproducing operations on any of said 55 machine units; means actuated by said transcribing actuating means for selecting any of said group and for connecting said transcribing actuating means thereto; means thereafter sequentially coupling said transcribing actuating means to all of the machine units in the selected group in the same sequential order as said units of said group were selected for said dictator; means actuated by said transcribing actuating means for connecting said actuating means to a machine unit other than those in the selected group and for disconnecting said actuating means therefrom; means for holding the previously selected group for reconnection to said transcribing actuating means; and means actuated in response to the disconnection of said transcribing actuating means from said last named unit for reconnecting said actuating means to the held group and to the last machine in that group to which said actuating means had been connected.
- 60 8. In a dictation recording system, the combination of: a plurality of recording and reproducing machine units, each of which includes a recording medium and translation means for recording material upon said medium and for reproducing recorded material therefrom; a dictator's station remote from all of said machine units and having dictating actuating means thereat for controlling recording operations on any of said machine units when connected thereto; a selecting means responsive to operation of said dictating actuating means for connecting said dictating actuating means to any one of said machine units; means for each unit actuated in 65 response to the recording upon any unit of material equal to the capacity of said unit for automatically selecting any other of said units not previously selected and for connecting said dictating actuating means thereto; means for interconnecting the machines selected into a group in the same sequential order as that in which said machines are selected; means for releasing the connection between said first named selecting means and the machines of said group, whereby subsequent actuation of said selector may start the selection of a new group; a transcribing station remote from all of said machine units and having transcribing actuating means thereat for controlling reproducing operations on any of said machine units; means actuated by said transcribing actuating means for selecting any of said group and for connecting said transcribing actuating means thereto; means thereafter sequentially coupling said transcribing actuating means to all of the machine units in the selected group in the same sequential order as said units of said group were selected for said dictator. 70
- 75 9. In a dictation recording system, the combination of: a plurality of recording and reproducing machine units, each of which includes a recording medium and translation means for recording material upon said medium and for reproducing recorded material therefrom; a dictator's station remote from all of said machine units and having dictating actuating means thereat for controlling recording operations on any of said machine units when connected thereto; a selecting means responsive to operation of said dictating actuating means for connecting said dictating actuating means to any one of said machine units; means for each unit actuated in response to the recording upon any unit of material equal to the capacity of said unit for automatically selecting any other of said units not previously selected and for connecting said dictating actuating means thereto; means for interconnecting the machines selected into a

- group in the same sequential order as that in which said machines are selected; a transcribing station remote from all of said machine units and having transcribing actuating means thereat for controlling reproducing operations on any of said machine units; means for coupling said transcribing actuating means to the machine units in said group in the same sequential order as said units were selected for said dictator; 10 means on each of said machine units for erasing from the associated recording medium material recorded thereon; and means operated by said transcribing actuating means for actuating the erasing means on the units of said group.
- 15 10. In a dictation recording system, the combination of: a plurality of recording and reproducing machine units, each of which includes a recording medium and translation means for recording material upon said medium and for reproducing recorded material therefrom; a dictator's station remote from all of said machine units and having dictating actuating means thereat for controlling recording operations on any of said machine units when connected thereto; a selecting means responsive to operation of said dictating actuating means for connecting said dictating actuating means to any one of said machine units; means for each unit actuated in response to the recording upon any unit of material equal to the capacity of said unit for automatically selecting any other of said units not previously selected and for connecting said dictating actuating means thereto; means for interconnecting the machines selected into a group in the same sequential order as that in which said machines are selected; a transcribing station remote from all of said machine units and having transcribing actuating means thereat for controlling reproducing operations on any of said machine units; means for coupling said transcribing actuating means to the machine units in said group in the same sequential order as said units were selected for said dictator; means on each of said machine units for erasing from the associated recording medium material recorded thereon; and means operated by said transcribing actuating means for simultaneously actuating the erasing means on all of the units in said group.
- 20 11. In a dictation recording system, the combination of: a plurality of recording and reproducing machine units, each of which includes a recording medium and translation means for recording material upon said medium and for reproducing recorded material therefrom; a plurality of dictator's stations remote from all of said machine units and each having a dictating actuating means thereat for controlling recording operations from any of said machine units when connected thereto; a plurality of dictator's selecting means, one for each of said dictating stations responsive to operation of the associated dictating actuating means for connecting said dictating actuating means to any one of said machine units; means actuated in response to the connection of any of said dictating actuating means to any one of said machine units for preventing the selection of that machine unit by any other selecting means; machine selecting means for each machine unit actuated in response to the recording upon that unit of material equal to the capacity of said unit for automatically selecting another one of said units not previously selected and for connecting to the newly selected unit the actuating means which
- 25 30 35 40 45 50 55 60 65 70 75

had previously been connected to the unit associated with said machine selecting means; and means for interconnecting the machine selected by the dictator's selecting means and the machines subsequently selected by the machine selectors into a group in the same sequential order as that in which said machines are selected. 5

12. In a dictation recording system, the combination of: a plurality of recording and reproducing machine units, each of which includes a recording medium and translation means for recording material upon said medium and for reproducing recorded material therefrom; a plurality of dictator's stations remote from all of said machine units and each having a dictating actuating means thereat for controlling recording operations from any of said machine units when connected thereto; a plurality of dictator's selecting means, one for each of said dictating stations responsive to operation of the associated dictating actuating means for connecting said dictating actuating means to any one of said machine units; means actuated in response to the connection of any of said dictating actuating means to any one of said machine units for preventing the selection of that machine unit by any other selecting means; machine selecting means for each machine unit actuated in response to the recording upon that unit of material equal to the capacity of said unit for automatically selecting another one of said units not previously selected and for connecting to the newly selected unit the actuating means which had previously been connected to the unit associated with said machine selecting means; means for interconnecting the machine selected by the dictator's selecting means and the machines subsequently selected by the machine selectors into a group in the same sequential order as that in which said machines are selected; a plurality of transcriber's stations, each having transcribing actuating means thereat for controlling reproducing operations on any of said machine units; and transcriber's selecting means associated with each of said transcribing stations and actuated by the transcribing actuating means associated with that transcribing station for selecting any one of said groups set up by said dictating actuating means, and for connecting said transcribing actuating means to that machine of said group which was selected by the dictator's selecting means. 35 40 45 50 55 60 65 70 75

13. In a dictation recording system, the combination of: a plurality of recording and reproducing machine units, each of which includes a recording medium and translation means for recording material upon said medium and for reproducing recorded material therefrom; a plurality of dictator's stations remote from all of said machine units and each having a dictating actuating means thereat for controlling recording operations from any of said machine units when connected thereto; a plurality of dictator's selecting means, one for each of said dictating stations responsive to operation of the associated dictating actuating means for connecting said dictating actuating means to any one of said machine units; means actuated in response to the connection of any of said dictating actuating means to any one of said machine units for preventing the selection of that machine unit by any other selecting means; machine selecting means for each machine unit actuated in response to the recording upon that unit of material equal to the capacity of said unit for automatically selecting another one of said units not previously selected and for connecting to the newly selected unit the actuating means which

55 60 65 70 75

- previously selected and for connecting to the newly selected unit the actuating means which had previously been connected to the unit associated with said machine selecting means;
- 5 means for interconnecting the machine selected by the dictator's selecting means and the machines subsequently selected by the machine selectors into a group in the same sequential order as that in which said machines are selected; a
- 10 plurality of transcriber's stations, each having transcribing actuating means thereat for controlling reproducing operations on any of said machine units; transcriber's selecting means associated with each of said transcribing stations
- 15 and actuated by the transcribing actuating means associated with that transcribing station for selecting any one of said groups set up by said dictating actuating means, and for connecting said transcribing actuating means to that
- 20 machine of said group which was selected by the dictator's selecting means; and means for segregating certain of said transcriber's selecting means from selecting any of said groups of machines set up by certain selected dictator's selectors.
- 25 14. In a dictation recording system, the combination of: a plurality of recording and reproducing machine units, each of which includes a recording medium and translation means for recording material upon said medium and for reproducing recorded material therefrom; a plurality of dictator's stations remote from all of said machine units and each having a dictating actuating means thereat for controlling recording
- 30 operations from any of said machine units when connected thereto; a plurality of dictator's selecting means, one for each of said dictating stations responsive to operation of the associated dictating actuating means for connecting said
- 35 dictating actuating means to any one of said machine units; means actuated in response to the connection of any of said dictating actuating means to any one of said machine units for preventing the selection of that machine unit by any
- 40 other selecting means; machine selecting means for each machine unit actuated in response to the recording upon that unit of material equal to the capacity of said unit for automatically selecting another one of said units not previously
- 45 selected and for connecting to the newly selected unit the actuating means which had previously been connected to the unit associated with said machine selecting means; means for interconnecting the machine selected by the dictator's
- 50 selecting means and the machines subsequently selected by the machine selectors into a group in the same sequential order as that in which said machines are selected; a plurality of transcriber's stations, each having transcribing actuating
- 55 means thereat for controlling reproducing operations on any of said machine units; transcriber's selecting means associated with each of said transcribing stations and actuated by the transcribing actuating means associated with that
- 60 transcribing station for selecting any one of said groups set up by said dictating actuating means, and for connecting said transcribing actuating means to that machine of said group which was selected by the dictator's selecting
- 65 means; and means actuated in response to the connection of any one of said transcriber's selecting means to any one of said groups for preventing the subsequent connection of another transcriber's selecting means to that group.
- 70 75 15. In a dictation recording and reproducing
- system, the combination of: a plurality of recording and reproducing machine units, each of which includes a recording medium; translation means for recording material upon said medium and for reproducing recorded material therefrom; means for producing relative advancing motion between said translation means and said recording medium toward one end of said recording medium; dictating actuating means for controlling recording operations on any of said machine units when connected thereto; means connecting said dictating actuating means to one of said machine units; means actuated in response to the relative approach of said translation means into close proximity with the end of the recording medium on that machine for connecting the dictating actuating means to another of said machine units; and means actuated in response to the arrival of the translation means on said first named machine unit to the end of its recording medium for starting recording operations upon the second of said machine units, whereby dual recording of dictated material on both of said units is avoided.
16. In a dictation machine, the combination of: a recording medium; recording means operable to record material upon said recording medium; means for moving said recording means in an advancing direction relative to said recording medium while recording said material, and for retracting; means operated in response to a retracting movement of said recording means for measuring the amount of said retracting movement along said recording medium; means actuated by said measuring means for locking said recording means against recording; and means actuated in response to the re-arrival of said recording means at the point of farthest advance for releasing said locking means.
17. In a dictating machine, the combination of: a recording medium; a translation means for performing normal recording and reproducing operations upon said recording medium; means for advancing said translation means and said recording medium relative to each other and for retracting; control means for selectively rendering said translation means operative and non-operative to perform said operations; means for measuring the displacement of said translation means from any point along said recording medium at which the normal translation operations are interrupted by said control means for purposes of play-back of material upon some other portion of said recording medium, said means being stationary during normal operations of said translation means; and means actuated in response to movement of said translation means away from said point for thereafter continuously imparting movement to said measuring means proportional to the amount of the displacement of said translation means away from said point of interruption.
18. In a dictating machine, the combination of: a recording medium; a translation means for performing normal recording and reproducing operations upon said recording medium; means for advancing said translation means and said recording medium relative to each other and for retracting; control means for selectively rendering said translation means operative and non-operative to perform said operations; means for measuring the displacement of said translation means from any point along said recording medium at which the normal translation operations are interrupted by said control means for pur-

poses of play-back of material upon some other portion of said recording medium, said means being stationary during normal operations of said translation means; means actuated in response to movement of said translation means away from said point for thereafter continuously imparting movement to said measuring means proportional to the amount of the displacement of said translation means away from said point of interruption; means under the control of a dictator or transcriber for causing said translation means to perform reproducing operations while said translation means is displaced from said point of interruption and for stopping said play-back operations; and means actuated in response to the stopping of said play-back operations and controlled by said measuring means for automatically returning said translation means through the remaining distance then defined by said measuring device between the then position of the translation means and the point of interruption.

19. In a dictating machine, the combination of: a recording medium; a translation means for performing normal recording and reproducing operations upon said recording medium; means for advancing said translation means and said recording medium relative to each other and for retracting; control means for selectively rendering said translation means operative and non-operative to perform said operations; means for measuring the displacement of said translation means from any point along said recording medium at which the normal translation operations are interrupted by said control means for purposes of play-back of material upon some other portion of said recording medium, said means being stationary during normal operations of said translation means; means actuated in response to movement of said translation means away from said point for thereafter continuously imparting movement to said measuring means proportional to the amount of the displacement of said translation means away from said point of interruption; means under the control of a dictator or transcriber for causing said translation means to perform reproducing operations while said translation means is displaced from said point of interruption and for stopping said play-back operations; and voice actuated means in response to the resumption of dictation by a dictator and under the control of said measuring means for automatically returning said translation means through the remaining distance then defined by said measuring device between the then position of the translation means and the point of interruption.

20. In a dictating machine, the combination of: a recording medium; a translation means for performing normal recording and reproducing operations upon said recording medium; means for advancing said translation means and said recording medium relative to each other and for retracting; control means for selectively rendering said translation means operative and non-operative to perform said operations; means for measuring the displacement of said translation means from any point along said recording medium at which the normal translation operations are interrupted by said control means for purposes of play-back of material upon some other portion of said recording medium, said means being stationary during normal operations of said translation means; means actuated in response to movement of said translation means away from said point for thereafter continuously imparting movement to said measuring means proportional to the amount of the displacement of said translation means away from said point of interruption; means under the control of a dictator or transcriber for causing said translation means to perform reproducing operations while said translation means is displaced from said point of interruption and for stopping said play-back operations; and voice actuated means in response to the resumption of dictation by a dictator and under the control of said measuring means for automatically returning said translation means through the remaining distance then defined by said measuring device between the then position of the translation means and the point of interruption.

away from said point for thereafter continuously imparting movement to said measuring means proportional to the amount of the displacement of said translation means away from said point of interruption; means under the control of a dictator or transcriber for causing said translation means to perform reproducing operations while said translation means is displaced from said point of interruption and for stopping said play-back operations; voice actuated means in response to the resumption of dictation by a dictator and under the control of said measuring means for automatically returning said translation means through the remaining distance then defined by said measuring device between the then position of the translation means and the point of interruption; and means actuated in response to the re-arrival of said translation means at the point of interruption for producing a signal for the dictator indicating said re-arrival.

21. In a dictating system, the combination of: an operator's station; control means at said operator's station; a dictating machine remote from said operator's station and including a recording medium, a translation means for performing normal recording and reproducing operations upon said recording medium, means for advancing said translation means and said recording medium relative to each other and for retracting; means actuated by said operator's control means for rendering said translation means operative and non-operative to perform said operations; means for measuring the displacement of said translation means from any point along said recording medium at which the normal translation operations are interrupted by said control means for purposes of play-back of material upon some other portion of said recording medium, said means being stationary during normal operations of said translation means; means actuated in response to movement of said translation means away from said point for thereafter continuously imparting movement to said measuring means proportional to the amount of the displacement of said translation means away from said point of interruption; means for connecting said operator's control means to said translation means and for disconnecting the same therefrom; and means actuated in response to disconnection of said operator's control means from said translation means for causing said advancing and retracting means to return the translation means to the beginning of said recording medium and for maintaining said measuring means stationary during said return movement.

22. In a dictating machine, the combination of: a rotatable magnetic recording medium having a recording surface capable of receiving a plurality of continuous and adjacent sound tracks; translation means for describing sound tracks on said recording medium; means for rotating said recording medium; magnetic erasing means for reconditioning said recording medium after material has been recorded thereon; means mounting said erasing means adjacent the surface of revolution of said recording medium, said erasing means having a pole-face directed toward said surface and which extends transversely of all of the sound tracks recorded on said recording medium; and means for simultaneously energizing said medium rotating means and said erasing means.

23. In a dictating machine, the combination of: a recording medium; a recording means for

recording material upon said recording medium; means for producing relative motion between said recording means and said recording medium to cause said recording means to describe a continuous recording path upon said recording medium; sound responsive means for transmitting undulations corresponding to said sound to said recording means for recording upon said medium; and means responsive to the existence in or absence from said recording means of said undulations for respectively starting and stopping said driving means.

24. In a dictating machine, the combination of: a recording medium; a recording means for recording material upon said recording medium; means for producing relative motion between said recording means and said recording medium to cause said recording means to describe a continuous recording path upon said recording means;

15 20 sound responsive means for transmitting undulations corresponding to said sound to said recording means for recording upon said medium; and means responsive to the existence in or absence from said recording means of said undulations originating solely at said sound responsive device for respectively starting and stopping said driving means.

25

25. In a recording system, the combination of:
a plurality of dictating machine units; a dictat-
ing station remote from all of said machine
units; selecting means for automatically select-
ing one of said machine units and connecting it
with said station; additional machine units;
means operable at will from said dictating sta-
tion for transferring the connection of said sta-
tion from said first-named units to said addi-
tional machine units and back to said first-
named units; and means for holding the connec-
tion between said selecting means and said previ-
ously selected machine unit while said station is
connected to said additional units.

26. In a dictation recording system, the combination of: a plurality of recording machine units, each of which includes a recording medium and a recording means for recording material for record on said recording medium; a dictator's station remote from all of said machine units and having actuating means thereat for controlling recording operations on any of 45 said machine units when connected thereto; a selecting means responsive to operation of said actuating means for connecting said actuating means to any one of said machine units; means for each unit actuated in response to the recording 50 upon any unit of material equal to the capacity of said unit for automatically selecting any other of said units not previously selected and for connecting said actuating means there- 55 to; means for interconnecting the selected ma- chines into a group in the same sequential order 60 as that in which said machines are selected; transfer means under the control of said actuating means for transferring the connection of said actuating means from the machines of said 65 group to a machine unit other than those previ- 70 ously selected; means responsive to operation of said transfer means for holding said group for re-connection to said actuating means; and means actuated in response to the disconnection of said actuating means from said last-named unit for re-connecting said actuating means to the held group and to the last selected machine in that group.

27. In a recording system, the combination of:
75 a plurality of recording and reproducing machine

units, each of which includes a recording medium and translation means for recording material upon said medium and for reproducing recorded material therefrom; a dictator's station remote from all of said machine units; means for automatically selecting one of said machine units and associating it with said station; control means at said dictating station for selectively controlling the selected machine to record or reproduce at will; means for back spacing said translation means of each of said units for reproducing operations; and means actuated by said control means for pre-selecting the distance through which said back spacing means will back space said translation means. 15

28. In a dictation recording system, the combination of: a plurality of recording machine units, each of which includes a recording medium and translation means for recording material upon said medium and for reproducing recorded material therefrom and including means for moving the translation means in an advancing direction relative to the recording medium and for moving in a retracting direction; a dictator's station remote from all of said machine units and having actuating means thereat for controlling recording and reproducing operations on any of said machine units when connected thereto; a selecting means responsive to operation of said actuating means for connecting said actuating means to any of said machine units; means for each unit actuated in response to the recording upon any unit of material equal to the capacity of said unit for automatically selecting any other of said units not previously selected and for connecting said actuating means thereto; means for maintaining the connections between said actuating means and all of the selected units in the same sequence as they were selected; means controlled by said actuating means for retracting the translation means on the units connected in sequence in a reverse sequential order to that in which said units were selected; and means actuated in response to operation of said actuating means to reproduce said previously recorded material for causing said translation means of said units to re-advance in said first-named sequential order. 10 20 25 30 35 40 45

29. In a dictation recording system, the combination of: a plurality of recording machine units, each of which includes a recording medium and translation means for recording material upon said medium and for reproducing recorded material therefrom and including means for moving the translation means in an advancing direction relative to the recording medium and for moving in a retracting direction; a dictator's station remote from all of said machine units and having actuating means thereat for controlling recording and reproducing operations on any of said machine units when connected thereto; a selecting means responsive to operation of said actuating means for connecting said actuating means to any of said machine units; means for each unit actuated in response to the recording upon any unit of material equal to the capacity of said unit for automatically selecting any other of said units not previously selected and for connecting said actuating means thereto; means for maintaining the connections between said actuating means and all of the selected units in the same sequence as they were selected; means controlled by said actuating means for retracting the translation means on the units connected in sequence in a reverse sequential 50 55 60 65 70 75 75

order to that in which said units were selected; means actuated in response to operation of said actuating means to reproduce said previously recorded material for causing said translation means of said units to re-advance in said first-named sequential order; and means actuated in response to operation of said actuating means to resume recording for causing the translation means of the machine unit last recorded upon to advance to the point of last recording and for

simultaneously advancing all other retracted translation means to the ends of their respective recording mediums.
